UNITED STATES PATENT OFFICE.

ALFRED S. McCASKEY, OF CHICAGO, ILLINOIS, ASSIGNOR TO McCASKEY ELECTRIC CALCULATOR CO., OF CHICAGO, ILLINOIS, A CORPORATION OF ILLINOIS.

CALCULATING-MACHINE.

1,147,957.

Specification of Letters Patent. Patented July 27, 1915.

Application filed April 20, 1910. Serial No. 556,623.

To all whom it may concern:

Be it known that I, ALFRED S. McCASKEY, a citizen of the United States, residing at Chicago, in the county of Cook and State of Illinois, have invented a new and useful Improvement in Calculating-Machines, which invention is fully set forth in the following specification.

The present invention relates to calculating machines, and particularly is an improvement in machines as described in my pending application, Serial Number 157,769, filed May 19, 1903.

Generally stated, the objects of the present invention are to provide a simplified and improved machine which is cheaper to manufacture, which is more durable and rapid in operation, and which possesses an enlarged scope of capability.

One of the features of improvement of the present machine resides in the key-board and escapement movement whereby, upon the depression of a key, the key rod is released, which latter effects instantaneously the release of a rotary escapement, the key stem being thereafter automatically and surely returned to its normal elevated position by the operation of the parts.

In the present machine, there is employed, in place of the rotary stop disk of my pending application, a carrier in the form of a cylinder which carries the rows of key stops or stop pins. The provision of this cylinder makes for a simplified machine and a more effective operation of the parts.

In machines of this class now in use, the number of columns to be printed on the page is predetermined and is invariable; and one of the objects of the present invention is to provide means whereby the operator may provide for any desired spacing on the printed page by simply rotating a ratchet spacing element which is provided with a number of series of stops, which stops are spaced at varying distances in the several lines.

In the present machine, there is also provided means whereby, in the operation of multiplication, the figures of the multiplicand and multiplier are disclosed at suitable openings in the machine.

A further improvement resides in the ink ribbon movement, certain means being provided for automatically reversing the feed of the ribbon.

A particular object of the invention resides in what is herein called the "secondary accumulator". Briefly stated, this secondary accumulator consists of a series of figure wheels with their appropriate carrying mechanisms, for the carrying of tens, said wheels being set in close proximity to the sectors of the primary figure wheels, and with the teeth of which sectors the secondary figure wheels may be engaged for the purpose of transferring numbers from time to time from the primary figure wheels to the secondary figure wheels, whereby one is enabled to carry a grand total, or a series of totals accumulated on the primary wheels, which may have resulted from adding extensions, either column or cross footing, or the grand total of all products resulting from a series of multiplications.

There is also provided by the present invention, an indicator lever which may be moved to any one of four positions corresponding to unison, sub-total, accumulator or accumulator total. When the indicator lever is so set the operation of the totalizing lever will effect the desired operation. There is associated with each of these operations of unison, sub-total, accumulator and accumulator total, an arbitrary symbol, and certain means are provided whereby, when any one of these operations is performed, said symbol is printed on the page at the number which represents said unison, sub-total, accumulator or accumulator total.

There is also provided in the present invention means for automatically effecting the vertical or cross feed of the platen. The operator determines whether the feed is to be a vertical one for column printing or a cross feed, such as is desired in cross-feeding operations, and by a simple operation, such as rotating a button, so shifts the parts that thereafter when the machine is operated the vertical or cross feed of the platen is automatically effected.

It is sometimes desirable to space the page in columns of varying widths, and if the desired spacing is different from, and cannot be effected by the hatchet spacing element heretofore referred to, an adjustable spacing bar carrying check nut stops is brought into operation. These stops may be set to any desired adjustment and the number of columns may be determined by the number of stops used, adapting the work

of the machine to the variable column spacing so often encountered in printed forms used in general business.

The foregoing sets forth but a few of the improvements of the present invention, many more of which will be pointed out in the following description and indicated in the appended claims.

The accompanying drawings, which illustrate one expression of the inventive idea, will be more fully understood by reference to the accompanying description.

In said drawings—Figure 1, Sheet 1, is a top view of the incased machine; Fig. 2, Sheet 2, is a side elevation, partly in section, of the key-board end of the machine, the left frame of the machine being removed; Fig. 3, Sheet 3, is a similar view of the intermediate parts of the machine; Fig. 4, Sheet 4, is a similar view of the upper rear part of the machine, and Fig. 5, Sheet 5, is a similar view of the lower rear part of the machine; Fig. 6, Sheet 6, is a rear end view of the cylinder carrying the stop pins; Fig. 7, Sheet 7, is a plan view of the intermediate parts of the machine, part of the top being removed; Fig. 8, Sheet 8, is a similar plan view of the rear end of the machine; Fig. 9, Sheet 9, is a front elevation of the key-board part of the machine, showing the key stems and escapement mechanism; and Fig. 9^a, Sheet 9, is a detail; Fig. 10, Sheet 10, is a plan view of the key-levers and part of the erasing and multiplication mechanism; Fig. 10^a, Sheet 10, is a section on the line $x-x$ of Fig. 10; Fig. 11, Sheet 11, is a plan view of the cam shaft and parts which effect the transmission of power; Fig. 12, Sheet 12, is an end elevation, partly in section, of the key rods and their retracting cams; Fig. 13, Sheet 12, is a side elevation, partly in section, of said key rods, a single retracting cam being shown in this figure; Fig. 14, Sheet 12, is a transverse sectional view of a key rod showing the spring-pressed foot, said view being taken on the line 14—14 of Fig. 13; Fig. 15, Sheet 12, is an elevation of a portion of the key rod showing the foot and the stop-pin; Fig. 16, Sheet 13, is a side elevation of the eraser mechanism; Fig. 17, Sheet 14, is an end view, partly in section, of the cylinder escapement wheel; Fig. 18, Sheet 14, is a longitudinal sectional view through one of the arms of the escapement wheel, the other arm illustrated being partly in elevation; Fig. 19, Sheet 14, is an end view, partly in section, of a section of the cylinder carrying the stop pins; Fig. 20, Sheet 14, is a cross-sectional view, partly in elevation, of one of the disks of the cylinder and the stop-pins carried thereby; Fig. 21, Sheet 15, is a side elevation of the figure wheel mechanism, the rack operating members being omitted; Fig. 22, Sheet 15, is a side eleva-

tion of one of the operating sectors and its associated clutch; Fig. 23, Sheet 15, is an end elevation of the same; Fig. 24, Sheet 15, is a side elevation of a figure wheel toothed member; Fig. 25, Sheet 15, is an end elevation of the same; Fig. 26, Sheet 14, is an end elevation, partly in section, of one of the spring-driven members associated with the main racks; Fig. 27, Sheet 14, is a sectional view of the same on the line $x-x$ of Fig. 26; Fig. 27^a, Sheet 23, is a side elevation, partly in section, showing details of the carrying and printing mechanism, and Fig. 27^b, Sheet 23, is a plan view of the same; Fig. 27^c, Sheet 24, is a front end view of the main racks and their associated drops; Figs. 28 and 29, Sheet 14, are, respectively, a side and end elevation of one of the cylinder rock-beams; Fig. 30, Sheet 16, is a side elevation, partly in section, showing mechanism associated with the unison and sub-total keys; and Fig. 31, Sheet 16, is an end elevation of the same; Figs. 32 and 33, Sheet 16, are details of mechanism associated with the unison and sub-total operations; Fig. 34, Sheet 17, is an elevation, partly in section, of mechanism associated with the multiplication operation; Fig. 34^a, Sheet 17, is an elevation of the multiplication-key and associated parts; Fig. 35, Sheet 17, is a sectional view of a dash-pot plunger; Figs. 36 and 37, Sheet 17, are details of part of the circuit closing mechanism; Fig. 38, Sheet 13, is an end elevation, partly in section, illustrating the cylinder stop pin releasing mechanism used in the multiplication operation; Figs. 39, 40, 41, and 42, Sheet 13, are details of the stop lever saddle used in multiplying; Fig. 42^a, Sheet 18, is a front elevation of the ribbon movement mechanism; Fig. 43, Sheet 18, is a plan view of the same; Fig. 44, Sheet 18, is a sectional detail view of part of the ribbon feeding mechanism; Fig. 45, Sheet 5, is an elevation, partly in section, of the left hand end of the ribbon feeding mechanism; Fig. 46, Sheet 5, is an elevation of the right hand end of the ribbon feeding mechanism; Fig. 47, Sheet 18, is a plan view showing the column space mechanism; Figs. 47^a and 47^b, Sheet 24, are details of said mechanism; Figs. 48 and 49, Sheet 19, are side elevations of the line spacing cams, the former being used in adding and the latter in taking totals and sub-totals; Fig. 50, Sheet 19, is a side elevation of the cam shaft retaining disk; Fig. 51, Sheet 19, is a side elevation of the cam sleeve retaining disk; Fig. 52, Sheet 19, is a side elevation of the figure-wheel clutch operating cam used in taking totals; Fig. 53, Sheet 19, is a view of the figure-wheel clutch operating cam used in registering; Fig. 54, Sheet 19, is a sectional view of the cam sleeve and cams on line 54—54 of Fig. 55; Fig. 55, Sheet 19, is an

end elevation, partly in section, showing the cam sleeve; Fig. 56, Sheet 19, is a side elevation of the cam for operating the erasing mechanism in registering; Fig. 57, Sheet 19, is a side elevation of the cam used in erasing in connection with the taking of totals and sub-totals; Fig. 58, Sheet 19, is a bottom view of the key-lock; Fig. 59, Sheet 20, is a side elevation, partly in section, of the mechanism for operating the multiplier and multiplicand indicators; Fig. 59^a, Sheet 25, is a top plan view of the factor indicator slide carriage, omitting the mounting plate; Fig. 59^b, Sheet 25, is an end elevation, partly in section, of some of the parts shown in Fig. 59^a; Fig. 60, Sheet 21, is a plan view of mechanism for indicating the multiplier and multiplicand; Fig. 61, Sheet 21, is a bottom view of the multiplicand and multiplier slide mounting plate, showing the general arrangement of springs and retaining pawls; Figs. 62 and 63, Sheet 20, are, respectively, a detail view of the multiplier slide and the multiplicand slide; Figs. 64, 65, 66 and 67, Sheet 22, are details of the printing mechanism; Fig. 68, Sheet 23, is a further detail of the printing mechanism; Fig. 69, Sheet 24, is a side elevation, partly in section, of part of the printing mechanism; Fig. 69^a, Sheet 6, is an end elevation of the printer hammer control; Fig. 70, Sheet 26, is a side elevation, partly in section, of the primary and secondary accumulating mechanism; Figs. 71 and 72, Sheet 26, are views of cams associated with the secondary accumulator mechanism; Fig. 73, Sheet 27, is a side elevation of mechanism for effecting the operations of unison, sub-total, accumulator and accumulator total, together with mechanism for printing the appropriate totalizing characters; Fig. 74, Sheet 27, is a top plan view of the indicator handle and connections to the mechanism for printing the totalizing characters shown in Fig. 73; Fig. 75, Sheet 28, is an elevation, partly in section, of the mechanism for automatically spacing the printer platen both for vertical and cross-feed movements; Fig. 76, Sheet 28, is a rear view of the same; Figs. 77 and 78, Sheet 28, are details of said mechanism; Fig. 79, Sheet 29, is a front elevation, partly in section, at the key-board end of the machine, showing means for preventing more than one key from being depressed at one time, said figure being taken on the line A—A' of Fig. 80; Fig. 80, Sheet 29, is a transverse sectional view of the mechanism shown in Fig. 79, said figure being taken on the line B—B' of Fig. 79; Figs. 81 and 82, Sheet 30, are, respectively, a front view and a top view of the sector basket; Fig. 83, Sheet 31, is a cross sectional view through clutch H, at right angles to that shown in Fig. 11; Fig. 84, Sheet 29, is a front elevation of the digit and cipher key rock bails; Fig. 85, Sheet 32, is a side view, partly in section, of the multiplication devices, and Fig. 86, Sheet 32, is a top plan view, partly in section, of the same; Fig. 87, Sheet 31, is a front view 70 of the printer carriage; Fig. 88, Sheet 31, is an end view, partly in section, showing the printer platen and paper guiding elements; Fig. 89, Sheet 31, is an end view, partly in section, showing the paper feed 75 roller frame; Fig. 90, Sheet 31, is an end view of the platen brake device; Figs. 91 and 92, Sheet 33, are, respectively, a side view and a top view of the multiplier slide retaining pawl; Fig. 93, Sheet 33, is a side 80 view of a detail of the frame-work; and Fig. 94, Sheet 33, is a top view of the same; Fig. 95, Sheet 33, is a sectional view on the line C—C' of Fig. 96, showing part of the factor indicating mechanism; and Fig. 96, 85 Sheet 33, is a rear view of said parts; Fig. 97, Sheet 34, is a front view of the secondary accumulator, and Fig. 98, Sheet 34, is a top view of certain parts of the same; Fig. 99, Sheet 34, is a top view of one complete section of the secondary accumulator; Fig. 100, Sheet 35, is a top plan view of part 90 of the secondary accumulator mechanism; Fig. 101, Sheet 35, is a plan view, partly in section, showing cam 2066 and associated 95 mechanism; Fig. 102, Sheet 36, is a side elevation, partly in section, showing part of the mechanism for determining the printing of the totalizing character elements; Fig. 103, Sheet 35, is a top plan view, partly in section, showing cam 2121 and associated parts; Fig. 104, Sheet 35, is a front elevation, partly in section, showing the printing and detail accumulation keys, and means for holding the same in their elevated and depressed positions; Fig. 105, Sheet 36, is a view, partly in section, through mechanism associated with the platen feed; Fig. 106, Sheet 36, is a view of a cross-feed spacing element; Fig. 107, Sheet 36, is an end view 110 of platen cross-feed elements; Fig. 108, Sheet 37, is an elevation of the multiplication, division and eraser keys and other associated mechanisms, and Fig. 109, Sheet 29, is a detail view of part of the subtraction 115 key mechanism; Figs. 109 and 110, Sheet 38, are details, Fig. 109, being a section on line A—A' of Fig. 110, and Fig. 110 being a plan view of part of shaft 551 and the clutch mounted thereon; Fig. 111, Sheet 38, is a cross-sectional view through part of plate 1077 which carries the multiplicand and multiplier slides, and through said slides and retaining means; and Fig. 112, Sheet 38, is a sectional view on the line 120 A—A', Fig. 43.

Key mechanism, (Sheets 1, 2, 7, 9, 10, 11, 13, 29; Figs. 1, 2, 7, 9, 10, 11, 16, 79, 80.)—
Referring to the drawings, A indicates the base of a suitable casing, the front of which 130

is indicated by A', the side frames by B, the top by B'. On the side frames B is mounted a plate 1132 (Fig. 9) through which pass digit key stems 227 provided at their upper ends with suitable key tops 229, and working in guides 230 (Fig. 2) mounted on said plate 1132. Said stems are retracted by springs 230^b (Fig. 80). Hinged to the lower extremity of stems 227, at point 235, are bell levers 236, the digit-key levers being pivoted on rod 237 mounted in brackets 238 secured to plate 1132, and the cipher key levers being pivoted on rod 237^a (Fig. 2). Pivoted to the lower extremity of said bell levers are the rams 243 retracted by springs 243' (Fig. 2), which are each connected one end to the ram 243 and the other to its corresponding bell lever 236. Upon the depression of key stem 227, ram 243 contacts with lever 291, pivoted in brackets 293 at 294. Adjacent to each lever 291 is a corresponding key rod hook 290 (Fig. 9) pivoted the same as lever 291 and carrying abutment pins 292, which, when struck by key rod hook lever 291 causes said hooks 290 to be released from the shelf edge of digit key rod guide 247 (Figs. 2 and 9) secured in the side frames of the machine. Said hook 290 and lever 291 are pressed toward guide 247 by springs 290' and 291', each spring 290' engaging a pin on hook 290 and each spring 291' engaging a pin on lever 291 (Fig. 2). Each of the brackets 293 is rigidly fixed to a lower key rod 246, working in guides 247 and 250, and being spring-pressed downwardly by spring 246^b (Fig. 9), the downward throw of each key rod being limited by head 246^c, mounted on said rod, abutting ledge 247.

At its lower extremity, at the point 337^a (Fig. 2) each key rod 246 is connected to one of a series of key levers 337^a—337^c, pivoted in bearings 337^e. Key levers 337^a to 337^c, inclusive, as shown in Figs. 7 and 10, are bent inwardly at their rear extremities in order to be under their respective stop pins carried by a cylinder C, hereafter described.

When the key rod marked with the figure 1 (Fig. 10) is depressed, it will be noticed that the rear end of key lever 337^a contacts with the rearmost stop pin of cylinder C, said pin being located in the row of said stop pins resting at the time nearest the base of the machine, which pin is number one of said row (Fig. 16). When the key stem marked with the figure 2 is depressed, the rear end of key lever 337^b contacts with the stop pin of the cylinder C adjacent to pin number one, which is pin number two. The depression of key tops 3, 4, 5, 6, 7, 8 and 9 will cause the contacting of their respective stop pins in said row. As will be hereafter shown, said carrier or cylinder C has a step by step movement, after the depression of

any key stem, the result of which is that but one of said pins in any one row is depressed by the aforesaid contacting of said key levers. Said step by step movement is brought about by the revolution of the cylinder through means of a proper propelling force tending to revolve said cylinder and an escapement operated by the depression of any key stem, which escapement normally checks the rotary movement of said cylinder, as will hereinafter be more fully described.

When any cipher key 0, 00, 000, 0000, 00000, is depressed (the key stems therefor being marked 231 in Figs. 2 and 9), the cipher key rods 246^a are tripped by means identical with those of the digit key rods 246, as shown in Fig. 2. Said cipher key-rods engage upper bearings 247^a and lower bearings 250^a (Fig. 2).

Restoring key stem movement, (Sheets 2, 9, 11 and 12; Figs. 2, 9, 11, 12, 13, 14 and 15.)—As seen in Figs. 9 and 11, shaft 149, on which cylinder C is mounted, is supported in bearings 149^a, 149^b, 149^c and 149^d, a constant force tending to rotate said shaft in the direction of the arrow (Fig. 9). As will be hereafter explained, when any digit key is depressed, the escapement is instantly operated and said shaft is rotated one-tenth of a revolution. When any cipher key is depressed, the shaft is similarly rotated one or more tenths of a revolution, depending upon the cipher key depressed. Rigidly fixed to said shaft is a bevel gear 336 (Figs. 2 and 11), meshing with bevel pinion 331, fixed to the shaft 330, suitably mounted, and carrying gear 328, meshing with intermediate gear 325, which in turn meshes with pinion 321 (Fig. 12), rigidly fixed to shaft 314, mounted in bearings 316 and 316^a (Figs. 12 and 13, Sheet 12). Fixed to said shaft 314 in any desired manner are double rotary restoring cams 309, one for each digit and cipher key. Each cam is provided with a curved flange 309^a. At the lower extremity of each key rod is a key rod foot 304 carrying a toe 305 (Figs. 12 and 13). Said foot is fixed to the pivot rod 306, said pivot rod working in the lower extremity of key rod 246 and carrying pin 306^a (Fig. 15), working in slot 306^b of the key rod 246 (Fig. 15). Said key rod feet are normally held in a spring-pressed position by springs 304^a, the movement being limited by the contact of pin 306^a against one end of the slot 306^b, as shown in Fig. 15. In this position the toes 305 take a position relative to the cams 309 as shown in Fig. 12. It will be observed that when said toes are in this position the cams 309 may rotate without contacting with them. When, however, any key rod is released the toe 305 comes in contact with the wide part of the cam 309 and within the flange 309^a. When, therefore, shaft 314 is revolved one-half of a revolution, said toe

comes in contact with flange 309^a and is carried to one side of its normal position onto the face of the cam which carries the foot 304 and also key rod 246 back to their normal position, where they are retained by hook 290, heretofore described. The mounting of cams 309 on shaft 314 in double form and the revolving of said shaft 314 one-half of a revolution is merely one expression of the inventive idea and, as herein illustrated, said shaft is made to revolve one-half of a revolution at each tenth of a revolution of the cylinder shaft 149, heretofore described.

Escapement movement, (Sheets 2, 9, 11, 14 and 29; Figs. 2, 9, 9^a, 11, 17, 18, 84.)—The escapement of the carrier or cylinder C (Fig. 2) is controlled by means of the following mechanism. A rock bail D for the digit keys comprising bar D', and end pieces D¹ and D^r, is rigidly mounted on shaft 273 pivoted in bearings 279 and D² (Figs. 2, 9, 11 and 84) and is normally retracted by a suitably-anchored spring D⁴ (Fig. 2). Said rock bail D is common to all the digit key rods 246, and is actuated therefrom through angle pieces 282, suitably secured to said rods 246, which engage rod D' of said rock bail. Formed integrally with end piece D¹ of said rock bail D, or otherwise suitably secured thereto, is an arm 274 (Figs. 2 and 9), which normally lies under tail piece 187^a of escapement hammer 187 suitably pivoted in bearing 189.

E designates the cipher rock bail, which is common to all cipher key rods 246^a, and is actuated by angle pieces 287, rigidly secured to the cipher key rods (Fig. 2). Cipher rock bail E is provided with end pieces E¹ and E^r, and also has an arm 284 (Figs. 9 and 84), which normally lies under the tail 187^a of escapement hammer 187. It is pointed out that cipher rock bail E is connected to a sleeve 285 which is mounted loosely on rock bail pivot shaft 273 (Figs. 9, 11 and 84). Shaft 273 is provided with a spring 273^x which at its right hand end abuts arm D^r of rock bail D and at its left hand end arm E^r of rock bail E. Said rock bail E is prevented from endwise movement on shaft 273 by studs 273^y and 273^z (Fig. 84) fixed to the base of the machine, between which studs projects arm 284 of bail E.

It will be readily understood that upon the release of any of the key rods the escapement hammer 187 will be thrown forward through the agency of said rock bails, elevating arms 274 and 284 into engagement with tail piece 187^a. The escapement hammer 187 is retracted by spring 187^b and is provided with a ram 192 pivoted at 193 and tensioned downwardly by spring 192^a. On the initial thrust of the ram 192 the pin 172 carried by escapement wheel F (Figs. 9, 17 and 18) is engaged thereby and dislodged from its abutment 185.

The escapement wheel F consists of a spider 170 (Fig. 17) rigidly keyed to shaft 149, and provided with a plurality, here shown as ten, escapement pins 172, radially disposed and pressed outwardly by springs 172^a. The outward movement of said pins is limited by screws 174, engaging in slot 174^a of said pins, and said pins are normally held in a depressed position by dogs 175 (Fig. 18), which are pivoted in lugs 175^a and are pressed against said pins by springs 175^b. The pins 172 are each provided with a notch 173^a for the engagement of dogs 175. Normally one of said pins 172 stands in a released position, engaging the top of abutment 185, thus preventing the rotation of cylinder shaft 149.

As before described, on the release of a digit key rod the escapement pin 172 engaging the abutment is dislodged permitting shaft 149 to rotate. Simultaneously with this movement escapement pin 172' is released and the spider 170 will turn one-tenth of a revolution, when it will be held from movement by said pin 172' engaging the abutment 185. This pin 172' is released by escapement-pin hammer 260 (Figs. 2 and 9) which is provided with a collar 260^b mounted on shaft 260^c, striking the tail of detent 175 (Figs. 2 and 18), said hammer 260 being actuated from digit rock bail D, through an intermediate lever 268 (Fig. 2) pivoted in a bearing 270. Said escapement pin 172' is also operated by the release of the single cipher key rod 246^a, through an intermediate lever 260^a, rigidly fixed to hammer 260, by engagement with an angle piece 288, pinned rigidly to said key rod 246^a. It will thus be seen that the actuation of any digit key-rod 246, and the actuation of the single cipher key-rod 246^a releases the escapement pin 172' and causes the cylinder to revolve one-tenth of a revolution, and that the depression of pin 172 and the release of pin 172' are simultaneous.

Upon the release of the key rod 246^a of the 00 cipher key, the escapement pin 172^a is released simultaneously with the dislodgement of pin 172, through the operation of escapement-pin hammer 261, and intermediate lever 261^a loosely pivoted on shaft 260^c and connected to hammer 261, angle piece 288 fixed to said cipher key-rod engaging said lever 261^a. Hammer 261 and lever 261^a are rigidly connected and are likewise provided with a collar 260^b (Fig. 9). Indeed, each of these cipher levers is connected to a collar 260^b, which acts as a bearing and also to space said levers and hammers. Upon the release of escapement pin 172^a and the dislodgment of pin 172, the cylinder will escape two-tenths of a revolution. In a similar manner, the escapement of three-tenths, four-tenths and five-tenths of a revolution is effected by the depression of the corre-

sponding cipher keys operating their respective escapement hammers 261^x, 261^y, 261^z (Fig. 9). It will be understood that by the designating numbers 172, 172', 172², etc., is meant the relative positions of the escapement pins with reference to the common starting point 172, where any pin rests on the abutment 185.

The abutment 185 is mounted on a dash-pot plunger 183 (Fig. 9^a), and engages the outer end of the last dislodged escapement pin in a saddle-shaped depression 185^a. Said plunger 183 working in dash-pot 177, which latter is fastened to the base of the machine, is thrown upward upon the dislodgment of pin 172 by a spring-pressed bell lever 194 (Fig. 9) pivoted at 194^a in bearing 195, engaging said dash-pot plunger at 183^b (Fig. 9^a) of the cored cavity 183^c of said plunger. Said upward movement is limited by pin 183^a carried by the plunger and working in a slot 177^c in dash-pot 177. A ball valve 177^a engages seat 177^b, in the bottom of the dash-pot and is operable to admit air on the upward movement of plunger 183. Accordingly an air cushion is formed which resists the force of the escapement pins 172' etc., striking the abutment 185.

Key-lock, (Sheets 2, 9, 19 and 29; Figs. 2, 9, 9^a, 58, 79 and 80).—It is highly desirable that, when a key has been depressed and the cylinder is rotating, the other keys should be locked to prevent the same or the register bar 471 (hereafter described) from being operated while the cylinder is in motion. This key lock is especially useful in case the successive striking of the keys is more rapid than the cylinder escapement, which is not likely to be the case while operating the digit keys and the first cipher key, but is useful while operating the multiple cipher keys, and where the operation of multiplication takes place before the retraction of the key rods or the escapement of the cylinder, which will be hereinafter described.

The means hereinafter shown for effecting the locking of the keys is a slide 223 (Figs. 2, 9 and 58) which is provided with notches 223^a, which slide reciprocates in guide rollers 224 pivoted on key plate 1132. Said slide is moved by a lever 220 (Fig. 9) fixed to shaft 214 journaled in bracket 217, the latter being fixed to cross-bar 247. To the front end of shaft 214 is fixed a depending lever 210, which latter is under the tension of spring 210^a. A latch 199 pivoted at 200 to the end of bell crank lever 194 serves to hold the lever 210 in its normal position, said latch engaging a pin 211, carried by lever 210, and holding said lever 210 against the action of spring 210^a. Latch 199 is provided with a T-shaped member 201, pivoted at 201^a, which T-shaped member is engaged and lifted by the cipher and digit rock bail

arms 284 and 274, said elevation of the T-shaped element being simultaneous with the movement of the tail piece 187^a of the escapement hammer 187 to dislodge pin 172 from abutment 185. Said T-shaped member is downwardly spring-pressed by spring 201^b, and has a guide bearing 203. T-shaped member 201 serves to release latch 199 from pin 211 carried by lever 210, and allows the spring 210^a to throw key-lock slide 223 under pins 226 (Figs. 2 and 58) of key stems 227 and 231, which normally stand above the notches 223^a in said slide. When the slide has been so moved the depression of any other key stems than the one then depressed is prevented, as is also the depression of register bar 471 (Figs. 2 and 9), until said slide is returned to its normal position. Said register bar has a lug 223^c (Fig. 9) standing normally opposite notch 223^b (Fig. 58).

The operation of the parts associated with said locking bar 223 is as follows:—Upon depression of a key rod 246, bail D is rocked, the tail piece 187^a is rocked, and the T-shaped member 201 is elevated through the engagement therewith of arm 274, thereby raising the latch 199, which results in movement to the left of lever 210 under the influence of spring 210^a. This in turn results in the movement of locking bar 223 to the right, thereby locking in its depressed position the key depressed, and preventing all the other keys from being depressed. Simultaneous with the depression of the key stem aforesaid occurs also the release of pin 172 from its ledge 185 (as heretofore described), whereupon ledge 185 connected as heretofore stated with the dash-pot plunger, is raised by movement of bell lever 194. This movement of bell lever 194, carries latch 199 to the left in a position, when lowered, to engage pin 211 of the lever 210.

As before stated, the pin 172' of the escapement spider being released, is in a position, when the cylinder C is revolved, to engage ledge 185, carrying said ledge and dash pot parts downwardly to their normal positions. During that part of the one-tenth of a revolution of the spider, however, previous to the engagement of ledge 185, the mechanism heretofore described for automatically returning the key-rods (Fig. 12, Sheet 12) operates, the effect of which is to cause the bail D to be returned to its normal position, thus lowering the arm 274, resulting in turn in the lowering of link 201, which thus engages latch 199 with pin 211. When the pin 172', therefore, contacts with the ledge 185 and carries it downward, bell lever 194 is returned to its normal position, the latch 199 is moved to the right, carrying with it the lower end of lever 210, and the lock bar 223 is moved to the left to its normal position, unlocking the key stem previ-

ously depressed and clearing the path for the depression of a succeeding key stem.

While the lock mechanism just described is effective for preventing depression of a 5 second key until the cylinder has completed its movement in response to the depression of the first key, it will not act to prevent the simultaneous depression of two or more keys. This may, however, be effected by the 10 mechanism illustrated in Figs. 79 and 80, wherein, as shown, key stems 227 have arms 227^x, and stems 231 have arms 227^y. Arms 227^x and 227^y carry dependent points 227^z. These points are arranged in a common line 15 as shown. In Fig. 79, the points of the digit key stems are broken away. Points 227^z pass through openings in a tube 2500 which is supported in bearings 238^a and 238^b secured to plate 1132. Said tube may be adjusted in 20 its bearings and fixed therein by set screws 2501 and 2502. Within said tube are inserted steel balls 2503. The diameter of these balls is such that when contacting each other and properly placed in the tube only 25 one point 227^z in its descent may pass between two adjacent balls. In the ends of the tube 2500 are the adjusting screws 2504 and 2505. The function of said screws is to 30 adjust the balls as above indicated and leave sufficient room in the tube for the number of balls placed therein, and one of the points 227^z. It will be evident, therefore, that while one key top is depressed, another cannot be simultaneously depressed for the reason 35 that there is not room enough in the ball race for more than one point 227^z. Adjusting screws 2504 and 2505 are held in position by check screws 2506 and 2507, respectively.

Cylinder, (Sheets 2, 3, 6, 11, 13 and 14; 40 Figs. 2, 3, 6, 11, 16, 19, 20, 28, 29 and 38.)—The carrier C here shown as a cylinder, which carries the stop pins is rigidly keyed to shaft 149, said shaft being supported in brackets 149^a, 149^b, 149^c and 149^d (Fig. 11). 45 Said cylinder C is composed of a number (here shown as nine), of plates 155 and is provided with a number (here shown as ninety), stop pins 156 (Figs. 2, 3 and 19) all of similar form. These stop pins are 50 mounted radially and at an angle of thirty-six degrees from each other in grooves (as shown in Fig. 19) in the nine plates 155 (Figs. 2 and 20) which are of similar construction, and which are provided with a 55 key-way 155^x (Figs. 6 and 19), so that when said plates are mounted on the cylinder shaft the pins stand in ten radial rows, surrounding the cylinder shaft. Said plates 155 are bound together by head plates C^e and C^f, plate C^e resting against shoulder 149^s of 60 shaft 149 and plate C^f being engaged by nut 149ⁿ (Fig. 11). Each pin is independently pressed by spring 156^e against a stop lug 155^a (Figs. 19 and 20), which is their normal position, and each pin is provided with

a perforation 155^b, through which the cylinder thrust rods 46 (Fig. 3) hereinafter described, may pass when said stop pins are in their normal position. If, however, any of the stop pins are depressed, as hereinbefore described, they form stops in the paths of said cylinder thrust rods. Said pins, upon being depressed, are held in this position by a rock bar 159 (Figs. 19, 28, 29 and 38)—one being provided for each of the ten longitudinal rows of pins—which engages along its edge 159^k the noses 155^e of said stop pins. Said rock bars 159, which are pivoted at 159^e and 159^f in head plates C^e and C^f, are provided with heads 159^a, which normally 70 cover the canals formed by the holes 155^b (Figs. 6 and 19) and close the entrance for the cylinder thrust rods. If, however, a stop pin is depressed in any row, the head 75 159^a (Fig. 6) is thrown out of line with holes 155^b. This is due to the fact that said rock bars 159 are pressed toward the cylinder stop pins by springs 159^d (Fig. 6) and are swung by engagement of cam surface 80 156^x on said pins (Fig. 19) with face 159^y of said bars, the latter resting on surface 156^e of said pins when the pins are in their depressed position, thereby leaving a free passage for the thrust rods, which may enter as 85 far as the pin which has been depressed. Each of said rock bars is common to all of the stop pins in any one row. Rock bar 159 is also provided with a tail 159^b, the office 90 of which will be hereinafter described. 95

It will be understood that if the first digit key is struck, the number one stop pin, indicated in Fig. 16, will be thrown and held in a depressed position, when the cylinder will escape one-tenth of a revolution, bringing the following row of stop pins on the line of 100 operation of the key levers; and similarly if any other key is depressed its corresponding cylinder stop pin will be operated in the same manner and the cylinder automatically moved one more space. Upon the depression of a cipher key (of which, in this machine, five are used), the cylinder stop pins 105 remain unaffected with relation to each other, but the cylinder is allowed to escape from one-tenth to five-tenths of a revolution, 110 according to the cipher key depressed, as heretofore described. Hence the rows of pins on the cylinder thus undisturbed are closed to the passage of the cylinder thrust rods and will stand for ciphers in the general result. It will, therefore, be observed 115 that, by the means described, the numbers are set up on the cylinder in their regular digital order, when so struck from the keyboard. 120

Figure wheel movement, (Sheets 2, 3, 4, 5, 8, 11, 14, 15, 19, 23, 24 and 30; Figs. 2, 3, 4, 5, 8, 11, 21, 22, 23, 24, 25, 27^a, 27^b, 27^c, 81 and 82.)—The figure wheels G (Figs. 3, 8, and 21) consist of a figure rim 104 provided with

four sets of figures, from 1 to 0, equally spaced thereon, and are each riveted to a corresponding toothed member 103, shown in detail in Figs. 24 and 25, which is provided with a hub 97, and is pivoted loosely on shaft 102. Each figure wheel, of which I prefer to use ten, is accompanied by a driving sector 87 (Fig. 22), engaging the figure wheel hub 97 and held in position by hub 5 nut 98. Said sectors are permanently engaged by main racks 24 (Figs. 3, 4 and 21), which are forwardly propelled by springs 19 (Figs. 4, 26 and 27) incased in gears 15 mounted in brackets 19', which gears also 10 engage said racks 24. The retraction of racks 24 is accomplished through gears 10 (Fig. 8) mounted loosely on rack-retracting shaft 9 secured in the side frames of the machine. Said gears are each provided 15 with a lug 10^a (Fig. 8), which forms an abutment for a similar lug 10^b, on each of collars 11. Collars 11, of which one is provided for each rack, are pinned rigidly to shaft 9, and may move a complete cycle, 20 although the racks 24 may be held from forward propulsion; but if racks 24 are free for their forward movement, the lugs 10^a and gears 10 will follow the lugs 10^b of collars 11, until said racks are stopped by a 25 mechanism, hereinafter described. It should be noticed that gears 10 mesh with and act directly on gears 15. Retracting shaft 9 is given a rotary movement, gear 13 (Fig. 8) carried thereby being driven from sector 49 (Figs. 4 and 8) pivoted at 50 (Fig. 5). Connected to the lower end of sector 49 is a lever 49^b (Fig. 5), which carries roller 49^c working on cam 49^a fixed to shaft 382, hereafter described. It will be furthermore 30 noted that when racks 24 are in their normal position, lugs 10^a and 10^b, on gears 10 and collars 11, are in contact, and the latter resists the tension of the propelling springs 19. 35 Main racks 24 are provided with suitable guides 1153 (Fig. 4) and 1156 (Figs. 2 and 27^a), supported by the framework of the machine. Upon racks 24 are mounted a series of slides 25 (Figs. 3, 27^a, 27^b and 27^c), one for each rack, normally held to move 40 therewith by pawls 26 (Fig. 27^a), which are pivoted on said racks 24 at 26^c, and engage said slides 25. Riveted to slides 25 are drops or arms 34 (Fig. 24^a) provided with butts or ends 44, to which are fastened the 45 cylinder thrust rods 46 (Fig. 3), thus forming a substantially rigid connection between thrust rods 46 and racks 24. Thrust rods 46 are provided with suitable guides 47 and 48 (Figs. 3 and 11), said guides being mounted 50 on base A. A series of carrying levers 106, pivoted in bearings 107 (Figs. 2, 3, 27^a and 27^b) mounted on the framework, are provided with a suitable guide bar 112, and with suspension springs 119, anchored at 115 to bracket 115'. These levers 106 lie almost 55

above racks 24, and parallel therewith, and serve to release pawls 26 from slides 25 when they are struck on edge 107^a (Fig. 27^a) by carrying pins 96, which are rigidly attached to the figure wheels. 70

Pawls 26 each have at their rear end a detent ledge 26^d (Fig. 27^a), which engages lug 25^a of slide 25, whereby when in this position the forward movement of rack 24 with relation to slide 25, is prevented. Pawl 26 75 also carries lug 26^b, working in notch 26^c of the slide 25, which lug upon the forward movement of rack 24 with relation to slide 25 at the time of the releasing of detent ledge 26^d from lug 25^a, contacts with end 25^b 80 of notch 26^c of the slide 25, thereby limiting the movement of rack 24 with relation to slide 25 to one unit space of the figure wheel movement. Pawl 26 at its working end is pressed upwardly by spring 26^e, secured to 85 rack 24 at 26^f, and to said pawl at 26^g. This is what is termed a "carrying movement," and through it racks 24 are propelled an extra space. It will be seen that when the figure wheel stands at 0 the engaging nose 90 107^a of carrying lever 106 stands directly behind the carrying pin 96; that as each figure wheel is provided with four sets of figures, ranging from 1 to 0, four carrying pins 96 are provided, each of which is located at ninety degrees from the other, and at the same radius; also that pawls 26 are spring-pressed upwardly, by spring 26^e so that they may lock the slides 25 relative to racks 24 upon the return of racks 24 to their 95 normal position; and that to the forward end of slides 25 are secured springs 32, which always exert a pressure rearwardly on the slide with relation to the racks 24. This pressure is merely to insure the separation 100 of surface 26^d from lug 25^a in case carrying takes place simultaneously with registry. In other words, during registry, racks 24 and slides 25 are moved forward together, and pin 96 at this time is liable to strike 110 edge 107^a, under which circumstances, if it were not for spring 32, pawl 26 might not be disengaged from lug 25^a, it being understood that the full movement of one space of rack 24, with relation to slide 25, which constitutes the carrying of tens, has for its motive power the barrel spring 19, heretofore described. The first or unit rack is not provided with a slide 25, because the first figure wheel is never carried to. In this case, the 115 drop is riveted directly to said rack 24. 120

A figure wheel clutch fork 88 is slidably mounted on each sector 87 by means of slot 88^a in said fork and shoulder pin 88^b fixed to sector 87. The prongs of fork 88 are 125 guided by a recess at 97^a (Fig. 25) and said fork is provided with a tooth 91 (Figs. 22 and 23), which engages the toothed member 103 of its corresponding figure wheel. This engagement is controlled in the fol- 130

lowing manner and by the following means (Figs. 21, 81 and 82): Sectors or guides 81 are mounted on rods 2508 and 2509 which latter are mounted, as shown, in brackets 82. 5 These sectors are separated by sleeves 2510. Said brackets 82, are fixed to rods 71, and the combination of elements just described is put together in one movable frame, which is denominated the "basket." The function 10 of the basket, as above indicated, is to engage the said teeth 91 with the teeth 103 of the main figure wheels whereby the main figure wheels are connected to the racks 24. Suitable bearings 72 and 75 (Figs. 3 and 15 21) are provided for guide rods 71. Said sectors 81 are provided with a slot 81^a in which engage pins 90 carried by forks 88, said pins being free to move in a circular arc of ninety degrees or less, dependent upon 20 whether the tooth 91 is engaged with or disengaged from the figure wheel toothed member 103. This engagement of tooth 91 is effected by the upward movement of the sector basket. When the basket is elevated 25 pin 90 is engaged by the lower surface 81^b of slot 81^a. When this engagement is effected the surface 81^b forms a true circular arc of which the center of the primary figure wheels is its center. Whenever tooth 91 is 30 disengaged, the upper surface 81^c of slot 81^a is a circular arc, the center of which is the center of the primary figure wheels.

A vertical reciprocating movement is given to operating sectors 81 by means of 35 cam 60, said cam operating lever 65, shaft 67 and levers 68 which are connected to guide rods 71 by pins 71^a (Figs. 11 and 21). It will be noted that by the shape of the 40 path of the cam the clutch tooth 91 is thrown into engagement with the figure wheel during the initial movement of the cam 60 (Fig. 53), thereby connecting the sector 87 with the figure wheel, which is then rotated proportionately to the movement of the racks 45 24. It will also be noted that, in adding, the clutch tooth 91 is disengaged or again thrown to its normal position at about two-thirds of the revolution of said cam 60, which occurs after racks 24 are fully forward.

The figure wheel lock (Figs. 3, 8 and 21) consists of a toothed bar 120, bridging the upper portion of the figure wheels. It is constructed so that the teeth 120^a engage the toothed member of each of the figure wheels in their normal position. This toothed bar is supported in blocks 122, to which are pinned the guide rods 123, which telescope in the guide rods 71 of the figure wheel clutch movement. Said toothed bar 120 is pressed downwardly by springs 124, connected to brackets 125 clamped to rods 71. Said toothed bar derives its movement from the same cam 60 that operates the figure wheel clutch. It, however, moves out of engage-

ment with the figure wheel toothed member simultaneously with the engaging movement for the teeth 91. It will be noted, however, that the figure wheel lock lags slightly in disengaging with relation to the figure 70 wheel clutch movement. Because of this lag, the said telescoping joint at 123 provides against a too early disengagement of bar 120, which engagement cannot take place until shoulder 123^a (Fig. 21) strikes 75 the lower surface of block 122.

It will be seen that the carrying pins 96 (Figs. 24 and 25) project through the figure wheel toothed member and form abutments 96^a for the spring-pressed dogs 92 80 (Fig. 22), one of which is mounted on each sector 87. These dogs 92 lie directly upon their abutments 96^a, when the figure wheels stand at zero, and are brought into action in taking unison and totalizing, as will be 85 more clearly shown hereinafter.

Releasing cylinder stop pins or erasing movement, (Sheets 2, 3, 10, 11, 13, 14, 19 and 37; Figs. 2, 3, 10, 11, 16, 19, 28, 29 and 108.)—After each adding or other operation, it is necessary to release the cylinder 90 stop pins. This operation is performed by means of the following mechanism: a plunger 505 (Fig. 16), located immediately at the rear of the cylinder C, is adapted to reciprocate on shaft 149. Said plunger is provided with ten teeth, each having an inclined surface 505^a. Said teeth are so disposed that when the plunger is thrust forward, they contact with the cylinder rock bars 100 159 (Figs. 16, 19 and 28), which are then thrown back from the cylinder stop pins 156, thereby releasing any pin that may have been depressed. Plunger 505 is connected to and rotates with cylinder shaft 149 by means 105 of key 505^c, but is longitudinally movable thereon through a fork lever 503, which at its rounded end engages in groove 505^a of hub 505^b (Figs. 10 and 16), which lever is oscillated from a shaft 492, mounted in 110 bearings 493 rigidly connected to the base of the machine. An arm 499 is rigidly connected to shaft 492, and is detachably connected to connecting rod 490 through a pin 500, engaging in a notch 490^a, in said connecting rod. Connecting rod 490 is pivoted at 490^d to a lever 485, which is mounted on shaft 484, located in bearings 487 rigidly attached to the base of the machine. A cam lever 483, fixed to shaft 484, carries at 120 its upper end a cam roller 483^a, working in cams 477 and 478. The working surfaces of cam 477 are so disposed that erasing takes place at the end of the adding cycle.

In the totalizing operation, hereinafter referred to, it becomes necessary to open the cylinder, that is to say, release the cylinder stop pins, before the main racks, and with them the thrust pins 46, go forward, and to keep the cylinder open during the whole 130

operation. This is accomplished by having cam roller 483^a contact with the working surfaces of cam 478, which operation will be hereinafter explained.

5 The automatic release of the cylinder stop pins to open the cylinder is obtained by having pin 500 normally in engagement with notch 490^a of reciprocating connecting rod 490. The movement of said connecting rod 490 is transmitted to said plunger 505, through the agency of lever 499 and shaft 492 and lever 503, as above described. The plunger 505 may also be operated manually by the depression of eraser key 514 (Figs. 2 10 and 16) when it is desired to erase the number set upon the cylinder stop pins before it is printed. This key 514 at its lower end engages lever 511 (Fig. 16), also rigidly connected to shaft 492. Said eraser key 15 passes through plate 1132 (Fig. 1) and bearing 514^a, the latter being secured to the cross-tie 149^b. Said bearing 514^a is provided with a slot 514^c (Figs. 16 and 108) in which engages a pin 514^b carried by key 20 stem 514, which prevents the latter from turning. Said key is spring-pressed upwardly by spring 514^d (Fig. 16). When the eraser key 514 is depressed, the connecting rod 490 must be raised so that the pin 500 25 is movable in slot 490^b, thus rendering the plunger cams ineffective. This is attained through the angle piece 524 (Fig. 2) first acting on pin 526 of lever 526^a rigidly attached to shaft 551, to which shaft is fixed 30 lever 509 whose engaging pin 528 works in slot 490^c of connecting rod 490 (Fig. 2).

It is here pointed out that if, at the time the eraser key is operated, either the multiplication key 561 or division key 537 (hereinafter described) is in a depressed position, said operation will effect the release of said key. This is effected by the following means: Shaft 533^a mounted in the side frames of the machine (Figs. 2, 16 and 108) 40 carries a sleeve 533 which is provided with an arm 534 associated with the division key and an arm 681^a associated with the multiplication key. These arms are provided with pins 534^a and 681^c, respectively, and 45 these pins engage notches on said key stems to hold the stems in a depressed position when they have been operated. Sleeve 533 is also provided with an arm 532 and eraser key stem 514 has mounted thereon an arm 529 which carries at its free end a pin 529^a. When, now, the eraser key is depressed, pin 529^a, engaging arm 532, will cause the rotation of sleeve 533 and consequently the withdrawal of pins 534^a or 681^c from the 50 notches in multiplication key 561 or division key 537, should either be in a depressed position, thereby permitting said key to return to its normal, elevated position (as hereinafter more fully described).

55 *Adding, unison and sub-total movements,*

(Sheets 1, 2, 3, 11, 16, 17, 19, 27^a, 32 and 37; Figs. 1, 2, 3, 11, 16, 23, 30-34, 54, 85, 86 and 108.)—In the adding movement the cylinder rock beams 159 adjacent to such cylinder pins as have been depressed, permit forward movement of thrust rods 46, and, accordingly, forward movement of corresponding racks 24. In order to connect said racks 24 with the figure wheels, the "basket" composed of sectors 81, of which 70 there is one for each figure wheel, as heretofore described, must be raised, carrying therewith clutch forks 88, thus connecting said figure wheels and sectors by means of clutch teeth 91. As heretofore stated, these 80 sectors which move together are raised by means of upright rods 71 through rocking lever 68 pivoted on shaft 67. To shaft 67 is fixed the lever 65 carrying cam roller 65^a working in cam 60, which is the adding cam. 85 As before indicated, the rise and fall of said cam 60 is so timed as to raise the sectors at the beginning of the cam shaft revolution, thereby engaging clutch teeth 91 aforesaid with the figure wheels, which results in the 90 turning of the figure wheels for adding when the racks 24 move forward. It is noted that thirty degrees of the revolution of the cam shaft is given to said raising of the sector basket, and the succeeding ninety degrees 95 following this is given to the forward movement of the racks; the ninety degrees following the forward movement of the racks is given to the carrying of tens, as hereinbefore explained. Thereafter thirty 100 degrees is given to the lowering of the sector basket, thereby disengaging clutch teeth 91 from the teeth of the figure wheels. The lowering of the basket engages the lock 120 with the figure wheels and locks the latter 105 in their forward position. Following the lowering of the basket, ninety degrees is given for the return movement of the racks. The remaining thirty degrees of the cam 110 shaft revolution is given to the automatic eraser movement, which is accomplished through link 490 and cam 477.

The office of the unison key is to clear the accumulator wheels by turning the same back to zero, and, accordingly, it is necessary to prevent engagement of teeth 91 with the figure wheels upon the forward movement of the racks. The engagement of the teeth 91 with the figure wheels must take place after the racks have gone forward, so 115 that the figure wheels may be returned to their unison or zero position when the racks move back to their normal position. A unison key 667 (Figs. 11 and 30) is provided, which key is mounted in a bracket 671, and 120 is spring-pressed upwardly by a spring 667^a. This key is provided with an angle piece 675 suitably secured thereto (Fig. 31), and said key is held against rotation by a guide pin 125 674 carried thereby engaging in a slot 674^a 130

in bracket 671 (Figs. 30, 93 and 94). Upon the depression of the unison key, said angle piece engages a pin 691 carried by lever 689, which latter is fixed on shaft 685, and said shaft is journaled in bearings 686 mounted on the right frame of the machine. Said shaft 685 has a lever 692 rigidly secured thereto, which lever is connected to a second lever 698 by means of pin 698^a (Fig. 31) working in a slot in the end of lever 698. This latter is carried by shaft 694 which is mounted in bearings 695 secured to the base A. Said shaft is provided with a fork 701 which engages at points 701^a a groove of cam sleeve 473 slidably mounted on main cam shaft 382 and retracted by spring 694^a suitably anchored at one end and at its other end connected to lever 694^b fixed to shaft 685 (Fig. 11). Said cam sleeve carries the cams 60 and 61 of the figure wheel clutch movement, cams 477 and 478 of the eraser movement, cams 937 and 938 of the line space movement, hereinafter described, and a cam sleeve retaining disk 725 (Figs. 11, 51 and 54). Said cam shaft 382 is provided with a key 382^a (Fig. 54), which engages a keyway in sleeve 473. Said cams are provided with suitable keys 382^x, and are spaced by sleeve 473^a and securely held together by sleeve nut 473^b and shoulder 473^c. A guide 726, secured rigidly to the base A, lies directly below retaining disk 725 (Figs. 54 and 55) and is provided with lugs 726^a and 726^b. These lugs are raised higher than the periphery of retaining disk 725, and normally are in alinement with a notch 725^a in said disk, so that the cam sleeve may slide upon shaft 382 without obstruction when said shaft is in its normal position.

40 By the mechanism just described, upon the depression of the unison key 667, the cam sleeve is shifted to the limit of its throw, so that the retaining disk 725 is just past the second lug of guide 726, and cam roller 65^a is brought into engagement with cam 61, and cam roller 483^a into engagement with cam 478. The cam sleeve is then rotated by mechanism, hereinafter described, and cannot be returned to its normal position until the cycle of operation is completed, when the notch 725^a is again in alinement with lug 726^a and 726^b on the guide 726.

50 Since it is necessary to measure the value of the numbers shown upon the figure wheels, if it is desired to print the total (which may be effected by depressing the printer key, hereinafter described, before the unison key is depressed), and since it is necessary to revolve said figure wheels in a reverse direction to that which takes place during the adding operation, the clutch teeth 91 must not be engaged with the teeth on the forward movement of the racks. Therefore, the sector basket must not be raised, and the lock 120 remains in engagement

with said figure wheels during the forward movement of the racks. The sectors 87, however, being in mesh with racks 24 will be carried forward to a point limited by the following means: On the side of each sector 70 87 is fixed a unison pawl 92 which moves forward until its end abuts the unison pins 96^a, thereby measuring the value of the forward movement of the rack engaging its respective figure wheel. The rise and fall of 75 the rack cam 61 is therefore so disposed as to hold the sector basket in its lowered position until the racks are fully forward, as stated, and the unison dogs 92 have contacted the unison pins 96^a. When this has 80 taken place, cam 61 raises sectors 81, thereby engaging clutch teeth 91 with their respective figure wheels, and simultaneously disengaging figure wheel lock 120. The basket is so held in its raised position during the 85 backward movement of the racks, resulting in the turning of the figure wheels in a reverse direction from that of adding, and thus bringing them back to zero.

The depression of the unison key, resulting in the shifting of cam sleeve 473, also results in the disengagement of cam roller 483^a from cam 477, and brings said roller into engagement with cam 478 (Fig. 57). The rise and fall of this latter cam is so 90 disposed that the opening up of the cylinder through the medium of rod 490, and the means heretofore described, takes place before the forward movement of the racks. This operation is not strictly an erasing operation,—since it is only made in this case to permit forward movement of the racks for all the figure wheels not standing at zero until the unison pawls on the sectors strike the unison pins on the figure wheels, and 100 occurs at the beginning of the revolution of the cam shaft; whereas, in the adding operation, the opening up of the cylinder took place at the end of the revolution of the cam shaft for the purpose of erasing. 105

If it is desired to print the total which has been indicated by the position of the figure wheels, and measured by the movement of the sectors 87 in the reverse direction in this unison operation, this may be 115 effected by depressing the printer key 729, hereinafter described, previous to the depression of the unison key. 110

If it is desired to take a sub-total, that is, to print or record at the foot of a column 120 the number represented on the figure wheels without disturbing said figure wheels, this object may be attained by the depression of the sub-total key 668, the printer key, hereinafter described, being previously depressed. This sub-total key 668 is, like the unison key 667, mounted in bracket 671, and is also provided with an angle piece 675. It is pressed upwardly by spring 668^a and acts upon cam sleeve 473 through the same 125 130

mechanism as described in connection with the operation of the unison key, but does not move the cam sleeve as far as it was moved during the unison operation, said cam sleeve taking an intermediate position so that the retaining disk 725 (Figs. 11 and 55) rotates between the two lugs of guide 726. In this position cam roller 65^a is disengaged from both cams 60 and 61, as the result of which, during the while operation, the sector basket 81 will not be elevated to engage teeth 91 with the figure wheels, and, accordingly, the figure wheels will remain undisturbed and engaged by the lock 120. This shifting of the cam shaft moves cam roller 482^a into engagement with cam 478, thereby operating the eraser bar 490 for the purpose of opening up the cylinder in the same manner as described in connection with the unison operation. Upon the forward movement of the racks 24 the unison dogs 92 abut unison pins 96^a, thus measuring the value of the number set up on the figure wheels. Inasmuch as the printer key has previously been depressed, and inasmuch as the type-bars are advanced in their various positions corresponding with the movement of the racks 24, as hereinafter described, the number represented upon the figure wheels will be printed. After this the racks 24 return to their normal position and the number shown upon the figure wheels remains thereon undisturbed, inasmuch as the figure wheels have not been moved during this operation. The printing takes place just after the pawls 92 have abutted unison pins 96^a, and upon the return movement of the racks 24, sectors 87 meshing therewith are, of course, brought back to their starting position.

Should the multiplier or division key be in a depressed position at the time of the depression of either the unison or the sub-total key, it is immediately released through the movement of slide bar 681 (Figs. 30 and 34) carrying a pin 681^b which engages the edge of lever 681^a, rigidly attached to rotating sleeve 533 (Fig. 34). Said lever 681^a carries a pin 681^c, which engages a notch 681^d (Fig. 34^a) on the multiplication key when the latter is in its depressed position. Accordingly, when lever 681^a is swung by reason of the engagement therewith of pin 681^b, pin 681^c is removed from notch 681^d, and multiplication key 561, accordingly, assumes its elevated position. Said arm 681 is slidably mounted in bracket 671 and is provided with inclined surfaces 674^b which are engaged by pin 674 on the unison and sub-total keys, so that said arm 681 is moved whenever either the unison or sub-total key is depressed. Similar mechanism effects the same result if the division key is in a depressed position, pin 534^c carried by arm 534 being removed from the notch in the

division key 537 (Fig. 108) when the unison 65 or sub-total key is operated.

The automatic release of the multiplication and division keys, just described, is necessary in case of the depression of the unison or sub-total key, for the reason that, 70 as will hereinafter more fully appear, by the depression of the multiplication or division key the forward end of lever 509 (Fig. 2) is raised, thereby rendering the automatic eraser link 490 inoperative; and 75 it is necessary that said link should be operative for unison or sub-total operations, which object will be accomplished by restoring the multiplication or division keys to their normal positions. 80

In the operation of addition, the cam shaft 382 is tripped by the register bar 471, as hereinafter described under the heading "Driving movement and trip." The means for tripping the cam shaft 382 for both the 85 sub-total and unison keys is the same, and is as follows: At the end of the movement of the unison key 667, for example, the lower end thereof engages a T-shaped member 703 guided in brackets 671 and 705 (Figs. 30 90 and 31),—a pin 703^a, (Fig. 85) on bracket 705 engaging a stop in said member—which member 703 is provided with a spring-pressed trigger 708, which engages a pawl 437 (Figs. 30 and 37), the operation of 95 which releases the cam shaft, as will be hereinafter described.

The depression of either the unison or sub-total key also acts to disengage dog 713 (Figs. 2, 27^a, 30 and 32) from slide 25 of the 100 tenth rack 24 pivoted on bearing 1156 (Figs. 2, 3, 27^a and 32). This is accomplished by a bell crank lever 719 (Fig. 32) which actuates said dog and which is connected to rod 721. This rod 721 is in turn connected to 105 lever 723 mounted rigidly on shaft 685 (Figs. 11, 27^a, 30, 31 and 32). The reason for this is that the tenth rack is not provided with a thrust rod 46, as are the other racks, because the tenth wheel is only turned 110 for the carrying of tens in the adding operation; but said rack is provided with a slide 25 (Fig. 27^a). Dog 721 prevents said tenth rack from moving forward except when the unison or sub-total key is depressed to remove said dog from engagement with said racks; but, in the unison or sub-total movement, the tenth rack must be permitted to move forward until the unison pawl on the tenth sector strikes the unison pin on the tenth wheel so that the value on said wheel may be measured. 115

It will be noted that while the cam sleeve is being shifted from one position to another, cam lever 65 must be held from movement in order that the various cam rollers on the cam sleeve may be in proper position for shifting. This is effected by a slide α , 125

operated from lever *b*, mounted on shaft 694, a rod *c* connecting slide *a* and lever *b* (Figs. 11, 30 and 33). A suitable guide *d*, secured rigidly to the base *A*, is provided for slide *a*. Lever *e* is rigidly attached to shaft 67 and the free end thereof projects into the cavity *f* in slide *a*. Said cavity is contracted in its intermediate position, and elongated at either end, so as to allow the lever *e* to 10 operate at each end of its movement (which is derived from shaft 694) and to hold the same stationary in its intermediate position, thus preventing sectors 81 from changing their position while the cam sleeve is being 15 shifted.

In Figs. 11, 50 and 59, I have shown a retaining disk 476^a, which is keyed rigidly to shaft 382 and provided with a projection 476^b, which normally lies directly below said 20 shaft and is engaged by a pawl 477^a, pivoted in bearing 477^b, and spring-pressed against said disk. Shaft 382 is held from rotation in the sense shown by the arrow (Fig. 50) by a dash-pot 413, and in a reverse direction 25 by the pawl 477^a. These elements hold the cam shaft in a definite position so that the cams on sleeve 473 may shift to their respective positions in taking totals and sub-totals, that is, so that the notch in disk 725 will 30 register with the lugs in disk guide 726 (Figs. 51, 54 and 55).

Driving movement and trip. (Sheets 2, 3, 5, 8, 11, 16, 17, 27 and 31; Figs. 2, 3, 8, 11, 30, 34, 35, 36, 37, 73 and 83.)—Any suitable 35 or preferred form of motor 338 is provided to furnish power which is transmitted from motor-shaft 338^a to a constantly running shaft 349 through a train of gears 339, 341 and 347. (Figs. 5, 8 and 11.) Shaft 349 is 40 mounted in suitable bearings 350 and arranged parallel thereto is a shaft 127 journaled in bearing 132, said shaft being driven through gears 128 and 129 from shaft 349. Shaft 127 is provided with bevel gear 135, 45 which meshes with bevel gear 137 forming part of clutch *H* and loosely mounted on shaft 149. The driven part of clutch *H*, mounted upon the rear end of cylinder shaft 149 consists of a shell 143 (Figs. 11 and 83) 50 keyed rigidly to said shaft, and is frictionally engaged by shoes 138, here shown as two, having suitable friction surfaces 139. Said shoes are provided with driving pins 141 (Fig. 83) which engage forks 137^a, these 55 latter being a part of bevel gear 137. Shoes 138 are pressed outwardly by springs 142 and constantly turn while gear 137 is in motion. It will readily be seen that a yielding source of power is applied to the cylinder shaft 149 through the aforesaid friction surfaces. The shell only turns to rotate shaft 149 upon the release of the cylinder escapement, heretofore described.

On the end of shaft 349 there is mounted

a magnetic clutch member *I*, adapted to instantaneously arrest and release the power from said shaft for driving the main cam shaft 382. This member comprises an armature 355, which carries a gear 356, and is mounted loosely upon shaft 349 (Fig. 11). 65 A shell or pole piece 361 and core 359 are pinned rigidly to shaft 349 and constantly rotate therewith. Said shell 361 incases a spool 362, provided with suitable winding 362^a, the terminals of which are connected to 70 two commutator rings 365, mounted on and insulated from the core 359. A pair of spring-pressed carbon brushes 369, provided with suitable brush holders 371, insulated from each other, serve to transmit electrical 75 energy through the winding 362^a upon the closing of the circuit, which takes place upon the release of the trip pawl 437 (Figs. 34 and 36), the operation of which is herein-after described. Armature 355 is connected 80 to shaft 382, through a train of gears 356, 377, 378 and 381, the latter of which is keyed rigidly to said shaft 382. Gears 377 and 378 being intermediate gears are mounted on an 85 idle stud 379.

A sleeve 383 is fixed rigidly to shaft 382, and has keyed thereto a trip claw 388 and a trip retracting cam 387 (Figs. 11 and 34). Also there is rotatively mounted on said sleeve 383 a multiple lever member 389, pivoted to which at 390^a is a trip pawl 390. Said member is also connected at 413^a to a dash-pot 413, which serves as a cushion at the completion of the cam shaft movement and which is provided with a head 424 having a needle valve 425 for adjusting the tension of the cushion. Said dash-pot contains a ball valve 418 for the admission of air and is also provided with a plunger 413^b (shown in detail in Fig. 35), which is 100 connected to the member 389 at 413^a (Figs. 34, 35 and 36). An arm 389^a of said member is connected to slide 393 which is movable to close an electric circuit through the winding of clutch member *I*, and which is 105 reciprocally operative in guide 394 secured rigidly to the base *A*. Said slide 393 carries a contact 398, which is insulated from said slide 393 (Figs. 36 and 37) and is adapted to engage terminals 401. Lever 389^a is also 110 connected to one end of a spring 411, which latter is anchored to the base of the machine. This spring tends to rotate the shaft 382 in a direction opposite to that of its normal rotation through the medium of trip 115 pawl 390 and claw 388 as will be seen herein-after, but its energy is resisted by the engagement of pawl 477^a and disk 476^a (Fig. 50) herein-after described. When, however, pawl 390 is disengaged from the claw 388, 120 the member 389 will immediately rotate, displace the dash-pot plunger and throw the contact 398 between the terminals 401, which 125

are normally insulated from each other and are connected to a suitable source of electrical energy (not shown). When the circuit is thus closed the armature 355 will be instantaneously attracted to the pole piece 361 and thus caused to rotate therewith, whereby movement will be imparted to cam shaft 382 through means heretofore described. When pawl 390 is again thrown into the path of the claw 388, the member 389 will be returned to its normal position against the tension of spring 411 and the contact will be disengaged from the terminals 401, thus opening the circuit of the magnetic clutch. Thus the armature is released and the cam shaft 382 is thrown out of action and into its normal position.

The disengaging of the pawl 390 from claw 388 is effected by means of the connecting rod 406, suitably supported and guided at its forked end in the recess 383^a (Fig. 11) between the trip claw 388 and the retracting cam 387. This connecting rod is also under tension toward said cams by spring 406^c, and is provided with two screws or pins 406^a (Fig. 34), between which the tail of trip pawl 390 is always located. Said rod 406 is held normally in position by spring-pressed trip pawl 437 (Figs. 34 and 73) which is pivoted at 437^a in the head 431 of said connecting rod 406 and engages a ratchet wheel 439 held normally stationary in the process of adding by means hereafter described, said ratchet wheel 439 being pinned rigidly to shaft 441. When pawl 437 is released from ratchet wheel 439, the connecting rod 406 is thrust rearward by reason of spring 406^c, and disengages pawl 390 from claw 388. The clutch member I being then thrown into action as before explained, the cam 387 will rotate and engage roller 407 mounted on connecting rod 406 (Fig. 34) and return said connecting rod to its normal position, that is in a position to reengage the pawl 437 with the ratchet wheel 439. When the connecting rod 406 is in its normal position the tail of trip pawl 390 describes an arc of a circle of which the center of shaft 382 is its center. This is the normal position of said pawl with relation to the member 389, and the hook of said pawl is in position to catch the claw 388 near the completion of the revolution of shaft 382. The releasing of pawl 437 in the process of adding, subtracting and dividing, is accomplished by means of trigger hammer 451 (Figs. 34 and 73) spring-pressed downwardly by spring 451^b and provided with an engaging pin 451^a which, when the hammer 451 is thrust rearward, rides over a spring-pressed pawl 447, pivoted in bracket 444, and drops upon the end of trip pawl 437, striking a blow of sufficient force to release said pawl 437 from its engaging ratchet wheel 439. The hammer

immediately clears said trip pawl 437 and is returned to its normal position, the pin 451^a passing under pawl 447 and engaging and riding up incline 444^a of the bracket. A slotted guide 453 (Fig. 73) is provided on trigger bracket 444 for said hammer. Hammer 451 is thrust rearward manually, it being pivotally connected at 464^a (Fig. 34) to the lever 464, which is connected rigidly to shaft 533^a on which registering bar bail 471 is mounted. This bail is retracted to its normal position by a spring 462^a and is locked from movement when either a digit or a cipher key is depressed, as hereinbefore described. 80

Subtraction, (Sheets 1, 2, 7 and 29; Figs. 1, 2, 7 and 109.)—The process of subtraction as carried out by this machine involves the well-known operation of adding to the minuend the complement of the subtrahend, 85 and accordingly this operation need not be further described. It is pointed out that, in Fig. 1, the complements of the various figures are indicated by the small figures under those representing the true value of the 90 keys. As will be recalled, when the minuend and subtrahend contain the same number of figures, the numeral "1" will always be carried to and appear on the next succeeding wheel to the left. If this "1" is disregarded the proper remainder will be shown upon the wheels. It will also be recalled that should the subtrahend consist of a less number of figures than the minuend, or should it be desired to show the exact remainder upon the figure wheels without superfluous figures appearing, it will be necessary to precede the setting up of the complement of the subtrahend by a plurality of numerals "9", whereby the "1" which is 95 carried to the left upon the adding of the two numbers is carried through the series of wheels, operating through the carrying mechanism to change all of said 9's to 0's, and the present mechanism is provided with 100 a tenth wheel to which a number cannot be entered directly from the cylinder, but to which numbers are added through a process of carrying tens. Since by the process of subtraction just described, one unit will be 105 added to the tenth wheel every time the number is subtracted, and since it is necessary to remove or prevent the carrying of a unit to said tenth wheel in order to make a record of the true result, it becomes necessary to 110 provide a subtraction key S (Fig. 1) provided with a stem 107^b (Figs. 2 and 109). Said key stem is mounted in a bearing 107^a carried by cross beam 107, and at its lower end is provided with a horizontal arm 107^c 115 which works in a slot in said bearing 107^a, and to which is secured one end of spring 107^e, the other end of said spring being secured to bearing 107^a. At its free end arm 107^c is provided with a lug 107^d in proxim- 120

125

130

ity to which is a notch 24^x cut into the upper edge of the tenth slide, heretofore described. It will be seen that, upon depression of subtraction key S, lug 107^a will enter 5 notch 24^x and in doing so will prevent the tenth slide 24 from reciprocating, to the end that there will be no carrying performed on the tenth wheel.

Division. (Sheets 1, 2, 3, 13, 17 and 37; 16 Figs. 1, 2, 3, 16, 34 and 108.)—The division operation, which consists of a series of repeated subtractions, is performed with the device of this application in the same way as fully set forth in my application Serial 15 Number 157,769, and need not be detailed herein. It is only necessary to point out that the function of the division key 537 (Fig. 2) is to render the eraser plunger 505 inactive. This is accomplished upon the depression of 20 said key, the lower end of which (dotted lines Fig. 2) engages lever 548, which is rigidly connected with shaft 551, to which is rigidly fixed the lever 509, which engages the connecting rod 490, by its pin 528 entering slot 490^c; so that when connecting rod 490 is reciprocated it will not affect the plunger 505 as the pin 500 is thrown out of its actuating notch 490^a, as heretofore explained, into slot 490^b. The division key 537 25 is spring-pressed upwardly or toward its normal position by spring 537^a, and is guided in key plate 1132 and guide 440. It is held in its depressed position by a detent 534 carrying a pin 534^a which enters notch 534^b 30 of the division key stem. Detent 534 also carries a pin 534^x (Fig. 108) to which is attached a spring 534^y anchored to the frame of the machine, said spring tending to keep pin 534^a in engagement with notch 534^b. 35 Said detent 534 is rigidly fixed to sleeve 533 mounted on shaft 533^a. Said key stem 537 is prevented from turning by the engagement of a pin 440^a, carried thereby, with a slot 440^b in bearing 440 (Fig. 108). The 40 multiplication key is held depressed in a similar manner by detent 681^a (Figs. 34 and 108). Said detents 534 and 681^a (Fig. 34) which retain the division and multiplication keys in their depressed position are released 45 by depressing the eraser key 514 (Fig. 16), which rotates said sleeve through pin 529^a of the arm 529 engaging the inclined surface of lever 532 (Fig. 16) fixed to sleeve 533. These keys are also released upon the 50 depression of the unison and sub-total keys, as heretofore explained. Further, the depression of the division key will release the multiplication key, if the latter has been depressed, by the rocking of sleeve 533 and the 55 consequent removal of pin 681^a from the notch in multiplication key 561 (Fig. 108), as heretofore particularly described in connection with the operation of eraser key 514. 60 It is understood that in the operation of division, as in those of addition and sub-

traction, cam-shaft 382 is tripped by means of register bar 471 (Fig. 2).

Multiplication. (Sheets 1, 2, 3, 9, 10, 11, 13, 17, 29, 32, 35, 37 and 38; Figs. 1, 2, 3, 9, 10, 10^a, 11, 16, 34-42, 84-86, 108, 109 and 110.)—The process of multiplication consists of a series of repeated additions, as fully set forth in my application Serial Number 157,769.

To carry out a process of multiplication, 75 in which the multiplier consists of a single figure, it is only necessary to set up the multiplicand on the stops and to transfer it in the usual manner, providing for as many rotations of cam shaft 382 as there are units 80 in the multiplier. The proper product will appear on the figure wheels. When the multiplier is a number consisting of two or more figures, the cam shaft is rotated as many times as there are units in the figure 85 of the multiplier in the units position, whereupon the stop cylinder is automatically advanced one step without releasing the depressed pins corresponding to the multiplicand. The cam shaft is then rotated 90 as many times as there are units in the figure in the tens position of the multiplier; and so on for as many figures in the multiplier to the capacity of the machine. The function of the multiplication key 561 (Figs. 9, 10, 95 11, 34 and 35) is to throw in and out certain mechanisms so that the machine may be operated a predetermined number of cycles by striking a digit key which corresponds to the multiplier or one of the figures thereof. 100

In multiplying, the escapement of the cylinder takes place at the end of the last cycle of the cam shaft, with the exception of multiplying by ten, or a power of ten, in which case the cam shaft remains normal and the 105 cylinder escapes in the usual manner, as in the process of adding; that is, the cipher keys simply space the cylinder. On shaft 273 (Figs. 9 and 84) which supports end pieces D^r and D^l of bail D', is mounted limiting sleeve D³ which is adapted to engage abutment D² secured to the base of the machine. Said bail is spring-pressed in its normal position by spring 273^x (Figs. 11 and 84) but when the multiplication key is depressed 110 said bail is shifted longitudinally so that arm 274 will not engage the escapement hammer tail 187^a upon the release of the digit key rod (Figs. 2 and 9). 115

The shifting is performed by means of a lever 567 (Fig. 9) pivoted on the right frame of the machine at 567^b, and having a pin 568 which is engaged by an angle piece 569 pinned rigidly to the multiplication key stem 561. The end 567^a of said lever engages the end of said rock bail pivot shaft 273, thus shifting rock bail D to the left. Further, upon the depression of the multiplication key 561 (Fig. 85), a notch at point k, in connecting link 666^b, engages the pin 120 125 130

666^a, which is a continuation of the digit rock bail rod D' (Figs. 9 and 84). This connecting link 666^b is normally held out of engagement with pin 666^a by a pin 666^c (Figs. 34 and 85) attached rigidly to the multiplication-key stem 561, and said link 666^b is hinged to a lever 666^d at 666^x. Lever 666^d is secured to shaft 666^e, journaled in bearing 666^h, screwed to the base of the machine. Said shaft 666^e also has a lever 666^k pinned thereto, said lever being provided with a forked end (Fig. 85) which engages a pin 666^m, which is attached rigidly to the T-shaped member 703 heretofore described. It will be observed that through this mechanism, if a digit key rod is released, while the multiplication-key 561 is depressed, and because of the engagement of lever 666^b with the pin 666^a, the rocking of bail D will cause the T-shaped member 703 to be depressed, the trip pawl 437 is released and the cam shaft 382 set in motion (Figs. 3 and 34), as heretofore described. Further, upon the depression of the multiplication-key 561 a pin 666^e (Figs. 10, 34, 85, 86 and 108) attached rigidly thereto, operates a lever 575, which is rigidly attached to a sleeve 577 working on shaft 551 mounted in the side frames of the machine. Sleeve 577 engages a collar 578 (Figs. 109 and 110) by means of clutch 578^a, which collar is pinned rigidly to shaft 551 by pin 551^a and which rotates therewith on the depression of the multiplication-key. Accordingly, through means of arm 509 and lever 490, heretofore described, the eraser plunger is rendered inactive, in the same manner as heretofore described in connection with the operation of the division-key. To sleeve 577 is rigidly attached by means of set screws a lever 579 (Figs. 10, 85, 86 and 108). Said lever is operable to shift a stop pin saddle 584 (Figs. 10, 38, 39 and 40), being connected thereto by a connecting link 582 at point 582^a, but it is only upon the operation of the multiplication key that the shifting of said saddle 584 is effected. This is due to the fact that clutch 578^a is cut away at 578^x (Fig. 109) and will not be engaged by collar 578 when the shaft 551 is rotated by the depression of the eraser or division key, but only upon the depression of the multiplication key. Said stop pin saddle is provided with a guide 585 (Figs. 41 and 42) mounted rigidly on the base A of the machine, flanges *g* and *h* of said guide entering slots *i* and *j* of the saddle. Upon said stop lever saddle are mounted a series of eight stop levers 588 (Fig. 38) pivoted at 588^x, the ends of which are normally out of engagement with the ends of the key levers 337^a (Fig. 10) but upon the depression of the multiplication-key 561 the ends of said levers are shifted to a position directly above the ends of the key levers 337^a to 337ⁱ. Said saddle is pressed rearwardly by a spring

584^x, which also tends to raise the multiplication-key.

Stop levers 588 are located in slots 558^a in saddle 584, and serve to obstruct the canal 558^b, which passes through the entire length 70 of said saddle, when said levers 588 are operated upon by the key levers. A rack 601 (Figs. 10 and 10^a) extends into said canal 558^b, the end of said rack normally lying flush with the rear stop lever 588. Rack 601 75 is provided with a guide 602 and with a return stop 604, both rigidly attached to the base A. Said rack engages gear 607 (Figs. 10 and 10^a), said gear being an integral part of clutch-member 607^a, the whole being loose 30 on a shaft 441. Rack 601 is normally spring-pressed against stop 604, the spring 608 being arranged internally in gear 607. The inner end of said spring is hooked to a disk 610 adjustably connected to bearing 612 85 by set-screw 612^a, so that the tension of said spring may be increased or decreased, as desired. Shaft 441 carries shiftable clutch member 615 loose on said shaft. Said clutch member has three sets of engagement-teeth, 615^a that engage with teeth 607^a, above described, 615^b that engage teeth 618^a of the member 618, pinned rigidly to shaft 441. The third set of teeth 615^c are radially disposed, each tooth being a part of a corresponding tooth 615^b, and are thus disposed in order to readily engage with tooth bracket 619 provided with a single tooth and fixed on the base of the machine. 95

The clutch member 615 in its normal position stands with its teeth 615^a disengaged from the teeth 607^a. Two of its teeth 615^c are then in engagement with the tooth bracket 619. Its teeth 615^b are at all times in engagement with teeth 618^a of the member 105 618, pinned rigidly to shaft 441. Clutch member 615 is reciprocated by the following means: Connecting rod 631 (Figs. 34 and 86), provided with bearings 632, 632^a and 632^b, screwed to the frame, is operated longitudinally from the lever 389^b (Figs. 36 and 85) heretofore described, being connected thereto by fork 635 (Fig. 86), by the turning of rod 631 on its axis, as follows: Upon the depression of the multiplication-key, the 110 connecting rod 631 is slightly rotated (Figs. 9, 34^a and 86), throwing the fork 635 into engagement with the lever 389^b, and thereby throwing said connecting rod into action. On the release of the multiplication-key, this 115 action is reversed. This connecting and disconnecting is accomplished by means of a bell lever 661, pivoted in bearing 663 (Figs. 9 and 34^a), rigidly attached to the right frame of the machine. Said bell lever is engaged by a pin 666 projecting from the multiplication-key, and is also connected by link 659 to a lever 658 rigidly attached to connecting rod 631. 125

Clutch member 615 is shifted by the fol- 130

lowing means: Rod 631 carries a collar 629 (Fig. 86) between the flanges of which collar works the free end of lever 627. Said lever is rigidly attached to the upper end of shaft 627^x, which latter is mounted in the arms of bracket 624 (Figs. 85 and 86), secured to the base of the machine. Pinned to shaft 627^x is a sleeve 622 having arms 622^m and 622ⁿ, carrying, respectively, pins 621^a 10 and 621^b, which latter work in the groove of movable clutch 615 (Figs. 10^a and 86). Through the means described, clutch 615 is moved out of engagement with bracket 619 and into engagement with teeth 607^a, leaving shaft 441 free to rotate under the influence of pawl 437, heretofore described.

Rigidly secured upon the end of the multiplier stop pin saddle 584 is a supporting beam 599, which carries a spring-pressed pawl 599^a (Figs. 10 and 38), pivoted at 20 599^b on beam 599 which, upon the shifting backward of the saddle 584 by the depression of the multiplication-key, is thrown into engaging proximity with the tails 159^b 25 of cylinder rock beams 159. The office of said pawl is to release any cylinder stop pins that may be depressed upon the set-up line during the process of multiplying (Figs. 10 and 38), thus preventing the figure of the 30 multiplier from entering the multiplicand on the cylinder.

There is no thrust bar associated with the stops at the setting up line; hence it is only necessary to prevent the figure of the multiplier from entering into the multiplicand when the cylinder is rotated.

It will be observed that when a digit key is struck, the cam shaft is tripped (it being understood, of course, that the multiplication-key has been previously depressed), and the connecting rod 631 will be thrown forward on account of the slight rotation of the member 389^b. It will be readily understood that the clutch 615 will be shifted into engagement with teeth 607^a and connecting bar 406 will reciprocate until the rack 601 strikes one of the stop pin levers 588, heretofore described, and prevents the shaft 441 from further rotation. Ratchet wheel 439 45 is provided with a retaining pawl 439^a (Fig. 34) and it will also be observed that upon each cycle of the cam shaft the rack 601 will move a step, equal to the distance from center to center of the stop levers 588. It will 50 also be observed that the connecting bar 406 will be held from further reciprocation by the pawl 437, since said pawl is prevented from further rotating shaft 441, heretofore described, after the contacting of rack 601 55 with the key-lever stops 588. As a result of such suspension of all action of trip-bar 406, the hook of 390 is thrown in the path, as heretofore explained, of engaging claw 388, whereby the dash-pot spider is operated, 60 65 which movement through its arm 389^b,

moves to the rearward connecting rod 631, thereby operating lever 627. Accordingly clutch 615 is shifted from engagement with teeth 607^a, thus preventing rotation of shaft 441, since the latter is locked to the base of 70 the machine by the engagement of teeth 615^c and stationary member 619. At the same time the multiplying rack 601 is returned to its normal position by spring 608 in gear 607.

During the return movement of the connecting rod 631, the cylinder C escapes one-tenth of a revolution. Said escapement is accomplished by means of the following mechanism: A bar 642 (Fig. 34) working in bearings 642^a and 642^b, is provided with an arm 637 (Figs. 9 and 34) rigidly attached thereto, and which connects same to connecting rod 631 through the sleeve 640. These connections cause a movement of the bar 642 similar to and simultaneously with 85 movement of connecting rod 631. Bar 642 carries a pawl 643, which engages and releases a nose 642^x (Figs. 34 and 85) on the cipher rock bail E, upon the backward movement of rod 642. As above stated, the rod 90 631 is moved forward immediately upon the striking of a digit key during the process of manipulation. It will now be understood that the engaging part 464^a of the pawl 643 will be thrown in front of the cipher rock 95 bail lug 642^x and, upon the arrest of connecting bar 406, as heretofore described, the connecting rod 631 will be thrown back to its normal position by the engagement of hook 388 with spider pawl 390, as heretofore described, and pawl 643 will engage the cipher rock bail and release the escapement 100 through arm 284 (Fig. 34), as above described, in the escapement movement. This is accomplished by the forward movement of cipher rock bail E, carrying, as heretofore described, lever 284 which operates the escapement bell lever 187 carrying plunger 192 impinging the spider pin 172. Briefly, then, in the process of adding, pawl 437 is disengaged 105 from ratchet 439 so that the cam shaft 382 may make one complete revolution, shaft 441 remaining stationary, as heretofore described. In multiplying, however, shaft 441 is caused to rotate, and this is effected by the 110 engagement of pawl 437 with ratchet 439. Furthermore, it is repeated that, though in multiplying the digit rock bail D is moved longitudinally so that its arm 274 cannot operate the escapement, the escapement is 115 effected automatically through the medium of the cipher rock bail E at the end of each multiplying operation.

It will be understood that after pawl 643 has operated the cipher rock beam E, its 120 engaging point passes beyond the point 642^x of the rock bail, in which advanced position it normally rests.

The multiplication-key stem 561 is held 125 in its depressed position by the engagement 130

of pin 681^c on arm 681^a with notch 681^d (Fig. 108). Said pin is held in engagement with said notch by reason of spring 534^f. As heretofore stated the division-key 537 will be released if it is depressed when the multiplication-key 561 is operated, by reason of the rotation of sleeve 533 to which arm 534, associated with said division-key, is attached.

10 At its lower end the stem of the multiplication-key 561 engages in bearing 561^y and said stem is prevented from turning by the engagement of a pin 561^x carried thereby, with a slot in said bearing (Fig. 108).

15 *Printing mechanism*, (Sheets 1, 4, 5, 6, 8, 22, 23 and 24: Figs. 1, 4, 5, 8, 27^a, 27^b, 64-69^a.)—Hinged to the rear end of slides 25 (Fig. 27^a) at 727^a are a series of racks 747, which are termed the primary type-operating racks. They are directly below and parallel to racks 24, and slide in bearing 115^a (Fig. 4). Said racks mesh with and, upon reciprocation, operate pinions 750, independently and loosely mounted on shaft 751 and set between collars 750' (Fig. 68). Shaft 751 does not rotate, but is capable of being shifted longitudinally for the purpose of engaging and of disengaging gears 750 from the racks 747, and thereby throwing 25 the printing mechanism in and out of action. This longitudinal shifting is accomplished by means of a printer key 729 (Figs. 68, 27^a and 27^b, Sheet 23) which, when in its depressed position, effects the printing of the 30 results of one operation of the machine (except as hereinafter explained in connection with the "accumulator" and "accumulator total" operations); whereas, when said key 729 is in its raised position none of the results of the operation of the machine will be recorded. The stem 729^a of said key carries a pin 729^b which engages in a slot of lever 729^c, which latter is rigidly fixed to shaft 729^d journaled in bearings 729^e and 729^f, to 35 which shaft is rigidly fixed fork lever 743, engaging groove 743^a (Fig. 68) of the shaft 751.

758 designates what I term the secondary type-bar operating racks, disposed vertically and operative in guides 769 and 776 (the latter being shown in Fig. 4). Racks 758 are always in engagement with gears 750 and are moved by the same. To the upper extremity of racks 758 are securely riveted 40 a series of arms 759, each of which is bent so as to engage the type-bars 783 (Figs. 4 and 8), a notch 783^a being provided in each of said type-bars for their engagement. Each type bar is provided with ten types 45 784 (Figs. 64, 65, 66 and 67), ranging from 0 to 9, the zero type being normally held on the printing line. The type bars 783 lie between guide plates 786 (Fig. 64), which are provided with grooves 786^a (Fig. 66), 50 that engage pins 783^d located on the lower

extremity of type bars 783. These plates are rigidly secured to a mounting member 790, which is in turn secured to the bridge 1161, spanning the entire machine and rigidly secured to the framework. The type 55 bars 783 and guide plates 786 are incased on either side by plates 789, also secured to mounting member 790.

787 is a bar used to separate the lower end of guide plates 786 and is secured by 50 screws 787^a.

Pivoted on rod 804 (Figs. 4, 67 and 69) supported by the plates 789 is a series of controlling dogs 803, each pressed toward the type bars by spring 804^a, each secured at one 80 end to a dog 803 and at the other end to a bar 804^b mounted in end plates 789. These dogs are provided with inclined surfaces 803^a, which engage inclined surfaces 783^b on the type bars 783, so that upon the upward movement of said type bars the dogs 803 are thrown slightly forward. These dogs control the printing of all ciphers to the right of the highest digit, and exclude all those on the left. This is accomplished 90 by means of a series of overlapping lugs 803^b (Fig. 67), which are arranged so that the lug on the first or unit dog slightly overlaps the dog in the second or tens position, and the lug on the dog in the tens position 95 slightly overlaps the dog in the hundreds position, and so on.

It will readily be observed that if a type bar 783 is slightly raised in the hundreds position the dogs in the units and tens positions will be thrown rearward simultaneously with that in the hundreds position. Dogs 803 are each provided with a hook 803^c at their upper extremity, which hooks normally lie in engaging proximity to similar 105 hooks 799^a of type hammers 799. These type hammers are pivoted on rod 800 supported by the cheek plates 789, and are pressed by springs 800^x toward the type bars, the tension of the springs normally being resisted by a cam 809, which also holds the type hammers low enough to keep lug 803^c from engagement with the nose 799^a. 110

Cam 809 is rigidly secured to a shaft 811, journaled in brackets 812 and 814 (Fig. 8). 115 This cam is given one revolution at a definite point in the cycle of operation of the machine, which point occurs during the time allotted for the carrying operation. The movement of said cam shaft 811 is controlled by the sector 818, whose lower lever 818^b (Figs. 4 and 5), is pivoted at 822 on the frame of the machine (Fig. 4), and operated from cam 821 (Fig. 5), keyed rigidly to the cam shaft 382, a cam roller 820 being 120 provided on said lower lever for engaging with the cam 821. Sector 818 meshes with and rotates the gear 825 (Fig. 69^a, Sheet 6), provided with a ratchet disk 826, rigidly attached to gear 825 and loosely mounted 125 130

therewith on cam shaft 811. Said ratchet disk is provided with a notch 826^a, which normally lies slightly out of engagement with a spring-pressed pawl 827, mounted on a lever 828, pinned rigidly to cam shaft 811, and said notch 826^a engages pawl 827 when the disk is rotated.

A retaining dog 833 is pivoted at 835 in bearing 814 (Fig. 8) and engages a notch 831^a in a disk 831 securely fastened to cam shaft 811. This dog serves to hold the cam shaft against rotation while said shaft is in its normal position. Dog 833 is disengaged from disk 831 on the initial movement of the sector. The lever 833^a, which is an integral part of said dog, is provided with a pin 833^b which is engaged by a spring-pressed pawl 836, pivoted on said sector lever 818^a. Immediately upon the disengagement of dog 833, disk 826 is revolved by reason of the engagement of pinion 825 and sector 818 and notch 826^a engages the pawl 827 and the cam shaft is rotated one complete revolution, when the dog 833 again drops into its notch 831^a in disk 831. The sector 818 is then returned to its normal position, the gear 825 of course turning in a reverse direction until it reaches said position. On account of the peculiar shape of cam 809 the type hammers 799 are disengaged simultaneously, and very rapidly, and those that are not held by the dogs 803 are thrown by their respective springs against the type bars 783.

Ink ribbon movement, (Sheets 1, 4, 5, 18 and 38; Figs. 1, 4, 5, 42^a, 43, 44, 45, 46, 47 and 112.)—The ink ribbon 841 is wound upon spools 842^x and 842^y (Figs. 42^a and 43), one of the terminals of said ribbon being securely fastened to the hub of each spool by any suitable means as by a spring clip (not shown). Spools 842^x and 842^y are loosely rotatable on a common sleeve 845, provided with locating collars 846. The spools feed, preferably, in different directions, the ribbon entering spool 842^x from the top (as shown in Fig. 43) and spool 842^y from its lower side. This sleeve 845 is journaled in bearings 850 and 851 which are rigidly secured centrally of the machine to bridge 1161, as shown in Fig. 43. A shaft 849 passes through said sleeve 845, to which shaft is attached spool-operating lever 875 (Figs. 42^a and 43, Sheet 18, Figs. 45 and 46, Sheet 5), which is reciprocated from the line space operating lever 923, through connecting rod 885 (Figs. 4 and 5). Lever 875 is fixedly secured to shaft 849, as is also lever 881 on the opposite end of shaft 849. Upon the right end of loose sleeve 845 is secured a lever 872 which carries a pawl 866, which engages the ratchet teeth 842^a, cut in one of the disks of spool 842^x. Said lever 872 carries also a pin 877 (Figs. 42^a and 46) having two inclined sur-

faces substantially V-shaped in form, as shown in Fig. 46, which pin 877 engages a roller 879, pivoted on a slide 880, spring-pressed outwardly by spring 880^a and guided in a slot in lever 881 (Fig. 46). While the pawl 866 is in engagement with the ratchet teeth 842^a, one of the inclined surfaces of pin 877 lies against the roller 879 and the other inclined surface of pin 877 lies against inclined surface 881^a in the upper end of lever 881, which surface is the limit of throw in one direction of pin 877 and its lever 872, while inclined surface 881^b of said lever 881 is the limit of throw in the other direction. Upon the other end of sleeve 845 is secured a lever 868, carrying a pawl 866^a, which latter is out of engagement with ratchet teeth 842^b when pawl 866 is in engagement with the teeth of ratchet 842^a, said pawl 866^a being held out of engagement by pin 866 projecting from lever 875.

A constant source of friction is applied to the two ribbon spools 842^x and 842^y, by means of a T-shaped member 883 (Figs. 42^a and 44), attached rigidly to shaft 884, and containing two friction plungers 883^a and 883^b, which are pressed against the inner disks of said spools by spring 883^c. The office of this friction member is to prevent the rotation of the ribbon spools while the operating pawl is taking its backward step.

Rigidly secured to shaft 858 which is also journaled in bearings 850 and 851, are two controlling levers 855, through the forked ends of which the ribbon 841 passes, in front of the type bars 783, and by means of which the ribbon is lowered from the sight line, or raised to the sight line, during the period of printing. This is accomplished by means of a lever 859 (shown in Figs. 45 and 46) rigidly secured to shaft 858, which lever is retracted to its normal position by a cam 864 mounted securely on cam shaft 811, heretofore described. When cam 864 is slightly rotated until fall 859^a of said cam is clear of lever 859, the latter moves toward the center of cam 864, under the influence of spring 862 (Fig. 45) secured at one end to said lever and at the other end to bearing 851, and levers 855, carrying the type ribbon, are thereby thrown upward. Cam 864 has a slight lead on the printer hammer cam 809, heretofore described (Fig. 69, Sheet 24) as the type ribbon must be at the printing line before the release of type hammers 799, heretofore described.

The type ribbon, in passing to or from the spools 842^x to 842^y, or vice versa, will pass over guide rollers 854 (Fig. 112), rotatively mounted on shaft 858. These rollers 854 perform an important function inasmuch as, without such means, the ribbon—which is given a quarter turn in passing through the end of guide arms 855 and is fed intermittently—could not be success-

fully advanced unless it were supported at a point near the pivotal movement of said guide arms. Indeed, these rollers constitute an intermediate and highly desirable 5 control for the ribbon in its passage from the spools, as they fill and refill, to the outer ends of the guide arms which move up and down for the purpose of moving the ribbon to and from the printing line.

10 The operation is as follows: Assume that the left hand ribbon spool 842^y has become empty. The strain on the ribbon, due to the pressure exerted from pawl 866, becomes greater than the pressure of spring 880^a on the roller 879 against the pin 877, and said roller will immediately be thrown under pin 877 and said pin will assume a position between the roller and the surface 881^b on lever 881; the pawl 866 will be disengaged 15 from the teeth of disk 842^a by pin 881^c and the pawl 866^a will become engaged with the teeth of disk 842^d of the empty ribbon spool 842^y, causing a reversal in the movement of said ribbon.

20 *Printer carriage*, (Sheets 1, 4, 11, 16, 18, 19, 24, 28 and 31; Figs. 1, 4, 11, 18, 47^a, 47^b, 48, 49, 68, 75, 76, 87-90.)—The printer carriage is composed of end plates 898 and 899 (Figs. 1, 4 and 47), which plates are secured 25 to a rear tie 892 and a front tie 888. A printer platen 900 is mounted on a shaft 903 (Figs. 4 and 88), which is journaled in said end plates 898 and 899, and said shaft is provided with knobs 905 and 905^x, which 30 are rigidly secured on each end thereof. A base plate 887 which is rigidly secured to the right and left frames of the machine, is provided with two angle pieces 889 and 890. In tie 888 is provided a groove 888^a, 35 which is oppositely disposed to a groove 889^a in angle piece 889 (Fig. 4), said grooves forming a race for balls 895^a. A groove 892^a is provided in tie 892, and is oppositely disposed to a groove 890^a formed in angle 40 piece 890, which likewise forms a race for balls 895. Upon these two sets of balls the printer carriage reciprocates.

45 Knob 905^x is provided with a sleeve 905^a (Fig. 87), and a ratchet wheel 908 is rigidly mounted on said sleeve. Pivotaly mounted on the left hand end of shaft 905, between said ratchet wheel 908 and end plate 899 (Figs. 1 and 87), is a spring-pressed line space adjustment lever 910 (Figs. 4 and 87), which 50 carries a pawl 911, pivoted at 911^a, and adapted to be spring-pressed against ratchet wheel 908 but normally held out of engagement therewith by a pin 913 mounted on end plate 899, which pin engages a nose or lug 911^b on said pawl 911. This line space adjustment lever 910 is provided with three 55 stops *a*, *b* and *c*, one of which engages an abutment 939 when said lever is allowed to rotate under the action of spring 910^l, 60 which spring is attached at one end to the

lever at 910^k and at the other end to end plate 899. Abutment 939 is movable toward and from platen 900, and is movably secured to plate 899 in any suitable manner, as by the engagement of a slot 939^c in said abutment with a pin 939^b carried by end plate 899. Said abutment may be moved by handle 934^a. Said abutment is maintained in position by a dog 942, pivoted to plate 899, and acted on by spring 942^a secured at 70 one end to said dog, and at the other end to plate 899. Said abutment may be moved so as to contact with the first, second or third step of the adjustment lever.

An operating lever 916 is rigidly connected to shaft 917, which latter is mounted in end plates 898 and 899 of the printer carriage. On said shaft is mounted a bail (rear view Fig. 76, Sheet 28), comprising end pieces 919 secured rigidly to shaft 917, and rod 922 secured rigidly to end pieces 919. The end of said lever 916 always lies against a projection 910^y on lever 910 so that, if said lever 916 is moved upwardly, the lever 910 will follow the same under the action of spring 910^l, until one of its three steps contacts with the abutment 939. The angle of movement of lever 916 is constant, said movement being transmitted from lever 923, 80 pivoted on shaft 926, which is journaled in bearings 927 attached to vertical rack guide tie 776. Lever 923 is forked at its upper end, and engages rod 922. Rigidly connected to shaft 926 is a cam lever 930, provided at its free end with roller 933, which latter in the ordinary adding operation engages cam 939 (Fig. 48), but engages cam 938 (Fig. 49) in taking totals and sub-totals, 85 these cams being fixed on the main cam sleeve 473, heretofore described.

90 It will be understood that the steps *a*, *b* and *c* determine the extent of movement of lever 910. At the end of the movement of said lever, pawl 911 engages ratchet 908, and upon the return movement of lever 910 95 the platen is rotated by the engagement of the pawl with ratchet 908.

100 It will be observed (Figs. 48 and 49) that cam 937 will produce only one movement, which occurs directly after the printing; while cam 938, which is used in taking totals and sub-totals, will space the platen before printing and after. This is done to make the totals and sub-totals more conspicuous than the recording of ordinary items, by producing an extra space on the printed page and between the last item added and the total.

115 Pivotaly mounted on the rock bail shaft 917 is a series of paper guide plates 946 (Figs. 1, 87 and 88), spring-pressed against the under side of platen 900 by springs 946^a (Fig. 4), and held in position on said pivot shaft by collars 950 (Fig. 1) secured to said shaft by screws 950^a. In each of end plates 120

898 and 899 is secured a screw 968, in which are pivoted arms 967, in the ends of which arms is mounted a rod 965^a (Fig. 87), which carries feed rollers 965. Said feed rollers 965 are pressed against the platen by spring 967^a (Fig. 88). The free ends of arms 967 rest in slot 960^a, provided in shaft 960 (Fig. 89), which shaft is mounted in the end plates of the carriage, and accordingly feed 10 rollers 965 may readily be raised out of contact with the platen by rotating said shaft 960. This rotation may be effected by any desirable means, as for instance levers 957 secured to either end of said shaft (Figs. 1, 15 4, 87 and 88).

A series of tongues 955, secured at one end to a swinging rod 952 (Figs. 4 and 88), is employed to guide the paper under the feed rollers 965, after the paper has passed 20 guide plates 946. Said rod 952 is fastened rigidly to bell crank levers 954 (Figs. 87 and 88) which are loosely mounted on platen shaft 903. To arms 954^a of said bell crank levers are connected one end of each of two 25 links 963, the other end of each of said links being connected with levers 961, rigidly secured to shaft 960 (Figs. 4, 87 and 88). By slightly rotating crank arm 957, the tongues 955 are rotated around the platen until they 30 meet the guides 946, so that the paper will pass around and be guided under feed rollers 965. The tongues are then retracted to their normal position, as shown in Figs. 4 and 88, leaving the paper in proper relation 35 to the platen.

In Fig. 88, there is shown a knife 2511 mounted on cross-bar 2511^a fixed in the end plates 898 and 899, said knife being for the purpose of cutting off a strip of paper. The 40 paper is usually used in large rolls mounted on a suitable bracket (not shown), and from time to time it is desirable to cut off a strip.

In Figs. 87 and 90 are shown the details of a printer platen brake. Fixed to sleeve 45 905^a of the right hand knob 905 is a brake disk 2512. Working against the edge of said disk is a brake shoe 2513 mounted as shown on the end of bell lever 2514, which latter is pivoted at 2515 to plate 898. Said bell lever is under the tension of spring 2516, which spring is secured at its upper end to 50 an adjustment screw 2517 working in a lug on plate 898. The object of this brake is to prevent an overthrow of the printing platen when fed automatically as heretofore described.

In Figs. 4 and 47, there is shown a means by which the paper may be automatically spaced in any number of columns. The 55 means consist of a spacing element 969 mounted on a shaft 969^a secured in end plates 898 and 899. This spacing element contains a number of lines of stop devices, such as notches, the stop devices in the several lines being spaced various distances

apart but equally spaced in any one line. This rack or spacing element is engaged by a double pawl escapement, the pawls being indicated by the numerals 977 and 979. Pawl 979 is pivoted at 983^a in a bracket 70 983 rigidly secured to plate 887 (Figs. 4, 47^a and 47^b), and pawl 977 is pivoted at 979^b on pawl 979. Pawl 979 is normally in engagement with one of the notches in said rack or spacing element, and is pressed by 75 spring 979^a toward the same (see Figs. 47^a and 47^b, Sheet 24). Pawl 977 is manually operated through a lever 985 pivoted at 985^a on plate 887 (Fig. 47), and said lever 985 is pressed by a spring 985^b connected 80 thereto at one end and at its other end to plate 887. By operating the hand lever 985 pawl 977 is forced against the smooth surface of the rack or spacing element 969, and being pivoted on pawl 979 withdraws the 85 latter from the notch with which it is in engagement, and the carriage moves to the left until pawl 977 engages the next notch in the rack or spacing element 969. Upon the release or retraction of lever 985, pawl 977 is withdrawn from the notch with which it was engaged and pawl 979 is engaged, when the carriage will move the remainder 90 of the column space.

On end plate 898 is mounted a spring- 95 pressed arm 969^b (Fig. 47) which is provided in its free end with a roller 969^c, which roller engages grooves in said rack or spacing element, there being one groove for each set of stops in said spacing element. 100 The engagement of said roller with one of said grooves holds the spacing element from rotation unless turned manually by knob 973. Knob 973 is provided with a numbered surface 973^a, incased in a shell 973^b secured to 105 end plate 898. Shell 973^b is provided with a slot, and surface 973^a is arranged so that the number of notches in the line upon which the escapement pawls are operating will be indicated at said slot (Fig. 47). 110

The entire printer carriage is constantly subjected to a spring pressure tending to move the same toward the left of the machine. This is effected by the provision of a rack 892^r (Figs. 4 and 68) provided at the 115 bottom of rear tie 892, which rack is engaged by a pinion 990 pivoted at 990^a to angle piece 890. Said pinion meshes with a gear 991, which is a part of spring barrel 991^a, in which is mounted a helical spring 993 (Fig. 120 68), one end of said spring being secured to said barrel and the other end being secured to a stud 995 on which said barrel is mounted, said stud 995 being mounted on a bearing 997 secured in any suitable manner to 125 the bottom of plate 887.

Multiplication indicators, (Sheets 1, 20, 21, 25, 33, 37 and 38; Figs. 1, 59, 59^a, 59^b, 60, 61, 62, 63, 91-96, inclusive, 108 and 111).—In the process of multiplication it is desir- 130

able that the operator should have some means for verifying the multiplicand and the multiplier and such a device is accordingly provided. In connection with the 5 mechanism an opening is provided in the top of the casing through which (Fig. 1) a plate 1077 is visible. The multiplicand is shown on a line indicated by J, and the multiplier on a line indicated by K on said plate.

10 The multiplicand is set up by means of a series of spring-pressed slides 1093 (shown in detail in Fig. 63) and the multiplier by a series of slides 1043^b (Figs. 62 and 111). Both these series of slides are mounted in 15 grooves in said plate 1077 (see Fig. 111), wherein they are held by plates 1077^x fastened by means of screws 1077^y. At the rear of each multiplicand slide is provided a tail 1093^a, which stands normally out of engagement with arms 1109, one of which is attached to each of racks 24; but, on the depression of the multiplication key 561 said tails 1093^a are thrown into operative engagement with arms 1109. This is accomplished 20 by means illustrated in Figs. 59, 59^a, 59^b and 60. Plate 1077 is attached by screws 1077^a, Fig. 60, to U-shaped guides 1078 and 1080 (Fig. 59^a), together constituting the factor indicator carriage, which slides in 25 bearings 1081, attached securely to the right and left frames of the machine. Guide 1078 is provided with lug 1117 (Figs. 59^a and 60) rigid therewith, which is engaged by a spring-pressed dog 1114, pivoted on lever 30 1109, which in turn is pivoted at 1110 on the key-board mounting plate 1132, and is operated from the multiplication key through angle piece 1112 of the said multiplication key.

35 Plate 1077 is normally pressed toward the left by spring 1077^c, secured at one end to the frame of the machine. Stops 1077^b attached to the guide 1080 abut guide bearings 1081 and limit the movement of the 40 guide. Upon the depression of the multiplication key the factor indicator carriage will be moved slightly to the right against the tension of spring 1077^c, in which position it will be retained by a detent lever 1131 pivoted at 1081^a on side frame 1081 engaging a pin 1131^a, rigidly secured to guide 1080. Said detent lever 1131 is notched at 45 its free end and is pressed against pin 1131^a by spring 1131^b. When the carriage has been moved to the right, the notched portion of said lever engages said pin, and the carriage is held from movement to the left by spring 1077^c. Dog 1114, after the shifting of the plate 1077 is thrown out of contact 50 with its engaging lug 1117 by the end of said dog 1114 striking a bracket 1116 (Figs. 59^a and 60) mounted rigidly upon rack guide 1049.

55 A rock shaft 1029 journaled in brackets 1032 and 1032^a (Fig. 59^a), rigidly secured to rack guide 1049, is operated from eccentric 1017 (Fig. 59), which is securely attached to disk 476^a on the cam shaft. Cam lever 1020, pivoted in bearing 1021, securely attached to the base of the machine, engages 60 said eccentric 1017, and is connected by rod 1027 to an arm 1030 securely fastened to rock shaft 1029. Said lever 1020 is spring-pressed against cam 1017 by spring 1020^a. A releasing lever 1034, is also rigidly attached to said rock shaft at 1034^a (Fig. 59^a) and is normally disposed in working proximity to retaining dog 1131.

65 It will be seen that, upon the rotation of cam shaft 382, the lever 1034 is given a rocking movement which will release lever 1131 from its engaging pin, and the factor indicator carriage will be retracted by spring 1077^c to its normal position. The release of lever 1131 occurs directly after the forward 70 movement of racks 24, during which forward movement of said racks the slides 1093 are thrust forward, showing a number on the line J corresponding to the multiplicand set up on the cylinder C. The slides 1093 are retained in their advanced position by pawls 1096 pivoted on pins 1096^a (Fig. 59^b), mounted on brackets 1096^x, which latter are fastened to plates 1077^x by screws 1096^y (Fig. 61), said pawls engaging ratchet 75 racks 1093^b on said slides. After the first reciprocation of racks 24 the tails 1093^a of slides 1093 will not be further affected as the mounting plate 1077 has been returned to its normal position, as before explained, 80 and the tails 1093^a are out of the path of movement of pin 1109. Rock shaft 1029 is also provided with a lever 1041 securely fastened to a sleeve 1042 (Fig. 59^a). Said lever is slidable longitudinally on said shaft, 85 through the agency of said sleeve 1042, but is not rotatable independent of said shaft 1029. The part of the shaft upon which the sleeve slides is square in cross-section (Fig. 59^b), the sleeve being provided with 90 a corresponding hole. Lever 1041 is provided with a spring-pressed pawl 1043 (Figs. 59, 59^a and 59^b)—spring not shown—which lies normally in working proximity to the teeth of indicator ratchet racks 1043^a 95 (Fig. 62), which are a part of the multiplier slides 1043^b. Pawl 1043 on lever 1041 normally stands adjacent to the unit multiplier indicator 1043^a. It will now be observed that upon each rotation of rock shaft 1029, the multiplier slide will be thrust rearward one space. To illustrate:—In the process of multiplication, should the multiplicand be multiplied by four, the rock shaft 1029 will be oscillated four times from the cam-shaft 382, moving the unit multiplying slide four notches, exposing the figure 4 at the end of the line K. The multiplier slide ratchet racks are each engaged by a retaining pawl 1088 (Figs. 59^b, 91 and 92) pivoted on rod 100 105 1042.

110

115

120

125

130

1096^a. These slides, as well as the multiplicand slides are spring-pressed to the zero position, the multiplicand slides by springs 1088^x and the multiplier slides by springs 1088^y (Fig. 61). Springs 1088^x at their front ends are connected to pins screwed to plates 1077^x and at their rear ends to pins fastened to said slides 1093; and springs 1088^y are fastened at their rear ends to plates 1077^y by a similar set of pins and at their forward ends to pins fixed in slides 1043^b.

Upon the completion of multiplication by a single digit the sleeve 1042 is forced to escape, shifting the pawl 1043 into working proximity with the multiplier slide occupying the tens position. This is accomplished through the fork 1046 engaging a recess 1042^a in said sleeve, which fork is rigidly secured to a rack 1048 (dotted line Fig. 59^a, end view Fig. 59), by screws 1048^b, said rack being slidably mounted in rack guide 1049 (Figs. 93 and 94), which is suitably secured to lugs 2519 on guide bearings 1081. Rack 1048 meshes with pinion 1052, secured by key 2522 (Fig. 95) to vertical shaft 1054, journaled in bracket 1055 and bearing 1058, and is spring-pressed to its normal position by spring 1048^a (Figs. 59^a, 95 and 96) secured to the shell of gear 1052 at one end and anchored at the other end to bracket 1055. This connection with the bracket 1055 is effected by the engagement of a loop 2520 on the end of said spring with a downwardly projecting finger 2521 carried by said bracket. Shaft 1054 is provided with a bevel pinion 1061, rigidly secured thereto, and when the multiplication key is depressed said pinion engages a gear 1062 (Fig. 59), which is fastened rigidly to and turns with the cylinder shaft 149.

Shaft 1054 is provided with a recess 1054^a which is engaged by a fork lever 1064 mounted on shaft 1066 and spring-pressed upwardly by spring 1064^a. Said lever 1064 is operated through lever 1070 mounted on shaft 1066 and provided with a pin 1070^a which is engaged in angle piece 1072 securely fastened to the multiplication key 561. Upon the depression of the multiplication key, the shaft 1054 will occupy a position as shown in Fig. 59, and the gears 1061 and 1062 will be in engagement. Therefore, should the cylinder escape one-tenth of a revolution the sleeve 1042 will also move longitudinally upon the shaft 1029 a space between the slides in the multiplier row K, and proportionally for any part of a revolution of said cylinder. When the multiplication key 561 is released, gears 1061 and 1062 are disengaged and rack 1048 is driven under pressure of spring 1048^a to its normal position at the right, carrying the lever 1041 therewith.

As heretofore stated, the release of the

multiplication key is accomplished upon the depression of the eraser key. So also is the clearing of the lines J and K, the following mechanism being installed for the purpose: The tails of the multiplicand slide retaining pawls 1096 and the multiplier slide retaining pawls 1088 are pivoted on a common pin 1096^a, as shown in Figs. 59, 59^b and 61, and in engaging proximity to swing rod 1120 of a rock bail pivoted on rod 1123 journaled in brackets 1124, which latter are fixed to cross-bar 107 (Fig. 59). To shaft 1123 is rigidly secured a lever 1127 which is connected by link 1128 to a lever 1130 (Fig. 108) secured to sleeve 533. As previously indicated, this sleeve is given a slight rotating movement upon the depression of the eraser key 514 (Fig. 59^b) through arm 529, pin 529^a and arm 532, whereby rod 1120 is elevated, disengaging the retaining pawls 1096 and 1088, and permitting the slides to return to zero position under the influence of springs 1088^x and 1088^y.

Secondary accumulator, (Sheets 26, 27, 34 and 35; Figs. 70, 71, 72, 73, 74, 97-100).— In these figures there is illustrated what is termed the "secondary accumulator." The principal use of this mechanism is to receive from time to time periodical accumulations of numbers on the primary figure wheels 103, whereby a grand total of a series of accumulations on the primary wheels may be registered on the secondary wheels. After a series of grand totals from the primary accumulator wheels have been transferred to the secondary wheels, they may be aggregated into what is called the "accumulator total," hereinafter referred to.

The transfer of a number or numbers on the primary figure wheels is effected by bringing the secondary accumulator wheels into engagement therewith in any suitable or desired manner. As here shown sectors 87, one of which is associated with each of the primary figure wheels, is provided with an extension having teeth 2000. The secondary accumulator wheels 2001 are brought into mesh with these teeth 2000 for the purpose of effecting the transfer from the primary to the secondary accumulator wheels. This transfer naturally occurs at the time of taking unison in the manner described, except that unison need not necessarily be taken at that time, *i. e.*, the primary wheels need not be moved. The unison process, heretofore described, includes the movement of the sectors 87 until their unison dogs 92 contact with unison pins 96 of the respective figure wheels, after which the figure wheels are returned to zero, the sectors 87 being revolved in the reverse direction the number of units that they are advanced in the first instance. During this return movement the secondary figure wheels being in engagement with teeth 2000, the value that was

previously represented on any primary figure wheel will be transferred to its corresponding secondary accumulator wheel. As heretofore stated, it is not necessary during this operation to bring the main figure wheels 103 back to unison, but it is more convenient to do so. During the forward movement of the main racks at the time that the value of the number represented on the primary figure wheels is being measured, in connection with the secondary accumulator operation, the amount may, if desired, be printed. Hereafter it will be seen that in practical work the sum of various groups of figures collected on the primary figure wheels may be recorded; likewise the various products obtained on said primary wheels may be successively recorded, and as it will be hereinafter noted, the sum of these various groups or various products may be accumulated in a grand total on the secondary accumulator wheels, which grand total likewise may be recorded.

The intermeshing of the teeth of the secondary accumulator wheels with teeth 2000 of sectors 87 is effected as follows: The secondary accumulator wheels 2001 are mounted on swinging shaft 2002 and are so disposed on said shaft that each wheel 2001 is in a position to mesh with the teeth 2000 of its corresponding sector. Said shaft 2002 is mounted at its ends in arms 2004 and 2005, which arms are connected at their other ends to shaft 2003 journaled in the side frames of the machine. On one end of shaft 2003 is rigidly fixed a lever 2006 (Figs. 70, 97^a and 98^a), to the free end of which lever at point 2006^a is hinged a link 2007, which link at its lower end is connected to lever 2008 secured to shaft 2036 mounted in brackets 2009 and 2009^a, (Fig. 100) the latter being fastened to main rack guide 1153. At the other extremity of shaft 2036 is secured a lever 2010^a (Fig. 100) to which is pivoted a cam roller 2010, engaging cam 2011 which is keyed to cam sleeve 473, heretofore described. Cam roller 2010 is kept in contact with the surface of its cam by means of spring 2012 connected with lever 2006 at point 2013, said spring at its other end being anchored to pin 2014 on rack guide 1153. Normally the engagement of roller 2010 with cam 2011 holds the secondary accumulator wheels out of engagement with the primary figure wheels and in mesh with the teeth of racks 2015, one of which is associated with each secondary accumulator wheel. These racks 2015, each of which preferably possesses three teeth, are normally held firmly in position by pawls 2016 pivoted on rod 2016^a, mounted in the side frames of the machine, and said racks act as aliners for the accumulator wheels. These racks are provided at their upper ends with slots 2015^a, through which slots passes a rod

2017 which is supported at either end in the side frames of the machine. Collars 2018 are fixed upon this rod and separate said racks from each other (Fig. 99).

Racks 2015 while in engagement with teeth 2001 are capable of a longitudinal movement, the object of which is the carrying of tens. This is performed by the following means: Each rack 2015 is pivoted at 2019 to the upper end of one of a series of levers 2020 mounted on shaft 2003. These levers are abutted on one side by separating collars 2021, and have at their lower ends pins 2022, to each of which is attached one end of a spring 2023 (one of which is shown in Fig. 97), said springs being attached at their upper ends to pins 2016^a of the pawls 2016. Said springs serve the double purpose of turning levers 2020 upon their shaft, and also of holding pawls 2016 in engagement with racks 2015. Pawls 2016 in their normal position rest in notches 2024 of racks 2015, and are disengaged from said notches during the operation of carrying tens by means of a lever 2025 pivoted on pin 2026, one of which is fixed in each of a plurality of plates 2005^a (Fig. 97) of like shape to arms 2004 and 2005. Said plates are supported at their ends by rod 2002 and shaft 2003 in the same manner as arms 2004 and 2005.

Each lever 2025 contacts with the lower end of a detent 2016 at point 2027, and the other ends of said levers 2025 carry pins 2028. These pins contact with the lower edge of a lever 2029, one of which is provided for each secondary accumulator wheel, said levers being mounted on shaft 2003. The forward ends of levers 2025 are spring-pressed upwardly by the action of springs 2023, by reason of the lower arms of detents 2016 contacting said levers 2025 at points 2027. Levers 2029 in turn are depressed by contacting with carrying pins 2030, carried by the secondary accumulator wheels, said pins engaging inclined surfaces 2031 of said levers for this purpose. It will be noted that the surface of each of said carrying pins 2030 which strikes levers 2029 is rounded in form, and that said pin is also provided with a flat surface, which is disposed so as to squarely abut the forward end of lever 2029. The levers 2029 are limited in their upward movement by stop rod 2041 which passes completely through the ends of arms 2004 and 2005, and also through plates 2005^a. When the secondary accumulator wheels 2001 are in their normal position, that is to say, the zero position, they are disposed with relation to levers 2029 as shown in Fig. 70, and the abutment of the flat faces of pins 2030 against levers 2029 causes said secondary accumulator wheels to stand at unison.

Each lever 2029 operates a detent 2016

which controls a rack 2015 which meshes with teeth 2001 of the accumulator wheel of the next higher order. It will be evident, therefore, that each time an accumulator wheel 2001 makes a complete revolution and passes a given point from 9 to 0 and depresses its corresponding lever 2029, the operating detent 2016 associated with the rack and secondary accumulator wheel of the next higher order is affected, *i. e.*, said detent is removed from notch 2024, thus permitting to said rack 2015 its initial movement for the carrying of tens. This initial movement takes place while the secondary accumulator wheels are in engagement with the primary accumulator wheels, and accordingly out of engagement with said racks 2015. To complete the process of carrying tens, which takes place when the secondary accumulator wheels have been disengaged from the primary figure wheels, and engaged with racks 2015, it is necessary to permit said racks to have an increased longitudinal movement, and this is effected as follows:—A cam 25 roller 2032 engages a cam 2033, mounted on cam sleeve 473, said roller being pivoted at 2034 to lever 2035, which in turn is mounted on shaft 2036 (Fig. 100). Said lever 2035 at its rear end carries a link 2037, which link at its upper end engages rod 2038, which rod is carried by arms 2039 pivoted on shaft 2003. Said cam 2033 is so shaped as to cause the lifting of rod 2038 a short distance after the same contacts with levers 2020, in order 30 to move the same and the racks 2015 a sufficient distance to permit a reentry of any detents 2016 which have been displaced from notches 2024 in the preceding operation of carrying tens. This return movement of racks 2015 is effected while the secondary accumulator wheels 2001 are out of engagement with racks 2015 and are in engagement with sector teeth 2000. After the reengagement of detents 2016 with their respective 35 notches 2024, rod 2038 recedes to a point slightly out of contact with levers 2020 for the purpose of permitting the initial movement of racks 2015 in a succeeding operation of carrying tens. This movement takes 40 place immediately after the forward movement of main racks 24, and before commencement of their return movement. The secondary accumulator wheels are brought into engagement with teeth 2000 immediately after forward movement of main 45 racks 24.

Since the secondary accumulator wheels are rotated on the return movement of racks 24, if any carrying pin 2030 engages a lever 60 2029, detent 2016 will be disengaged from its notch 2024, as heretofore described, the rack 2015 will be moved slightly rearward and downward until its lever 2020 contacts with said rod 2038, which is at this time 65 only slightly removed therefrom, as hereto-

fore stated. This initial carrying movement, which takes place while the secondary accumulator wheels are in mesh with teeth 2000, results in the engagement of detent 2016 with surface 2040 of said rack, whereupon after the return of the rack 24 and sector 87, and by the further lowering of rod 2038, due to the shape of cam 2033, levers 2020 swing downward, permitting a corresponding movement of racks 2015 with which wheels 2001 are now in engagement, thus bringing about the rotation of the corresponding accumulator wheel 2001 the distance of one space, which completes the carrying of tens. As heretofore indicated, 70 upon the succeeding forward movement of racks 24, and after the secondary accumulator wheels 2001 are engaged with teeth 2000, cam 2033 causes rod 2038 to be elevated, whereby all the racks which were 75 previously displaced from their normal position for the purpose of carrying tens are returned so that detents 2016 will engage notches 2024.

To restate briefly the operation of the secondary accumulator: We will assume that a number is represented on the primary figure wheels 103. That value will also be represented by the position of unison stops 96. As shown in Fig. 70, said 90 stops 96 have an abutting straight face against which unison pawl 92 may abut. Pawl 92, it will be remembered, is fixed upon sector 87, and in order to transfer the value represented on the primary wheels to 95 the secondary wheels, the racks 24 are first moved forward until unison pawls 92 abut the unison pins 96. The secondary accumulator wheels are then brought into engagement with the sector teeth 2000. As the 100 racks 24 and the sectors 87 are retracted until they reach their normal position, they turn the corresponding secondary accumulator wheels a distance corresponding to their previous forward movement. If in 105 this movement, any one or more of lugs 2030 engage incline 2031 of lever 2029, the pawl 2016 will be lifted from engagement with racks 2015. At this point, as heretofore explained in detail, said racks may 110 move rearwardly and downwardly a slight distance, said movement being limited by the position at that time of rod 2038, which has been elevated until it nearly contacts with the levers 2020. This short movement 115 is the initial movement for the carrying of tens. The movement must be a slight one, simply sufficient to cause pawl 2016 to rest on the surface 2040, and not great enough to move rack teeth 2015 out of a proper alignment with teeth 2001 of the secondary accumulator when these shall have been again lifted into engagement with rack teeth 2015. When, therefore, teeth 2001 are disengaged 120 from sector teeth 2000 and engaged with 125 130

rack teeth 2015, the carrying of tens may be completed when rod 2038 is lowered. This carrying movement is effected as follows: The cam roller 2010 travels upon the surface of cam 2011 from the position indicated in Fig. 70, when the racks start forward, to the point *e* while the racks are going forward. When said roller 2010 at the point *e* begins to follow the fall of said cam, the secondary accumulator wheels are brought into engagement with the teeth 2000 and disengaged from the racks 2015. After the drop and until the point *f* is reached, the cam being concentric, said teeth 2001 of the secondary accumulator will remain in engagement with the teeth 2000 of the sector, which time is occupied by the backward movement of the racks 24 and of the sectors. When the roller 2010 has reached the point *f*, the rise of the cam disengages the secondary accumulator teeth 2001 from the teeth 2000.

Following the action of cam 2033 as affecting cam roller 2032 from the starting position, as shown in Fig. 70, it is pointed out that said cam is concentric to the point indicated by 2033^a, and hence the rod 2038 will remain in its normal lowered position. When the roller strikes the rise of the cam, commencing at 2033^a, the rod 2038 is moved upwardly a sufficient distance to restore the carrying racks 2015 which engage detent pawls 2016, with recesses 2024 thereof. After the roller has passed the rise of the cam 2033^a, the slight depression of said cam causes rod 2038 to recede a slight distance from contact with levers 2020, said cam from that point on to the point *g* being concentric. Rod 2038 is held in close proximity to levers 2020 during the time of the movement just indicated, and while the cam roller 2032 is tracing the concentric part of the cam just mentioned. If any of the secondary figure wheels 2001 are turned so that their carrying lug 2030 passes the carrying lever 2029, thereby lifting, as before indicated, the carrying pawl 2016 from engagement with the notch 2024, the racks 2015 are free to move downwardly a slight distance until the corresponding lever 2020 contacts with the rod 2038, where it will remain until cam roller 2032 traces the drop in said cam at the point *g*, when, as before indicated, the rod 2038 is lowered sufficiently to permit of the completion of the movement of carrying tens.

Accumulator total, (Sheets 26, 27; Figs. 70-74.)—When it is desired to take from the secondary accumulator wheels a total of the numbers aggregated thereon from the primary figure wheels; in other words, when it is desired to take what is called an "accumulator total"—this may be performed through the medium of cams 710 and 720 (Figs. 71 and 72). These cams are secured upon cam

sleeve 473 which also carries cams 2011 and 2033, heretofore described, in connection with the secondary accumulator operation. Said cam sleeve 473 is shifted by the same means as for a sub-total operation (as hereafter described) when it is desired to take an accumulator total, at which time said cam 710 is brought into the path of roller 2010 (Fig. 70) and cam 720 is brought into the path of roller 2032. The surface of cam 710 is so arranged and disposed that previous to the forward movement of main racks 24, the secondary accumulator wheels 2001 are brought into engagement with teeth 2000 of sector 87; hence, when said racks move forward, all of the secondary accumulator wheels 2001, which have been displaced from unison position by being added upon, are turned in a reverse direction from that in which they were turned when accumulation upon them took place, and said wheels 2001 will be rotated in the reverse direction until their carrying-pins 2030 contact, as heretofore described, with the abutment end of levers 2029, in which position they are brought to rest, and said secondary accumulator wheels are then in unison. The surfaces of cam 720 cause the restoring of racks 2015 immediately following disengagement of the secondary accumulator gears from said racks. During this time, by the forward movement of the racks 24, and by means of the printing mechanism heretofore described, the number which was accumulated on the secondary accumulator wheels is recorded on the printed page. Said number represents the grand total of the several numbers previously gathered upon the primary wheels.

It is pointed out that while the operation of taking an "accumulator total" is in progress, the primary figure wheels 103 remain immovable by means of lock 120 (Fig. 3); that is, the so-called basket sectors 81 are not lifted and the unison dogs 92 are, at their rear ends, depressed by levers 2042 (Fig. 70), one of which is associated with each unison dog, said levers being mounted on rod 2043 which is journaled in the side frames of the machine. This rod is operable so as to lift the forward ends of said unison dogs by means of said levers 2042, so that said dogs are elevated out of the path of unison pins 96, to the end that racks 24 may move forward sufficiently to return the secondary accumulator wheels to unison. It will, therefore, be appreciated that in order to take an accumulator total, it is not necessary to return the primary figure wheels 103 to unison (the position indicated in Fig. 70). On each of sectors 87 is pivoted at 2047 a detent 2045 which is tensioned, as shown, by spring 2048 anchored to its sector. When said unison dogs 92 have been depressed a sufficient distance by levers 2042, a pin 2044,

one of which is carried by each unison dog, engages notch 2046 formed in each of said detents 2045, whereby the forward ends of the unison dog are held in an elevated position out of the path of unison pins 96. Each of said detents 2045 carries a tail-piece 2049 which moves in the path of levers 2042, whereby on the return movement of said fingers, when the racks return to their normal position, said detents are operated to disengage pins 2044 from the notches 2046, thereby restoring pawls 92 to their normal position, in which they may engage unison pins 96. The connections for operating rod 2043 will be hereinafter described.

Link 2037 (Fig. 70), which is normally held in engagement with rod 2038 by a spring 2050, is removed from engagement with said rod 2038 when the secondary accumulator is not in operation. This is effected by depending lever 2051 carrying a pin 2051^a, which latter contacts with said link 2037. Lever 2051 is fixed to shaft 2052 which is journaled in bracket 2053, which is fastened on main rack guide 1153. Secured to said shaft 2052 is an arm 2054, the upper end of which, as shown in Fig. 70, engages with the surface of cam 2055 mounted on shaft 2082, which cam acts upon lever 2054 and its companion lever 2051 to move link 2037, at the appropriate time, to disengage the upper end thereof from rod 2038. The means for rotating cam 2055 are hereinafter described.

35 *Totalizing lever and associated parts, (Sheets 26, 27, 28, 35 and 36; Figs. 70, 75, 100, 101, 102, 103 and 104.)*—There has heretofore been described mechanism for effecting the unison and sub-total operations 40 (illustrated in Figs. 30 and 34), wherein unison key stem 667 and sub-total key stem 668 were actuated by the operator pressing upon suitable key-heads mounted on said stems. It is, however, possible to effect 45 the depression of the unison and sub-total key stems for the purposes described, by means of a totalizing lever; and such operation of the unison and sub-total keys is particularly desirable in machines employing 50 a secondary accumulator mechanism, as it is also possible with the totalizing lever and the associated mechanism which is herein shown and described, to effect the transfer of numbers from the primary figure 55 wheels to the secondary figure wheels, and also to perform the step of taking an accumulator total. Therefore, when the secondary accumulator mechanism is employed, the totalizing lever is operated to 60 trip the machine in the unison, sub-total, accumulator and accumulator total operations. The machine is tripped in connection with the addition, subtraction and division operations by register bar 471, and in the 65 multiplication operation the machine is

tripped by the depression of the digit key, as heretofore described.

As will hereinafter more fully appear, unison key stem 667 is depressed by the totalizing lever when it is desired to transfer 70 the number from the primary figure wheels to the secondary accumulator wheels, and the sub-total key stem is depressed by the totalizing lever when it is desired to take a total of the numbers aggregated on the secondary accumulator wheels.

The depression of said key stems 667 and 668 by the operation of totalizing lever 2058, causes the downward movement of the T-shaped member 703 (Fig. 73) in exactly 80 the same manner as in the construction illustrated in Figs. 30 and 34. The totalizing lever is connected to a three-armed spider which is pivoted at 2057 on the right hand frame of the machine, and said T-shaped member 703 is connected at its lower end to arm 2056 of said spider. The totalizing lever is rigidly attached to said spider at 2057 and carries at its upper end a handle or grip 2059. When the operator pulls forward 90 said totalizing lever, the T-shaped member is depressed and carries with it stem 668, when said T-shaped member is in a position to engage pin 2061 carried thereby, or stem 667 when said T-shaped 95 member is in position to engage pin 2060 carried thereby; and the depression of said stems results in the unison or sub-total movements heretofore described, as the case may be.

As shown in Fig. 73, arm 2056 of the totalizing lever spider is provided at its end with a finger 2056^a which normally contacts with inclined surface 2184^a of detent lever 2184, which latter is pivoted at 441^a to 105 bracket 444, and kept in contact with said detent finger 2056^a by a spring 2185 anchored to the frame of the machine. Arm 2056 is also provided with a pin 2186 which is engaged by a slotted link 2188, which latter at its lower end is connected at 2189 to a link 2187, which is pressed downwardly by a spring 2190 anchored to the base of the machine. Said link 2187 is hinged at 2192^a to arm 2192 of a three-armed spider 2191. Said spider 2191 is pivoted on the right hand frame of the machine at 2193 and is operated to lock the totalizing lever after 110 the latter is actuated. The locking movement is effected through arm 2194, which 115 is provided with a forked end 2194^a which engages a pin 413^a of dash-pot pitman 419, heretofore described. The operation of this mechanism is as follows:—When totalizing lever 2058 is operated, detent finger 2056^a 120 engages notch 2184^b of detent lever 2184 through the action of spring 2185, thereby holding the totalizing lever in its tripped position until the cam shaft has nearly completed its rotation. At the same time when 125 130

the cam shaft rotates, as heretofore stated, dash-pot plunger 413^b will drop a limited distance, causing spider 2191 to rock correspondingly. Inasmuch as link 2187 is hinged 5 to arm 2192, said link will move backward and its notched end 2187^a will engage a square pin 2184^c on detent lever 2184. The movement in the opposite direction of the dash-pot plunger 413^b will cause link 2187 10 to move forward, and the engagement of notched end 2187^a with pin 2184^c will cause detent lever 2184 to swing forward, thereby disengaging finger 2056^a from notch 2184^b, thus releasing totalizing lever 2058. Notch 15 2187^a is thereupon disengaged from pin 2184^c by reason of the link connection 2188 between arm 2056 and link 2187.

It will be appreciated that should cam shaft 328 be tripped in an adding operation 20 the locking spider 2191 will be rocked in the same manner as when the machine is tripped for totalizing; and to prevent the operator from pulling the totalizing lever 2058 for a totalizing operation simultaneously with the depression of registry bar 471 and while the machine is tripped for adding, said spider 2191 is provided with an arm 2195, the end of which is brought into the path of finger 2143^a of arm 2143 25 of the totalizing lever spider when said spider is rocked.

The T-shaped member 703 is controlled 30 to engage pins on the unison stem 667 or sub-total stem 668 by the following means, best shown in Figs. 73 and 101: T-shaped member 703 carries a slotted arm 2062 and in said slot engages a pin 2063 fixed in plunger 2064 moving in bearing 2064^a in the right hand frame of the machine. Said 35 plunger is provided at one end with a roller 2065 which engages the surface of cam 2066 fixed to shaft 2068, said roller being held in contact with said cam by a spring 2067 secured at one end to pin 2063 and at its other 40 end to pin 2141 carried by a slide 2138. Shaft 2068 has a bearing (not shown) in the right hand frame of the machine and at the upper end of said shaft is secured a lever 2070 carrying handle or grip 2071. Said lever 2070 has four operative positions. As shown in Fig. 74, these positions are 45 represented by symbols 2072 indicating unison position, 2073 indicating sub-total position, 2074 indicating accumulator position and 2075 indicating accumulator total position. These symbols are arranged in any suitable manner beneath indicator lever 2070, as for instance, they may be carried by a suitable plate, or indicated on the casing of the 50 machine. When lever 2070 is moved to unison position 2072, cam 2066 is so disposed with reference to roller 2065 as to hold T-shaped member 703 in a position to engage pin 2061, so that stem 668 may be 55 lowered when the totalizing lever is actu-

ated, resulting, as heretofore set forth, in shifting the cam sleeve 473 into unison position and tripping the cam shaft for the performance of the unison operation.

When the lever 2070 is moved to sub-total 70 position 2073, said cam is so disposed as to bring the T-shaped member into engagement with pin 2060, whereby stem 667 may be pulled downward by the totalizing lever, thereby shifting the cam sleeve into sub-total position. If said lever is moved to the 75 accumulator position 2074, cam 2066 is so disposed as to shift member 703 into engagement with unison stem 667; and if the lever is moved to accumulator total position 80 2075 said cam is so disposed as to cause T-shaped member 703 to engage sub-total stem 668. It is necessary to have the cam sleeve in unison position while accumulating 85 a number on the secondary accumulator wheels, and it is also necessary to have the cam sleeve in the sub-total position while turning said secondary accumulator wheels back to zero when the operation of accumulator total is being performed. 90

For the purpose of tripping cam shaft 382 when totalizing lever 2058 is operated, a link 2146 is hinged on pin 2142 carried by arm 2143 of the totalizing lever spider. This link 2146 rests on a pin 2147 carried by 95 a lever 2148 pivoted at 2149 to bracket 444, and at its free end said link 2146 is provided with a hook 2146^a which, when link 2146 is moved, engages said pin 2147. Lever 2148 is slotted at its upper end, and in this slot 100 engages a pin 2150, which latter is fixed on trip lever 451 heretofore described (see Fig. 34). It will therefore be seen that through these connections, when the totalizing lever is operated, the cam shaft 382 will be 105 tripped.

It is very desirable that the symbols representing unison, sub-total, accumulator and accumulator total, should appear on the 110 printed page opposite their respective numbers, and means to this end are provided as follows: In mesh with gear 2069, carried by shaft 2068, is a gear 2076 fixed on rod 2077 carrying at its rear end gear 2078 (Fig. 74). In mesh with gear 2078 is a gear 2079 secured to sleeve 2080 shouldered in bearing 2081. This sleeve 2080 rotates on shaft 2082 and carries at its other end cam 2055 heretofore described, and illustrated in Fig. 70, Sheet 26. Bevel gear 2078 is also in mesh 115 with bevel gear 2083 rotating freely on shaft 2082 and carrying on its hub cam 2084 (Figs. 73 and 102). The periphery of said cam 2084 is engaged by a pin 2085 secured in the end of lever 2086, which lever is pivoted at 2087 on bracket 2088 fixed to main 120 rack guide 1153 (see Fig. 70). Said lever is forced toward said cam 2084 by a spring 2086^a. As indicator lever 2070 is turned 125 from the unison position toward sub-total 130

position, cam 2084 is rotated by means of the engagement of gears 2078 and 2083, and accordingly moves the upper end of lever 2086 a corresponding distance from the center of shaft 2082. Fixed on shaft 2082 is a stop disk 2089 provided with four notches, as shown in Figs. 73 and 102. These notches from the first to the fourth are in progression as to their radii from the center of shaft 2082, said radial progression corresponding to the increase of cam 2084. These notches are designed to abut the upper end of stop lever 2086, thus limiting the rotation of shaft 2082 according to the position to which indicator lever 2070 has been turned. Stop disk 2089 is fixed to the same hub as pinion 2090 and both are fixed rigidly to shaft 2082. In mesh with pinion 2090 is sector 2091, whose lever 2092 is pivoted at 2093 in bracket 2088, and is forced in one direction by a spring 2094. Lever 2092 carries a roller 2095, which roller contacts with cam 2096 mounted on shaft 9 (see Figs. 4 and 73, Sheets 4 and 27). It will be evident that as shaft 9 rotates and roller 2095 rides toward the lower part of cam 2096, shaft 2082 will be rotated by the engagement of rack 2091 with pinion 2090 and the extent of this rotation will be determined by the position of lever 2086, which is moved by cam 2084 and the position of which determines the notch on disk 2089 which is to engage the upper end thereof.

Shaft 2082 carries at one end pinion 2097 (Fig. 74) meshing with the teeth of a rack 2098, which rack is secured, as shown in Fig. 73, to type bar 2099, said type bar carrying unison character type 2100, subtotal character type 2101, accumulator character type 2102 and accumulator total character type 2103. In practice, type having the symbolical outlines shown in Fig. 74 are being used for these four characters. It will therefore be seen that the turning of indicator lever 2070 to any of its four positions results in the rotation of shaft 2077, and the turning of cam 2084 into one of four positions determines the degree of rotation of shaft 2082; that the rotation of said shaft is limited by the engagement with lever 2086 of one of the notches in disk 2089; and that through the engagement of gear 2097, fixed on shaft 2082, with rack 2098 fixed on type bar 2099, the appropriate character is brought opposite the printing line.

The types 2100, 2101, 2102 and 2103 are forced against the paper by hammer 2104, pivoted on rod 800, which latter is the same as heretofore described (Fig. 69, Sheet 24). Said type bar 2099 in practice is located in the type bar frame (Fig. 64, Sheet 24) in the position marked 2105 (Fig. 64, Sheet 22) between the plate 789 and the unit type bar, in order to place upon the printed page 65 these totalizing signs at the right of their

respective numbers. The hammer 2104 is actuated to strike the paper in the same manner as heretofore described for the other hammers. Cam 809 (Fig. 69, Sheet 24), which controls all the other type hammers, 70 controls this type hammer, and said type hammer is driven against the type by means of spring 2106 (Fig. 73). On the lower part of said hammer is provided a hook 799^a which is normally engaged by detent 2107 75 pivoted on rod 804 (Fig. 69), said detent 2107 corresponding with detent 803 (shown in Fig. 69) and being engaged by a spring (said engagement being similar to that of spring 804^a and eyelet 804^b, Fig. 69), whereby said detent is held in position. Detent 2107 carries a pin 2108 (Fig. 73), which pin is engaged by a bell-crank lever 2109 pivoted at 2110 on plate 789 (Fig. 64). The horizontal arm of bell-crank lever 2109 is provided with a slot in which a bent portion of the upper end of link 2111 engages. Said link 2111 is hinged at its lower end to lever 2112 which is fixed on shaft 729^d, shown in Fig. 27^a, Sheet 23. It will be remembered that 90 said shaft 729^d has a slight turning movement on its axis when the printer key 729 is depressed, whereby link 2111 is drawn downwardly, and by the mechanism just described detent 2107 will be disengaged from hook 799^a, thus releasing hammer 2104 so that it is free to strike one of the type in question.

Secondary accumulator control, (Sheets 26, 27 and 35; Figs. 70-74 and 103.)—Means 100 are herein provided whereby the secondary accumulator wheels are prevented from being moved into engagement with the sectors associated with the primary figure wheels, (which engagement, as heretofore described, was effected by means of cams 2011 and 2033 and cams 710 and 720, and the associated mechanism), except when the indicator handle 2070 is turned into accumulator position 2074 or accumulator total position 2075. 105 These means are clearly shown in Fig. 73, wherein is illustrated a collar 2113 preferably eccentrically mounted on one end of rod 2002, which rod carries the secondary accumulator wheels. On one end of shaft 110 102, which carries the primary figure wheels, is mounted a lever 2114, which lever at its upper end engages said collar 2113 and supports rod 2002, with the teeth of the secondary accumulator wheels 2001 engaged with racks 2015 (Fig. 70), as heretofore described. Whenever, therefore, it is desired to engage the secondary accumulator wheels with the teeth of sectors 87, it is necessary to remove the upper end of lever 2114 from engagement with rod 2002. This operation is effected by the following means: Hinged to lower end of lever 2114 is a link 2116, which is provided with a notch 2117. This link, 115 as shown in Fig. 73, is connected to one end 120 of lever 2114.

of link 2118, which in turn is connected to bell-crank 2119, which latter is pivoted at 2120 in the frame of the machine. The upper end of said bell-crank 2119, as clearly 5 shown in Fig. 103, engages a cam 2121, mounted on shaft 2068, and is held in contact therewith by spring 2119^a. The shape of said cam 2121 is such that when indicator lever 2070 is turned into accumulator position 2074 or accumulator total position 2075, 10 said cam will move said bell-crank against the tension of spring 2119^a, and will accordingly effect the engagement of notch 2117 with pin 2122, which latter is fixed on arm 2123 of the totalizing lever spider, heretofore described. It will be seen that, by reason of the engagement of said notch with 15 pin 2122, whenever the totalizing lever 2058 is pulled forward by the operator, lever 2114 will be removed from engagement with collar 2113, and the secondary accumulator wheels will then be free to be operated by 20 the means heretofore described.

Unison dog control in accumulator total, 25 (Sheet 27; Figs. 73 and 74.)—It has heretofore been stated that in taking an accumulator total, it was necessary that arms 2042, mounted on shaft 2043, must be operated to effect the disengagement of unison dogs 92 30 with unison pins 96, so that sectors 87 might be free to rotate a sufficient distance to bring the secondary accumulator wheels back to unison; and the means for effecting this result were described in detail. The means 35 for rotating shaft 2043 were not, however, described, and these means are as follows: There is provided on lever 2114 a forked arm 2114^a, and in the forked end of this arm engages a pin 2124 fixed to a lever 2125, 40 which latter is rigidly mounted on rod 2043, which also carries levers 2042, which engage and move unison dogs 92. It will, therefore, be seen that when said lever 2114 is 45 operated to disengage the upper end thereof from sleeve 2113, said arm 2114^a will act to rotate rod 2043 and accordingly to depress said levers 2042, thus lifting unison dogs 92 out of the path of unison pins 96.

Automatic operation of the printer key, 50 (Sheets 27 and 35; Figs. 73, 74, 101, 103 and 104.)—It has heretofore been shown that, in order to effect the recordation of any desired number or total on the paper, it is first necessary to depress printer key 729, in order to throw the printing mechanism into operation; and the connections between said printer key and the printing mechanism were fully described. It is possible, however, by the mechanism herein 55 after described, to effect automatically the depression of the printer key when totalizing lever 2058 is operated, this automatic printing operating taking place when the indicating lever 2070 is in accumulator position 2074, or in accumulator total position

2075. This automatic printing is very desirable in some forms of commercial work, especially in billing, wherein the several products are separately accumulated on the primary figure wheels by means of the multiplying attachment, during which time it is not desired to print the detailed operations of the machine. When, however, the different products are transferred from the primary figure wheels to the secondary accumulator 70 mechanism, it is desirable to have them printed, and this printing is effected automatically when the totalizing lever is pulled. It is also desirable at times to have the printer key remain continually in its depressed position,—when the totalizing lever is at “accumulator” or “accumulator total” position—so that all the detailed operations of the machine are recorded, and accordingly there are provided means for holding 75 said key in its lowermost position for this purpose.

Referring to Figs. 73 and 104, 2128 is a pin provided in the lower end of printer key stem 729^a, which pin engages in the 80 forked end of a lever 2129, mounted on a shaft 2130 supported in the side frames of the machine. On the other end of said shaft 2130 is mounted a second lever 2130^a, to which is pivoted a lever 2131, the front 85 end 2145 of which tends to move upward through the action of spring 2132 connected thereto. At its rear end said lever 2131 is provided with a notch 2133, said rear end also having connected thereto a link 2134, 90 which latter at its upper end is provided with a slot in which engages a pin 2135 carried in one end of a bell-crank 2136 pivoted at 2137 in the frame of the machine. The upper end of said bell-crank lever 2136 engages in a slot 2138^a (Fig. 101) of slide 2138, which latter has bearings in the side frame 95 of the machine. To the forward end of this slide is secured a member 2139, carrying in its rear end roller 2140, which roller engages the surface of cam 2066, and is held in such engagement by spring 2067, heretofore referred to. Cam 2066 is so shaped that 100 when indicator lever 2070 is turned to accumulator position 2074 or accumulator total 105 position 2075, the slide 2138 is moved forward, causing bell crank lever 2136 to be rocked and link 2134 to be depressed, thus effecting the engagement of notch 2133 with a pin 2142 carried by arm 2143 of the totalizing lever spider; and accordingly, when the totalizing lever 2058 is moved forward 110 lever 2131 will be given a rearward movement, which will rock said shaft 2130 and cause said printer key 729 to be depressed, 115 in which position it will be locked during the revolution of the cam shaft by the locking of the totalizing lever, as heretofore described, and while so locked the printing takes place.

Upon the return to normal position of totalizing lever 2058, by means of its spring 2144 secured at one end to arm 2123 of the totalizing lever spider and at the other end 5 to the frame of the machine, lever 2131 being in engagement with pin 2142, the printer key will be caused to rise automatically. So long, therefore, as the indicator handle 2070 is in accumulator position 2074 or accumulator 10 total position 2075, the printing operation will be automatically effected when the totalizing lever is operated, but none of the intermediate detailed operations of the machine will be recorded, unless what is called 15 the "detail accumulation key" 2127 is depressed.

There are certain times when the indicator lever is in accumulator position or accumulator total position, when it is desirable that 20 the printer key 729^a remain continually in its depressed position and not be automatically elevated or depressed by the operation of the totalizing lever. An instance of this class of work is in cross-footing, where all 25 the details of each accumulation on the primary figure wheels are printed. This detail accumulation key 2127 (see Fig. 104) is mounted in bearings on the right-hand frame of the machine and is in line, directly across 30 the machine, with printer key 729. When this key 2127 is depressed, its lower end comes in contact with the forward end 2145 of lever 2131 (see Fig. 73), thus disengaging the rear end of lever 2131 from pin 2142 carried 35 by arm 2143, and hence, while this key 2127 remains depressed, the printer key will also remain in its lowermost position, whereby the desirable result of having all the detail operations of the machine recorded is 40 effected.

The printer key stem 729^a is held in its elevated or depressed position by the provision in its stem of two notches 729^b and 729^c (Fig. 104), which are arranged to be engaged by a lug carried at one end of a spring 729^d mounted on cross bar 149^b secured to the side frames of the machine. When the lug on the end of the spring enters either of these notches, the printer key is retained in 50 its raised or depressed position. The accumulation detail key is maintained in its raised or depressed position by a similar construction, the notches being indicated as 2127^b and 2127^c, and the spring carrying the lug as 2127^d. Said detail accumulation key 55 2127 is raised or lowered manually. The printer key 729 is likewise raised and lowered at the will of the operator by hand, though, as heretofore stated, it may be raised and lowered automatically by the totalizing lever, and will be so operated as long as detail accumulation key 2127 is in its elevated 60 position. When, however, said key is depressed so that lever 2131 is disengaged from pin 2142 of the totalizing lever spider, it

will be apparent that the printer key 729 will not be affected by the operation of the totalizing lever.

Automatic vertical and cross feed of the printer platen, (Sheets 28 and 36; Figs. 75, 70 76, 77, 78, 105, 106 and 107).—There has heretofore been described means for automatically effecting the vertical feed of the platen from cam shaft 382 through cams 937 and 938, and means manually operated 75 (lever 985) for effecting the cross feed of the platen. It is sometimes desirable, however, to effect both the vertical and cross feed of the platen automatically, and a construction for performing these functions is 80 illustrated in the figures above indicated.

On cam sleeve 473 mounted on cam shaft 382 is a cam 2151 (Fig. 75). The surface of this cam is engaged by a roller 2152 which is carried by the lower end of a lever 2153 85 which latter is mounted on shaft 751, which, as heretofore stated, carries printing gears 750. Roller 2152 is held in contact with said cam 2151 by means of spring 2158 connected to the upper end of said lever 2153. This 90 lever 2153 is provided with an arm 2154 which projects in the path, and engages the lower end of a plunger 2155, which latter is mounted in bearings 2156 and 2157. Bearing 2156 is carried by a cross rod 2156^a (Figs. 95 75 and 76), and to one end of this cross-rod is secured a small bracket 2156^b which carries in its lower end a bearing for printer key shaft 729^d. Said bracket 2156^b is in turn secured to main cross-tie 1153, Fig. 70. The 100 upper end of said plunger 2155 contacts with a lever 2159 which is fixed to one member 2160 of a clutch, and is mounted in said bearing 2157 (Figs. 75, 76 and 105). This member 2160 is provided with a slot in 105 which the other member 2161, which is likewise mounted in bearing 2157, engages. To member 2161 is attached a lever 2162. Both the lever 2162 and member 2161 are securely fastened to a sliding shaft 2163 provided at 110 one end with a groove in which the lower end of a lever 2164 engages. This lever is pivoted at 2165 on said bearing 2157. Lever 2164 is forked at its upper end, as shown in Fig. 76, and in said forked end engages an 115 eccentric collar 2166 mounted on shaft 2167 having bearings in the case of the machine. On the end of said shaft 2167 is mounted a knob 2169 which carries a pointer 2170 (Fig. 76). 120

At its upper end lever 2162 is provided with a rounded surface which is arranged to engage one end of lever 923, pivoted at 2172, the upper end of said lever 923 being provided with a fork in which engages rod 922 (Figs. 4, 75 and 76) which is part of the vertical feed bail for the platen, heretofore described. Said lever 2162 is also arranged to engage lever 977, heretofore described, in connection with the manually 125 130

operated cross feed of the platen. When it is desired to shift said lever 2162 to effect an automatic vertical or cross-feed of the platen, knob 2169 is turned, and the rotation of eccentric sleeve 2166 will cause lever 2164 to rotate about its pivot 2165, thus moving rod 2168 longitudinally, and accordingly shifting lever 2162 from cross-feed lever 977 to vertical feed lever 923, or vice 10 versa.

In the construction illustrated in the figures above indicated, the form of escapement rack 969, heretofore described and illustrated in Fig. 47 is slightly changed. 15 As illustrated in these figures, and particularly in Fig. 106, the same is shown as a rack, star-shaped in cross-section, each of the ridges of which is provided with a plurality of notches 969^x, said notches on each 20 ridge being spaced apart at varying distances. The operation of this rack with respect to the cross-feed escapement is the same as that heretofore described.

On one end of the shaft which carries 25 rack 969 is mounted a notched disk 2174 (Figs. 77 and 78 and 106), in the notches of which engages one end of a spring-pressed plunger 2175 mounted on plate 899, the function of said plunger being to hold said 30 disk, and accordingly said notched rack, in a fixed position. The edge of said disk is provided with two sets of notches 2174^a and 2174^b, the former being deeper than the latter. When said plunger 2175 engages the 35 deeper notches, the rack is held so that one of its notched ridges is in the path of the escapement levers 977 and 979. When the said plunger 2175 engages one of the shallower notches 2174^b, the escapement rack 40 is held so that its notches are out of engagement with escapement levers 977 and 979 (Fig. 107), which latter then are in engagement at their upper ends with an adjustable spacing bar 2176 (Fig. 76). This bar 45 2176, which is mounted in the end plates of the carriage, carries a plurality of double check nuts 2177 and 2177', which may be set to any position on the rod, so that, if it is desired that the spacing of the printed 50 page be different from that obtainable with the arrangement of notches on the escapement rack 969, this may be effected by moving the nuts 2177 and 2177' to any desired position, and adjusting them on said rod 2176. Nut 2177 of each of the pairs of 55 double nuts has a bevel face, as shown, over which the working points of the double dog escapement levers 977 and 979 may readily pass. The other of said double nuts 2177' 60 has a square face against which the working points of said levers abut, in which position the carriage is held from advancing to the left. As shown in Fig. 76, nuts 2178 and 2179 are mounted on the ends of said 65 rod 2176, and are used to secure said shaft

in position in slots 2176^a in the end plates. When it is desired to disengage notched rack 969 from escapement levers 977 and 979, the shaft on which said rack is mounted is turned so that plunger 2175 engages a shallow notch 2174^b, and said shaft 2176 is moved to point 2181 of said slot 2176^a, in which position the double check nuts 2177 are in the path of the working points of the escapement levers 977 and 979. When 70 75 said shaft occupies position 2180 in said slot 2176^a the check nuts 2177 are out of the path of said escapement levers.

When, as heretofore described, shaft 751 is shifted lengthwise for the purpose of disconnecting printer gears 750 from racks 747, lever 2153 is also shifted and accordingly its arm 2154 is moved out of the path of the lower end of the plunger 2155. This, of course, renders it impossible to operate 85 plunger 2155, and thereby prevents either a vertical or cross-feed of the printer platen when the printer mechanism is disconnected.

While there has heretofore been described in detail one expression of the inventive 90 idea, it will be appreciated that other mechanical embodiments may be had without departing from the spirit of the invention and that the invention is not limited to the particular construction shown and described; the breadth of the invention being 95 indicated in the appended claims.

What is claimed is—

1. In a calculating machine, a plurality of figure wheels, rotating mechanism for 100 said wheels, a rotating carrier, a plurality of normally inoperative key stops carried thereby, means for rendering one or more of said stops operative, and means advancing said rotating means in a line parallel with the axis of rotation of said carrier into contact with said operative stops.

2. In a calculating machine, a plurality of figure wheels, independent rotating mechanism for each of said figure wheels including a rod, a rotating carrier, a plurality of normally inoperative stop pins carried thereby, means for rendering one or more of said stop pins operative, and means advancing said rods in a line parallel with the axis of rotation of said carrier into contact with said operative pins. 110 115

3. In a calculating machine, the combination with a series of figure wheels, of a carrier rotating on a horizontal axis, a plurality of normally-inoperative key stops carried thereby, means for rendering one or more of said stops operative, mechanism for rotating said figure wheels, and means for advancing said rotating mechanism into said carrier into contact with one or more of said operative stops to limit the movement of one or more of said figure wheels. 120 125

4. In a calculating machine, the combination with a series of figure wheels, of a ro- 130

- 5 tating carrier, a series of rows of normally
inoperative key stops carried thereby, means
for rendering any one stop in one or more
rows operative, independent rotating mecha-
nism for each of said figure wheels, and
means for advancing said rotating mecha-
nism into said carrier in contact with said
operative key stop to limit the rotation of
said figure wheels.

10 5. In a calculating machine, the combina-
tion with a series of figure wheels, of a rot-
ating carrier, a continuous series of rows of
normally inoperative key stops carried
thereby, means for rendering any one stop
15 in one or more rows operative, independent
rotating mechanism for each of said figure
wheels, and means for advancing said rotat-
ing mechanism into said carrier in contact
20 with said operative key stop to limit the ro-
tation of said figure wheels.

25 6. In a calculating machine, the combi-
nation with a series of figure wheels, of a car-
rier rotating in one direction only, a continu-
ous series of rows of normally inopera-
tive key stops carried thereby, means for
30 rendering any one stop in one or more rows
operative, independent rotating mechanism
for each of said figure wheels, and means for
advancing said rotating mechanism into said
35 carrier in contact with said operative key
stop to limit the rotation of said figure
wheels.

40 7. In a calculating machine, the combina-
tion with a series of figure wheels, of a car-
rier rotating on a horizontal axis, a series of
rows of normally inoperative key stops car-
ried thereby, means for rendering any one
45 stop in one or more rows operative, inde-
pendent rotating mechanism for each of said
figure wheels, and means for advancing said
rotating mechanism into said carrier in con-
50 tact with said operative key stop to limit the
rotation of said figure wheels.

55 8. In a calculating machine, the combina-
tion with a series of figure wheels, of a car-
rier rotating on a horizontal axis, in one di-
rection only, a continuous series of rows of
key stops carried thereby, means for render-
60 ing any one stop in one or more rows oper-
ative, independent rotating mechanism for
each of said figure wheels, and means for
advancing said rotating mechanism into said
65 carrier in contact with said operative key
wheels.

70 9. In a calculating machine, the combina-
tion with a series of figure wheels, of a rot-
ating carrier comprising a plurality of rela-
tively fixed plates, a plurality of normally
65 inoperative key stops carried by each plate,
means for rendering one or more stops oper-
ative, independent rotating means for each
of said figure wheels, and means for ad-
vancing said rotating mechanism into said
75 carrier in contact with said operative key
wheels.

80 10. In a calculating machine, the combi-
nation with a series of figure wheels, of a car-
rier rotating on a horizontal axis and
comprising a plurality of relatively fixed
85 plates, a plurality of normally inoperative
key stops carried by each plate, means for
rendering one or more stops operative, inde-
pendent rotating means for each of said
90 figure wheels, and means for advancing said
rotating mechanism into said carrier in con-
tact with said operative key stop to limit the
rotation of said figure wheel.

95 11. In a calculating machine, the combi-
nation with a series of figure wheels, of a rot-
ating carrier, a series of rows of normally
inoperative key stops carried thereby, means
100 rendering any one stop in one or more rows
operative, independent rotating mechanism
for each of said figure wheels including a
rod, and means for advancing said rod into
105 said carrier in contact with an operative key
stop in one of said rows to limit the rotation
of said figure wheel.

110 12. In a calculating machine, the combi-
nation with a series of figure wheels, of a rot-
ating carrier, a series of rows of key stops
provided with perforations which are in
115 alinement when said key stops are in their
normal inoperative position, means render-
ing any one stop in one or more rows oper-
ative, independent rotating mechanism for
120 each of said figure wheels including a rod,
and means for advancing said rod into said
carrier in contact with an operative key stop
in one of said rows to limit the rotation of
125 said figure wheel.

13. In a calculating machine, the combina-
tion with a series of figure wheels, of a car-
rier rotating on a horizontal axis, a series of
rows of key stops provided with perfora-
130 tions which are in alinement when said key
stops are in their normal inoperative pos-
ition, means rendering any one stop in one
or more rows operative, independent rotat-
ing mechanism for each of said figure wheels
including a rod, and means for advancing
said rod into said carrier in contact with an
operative key stop in one of said rows to
limit the rotation of said figure wheel.

14. In a calculating machine, the combina-
tion with a series of figure wheels, of a rot-
ating carrier, a plurality of rows of key
stops carried thereby, independent rotating
140 mechanism for each of said figure wheels ar-
ranged to project into said carrier to de-
termine the degree of rotation of said figure
wheel, obturating means preventing said
movement of said rotating mechanism when
145 said key stops are in their normal inoperative
position, means for rendering one stop in one
or more rows operative and simultaneously
removing said obturating means, and means
150 for projecting said rotating mechanism into
155

said carrier in contact with said operative stop to limit the rotation of said figure wheel.

15. In a calculating machine, the combination with a series of figure wheels, of a rotating carrier, a series of rows of normally inoperative key stops carried thereby, independent rotating mechanism for each of said figure wheels including a rod for each of said rows of stops, obturating means for preventing said rod from projecting into said carrier when said stops are in their inoperative position, means for rendering one stop in one or more rows operative and simultaneously removing said obturating means, and means for advancing said rod into said carrier in contact with said operative stop to limit the rotation of said figure wheel.

20. 16. In a calculating machine, the combination with a series of figure wheels, of a rotating carrier, a plurality of rows of key stops carried thereby, independent rotating mechanism for each of said figure wheels including a rod, pivoted obturating means for each row of stops for preventing said rod from projecting into said carrier when said stops are in their normal inoperative position, means for rendering one stop in one or more rows operative and simultaneously removing said obturating means, and means for advancing said rod into said carrier in contact with said operative stop to limit the rotation of said figure wheel.

35. 17. In a calculating machine, the combination with a series of figure wheels, of a rotating carrier, independent rotating mechanism for each of said figure wheels, a plurality of rows of key stops carried thereby, the stops in each row being provided with perforations which are in alinement when said stops are in their normally inoperative position, obturating means in line with said perforations, means for rendering one stop in one or more rows operative and simultaneously removing said obturating means, and means for advancing said rotating means into said perforations in contact with said operative stop to limit the rotation of said figure wheel.

50. 18. In a calculating machine, the combination with a series of figure wheels, of a rotating carrier, a plurality of rows of key stops carried thereby, independent rotating mechanism for each of said figure wheels including a rod, spring-pressed pivoted obturating means for each row of stops for preventing said rod from projecting into said carrier when said stops are in their normal inoperative position, means for rendering one stop in one or more rows operative and simultaneously removing said obturating means, and means for advancing said rod into said carrier in contact with

said operative stop to limit the rotation of 65 said figure wheel.

19. In a calculating machine, the combination with a series of figure wheels, of a rotating carrier, independent rotating mechanism for each of said figure wheels, a plurality of rows of key stops carried thereby, the stops in each rod being provided with perforations which are in alinement when said stops are in their normally inoperative position, spring-pressed, pivoted obturating 70 means in line with said perforations, means for rendering one stop in one or more rows operative and simultaneously removing said obturating means, and means for advancing said rotating means into said perforations 75 in contact with said operative stop to limit the rotation of said figure wheel.

20. In a calculating machine, the combination with a series of figure wheels, of a rotating carrier, a plurality of rows of key 80 stops carried thereby, independent rotating mechanism for each of said figure wheels, pivoted obturating means for each row of stops for preventing said rotating means from projecting into said carrier when said 85 stops are in their normal inoperative position, means for rendering one stop in one or more rows operative and simultaneously removing said obturating means, and means for advancing said rotating mechanism into 90 engagement with said operative key stop to limit the rotation of said figure wheel, means for retaining said stops in their operative 95 position, and means for automatically restoring them to their inoperative position. 100

21. In a calculating machine, the combination with a series of figure wheels, of a carrier having a plurality of series of normally inoperative key stops, a plurality of downwardly-pressed key stems, means for 105 maintaining the latter in an elevated position, means for releasing said stems, connections therebetween and said key stops whereby the latter are rendered operative, 110 rotating mechanism for said figure wheels, and means for advancing said mechanism into contact with said operative stops.

22. In a calculating machine, the combination with a series of figure wheels, of a carrier having a plurality of series of normally inoperative key stops, a plurality of key stems spring-pressed downwardly, means for maintaining the latter in an elevated position, means for releasing said stems, connections therebetween and said 115 key stops to render the latter operative, rotating mechanism for said figure wheels, and means for advancing said mechanism into contact with said operative stops.

23. In a calculating machine, the combination with a series of figure wheels, of a carrier having a plurality of series of normally inoperative key stops, a plurality of

downwardly-pressed key stems, means for maintaining the latter in an elevated position, an upwardly-pressed key stem associated with each downwardly-pressed key 5 stem, connections between said upwardly and said downwardly-pressed key stem to release the latter, connections between said downwardly-pressed key stems and said key stops to render the latter operative, rotating 10 mechanism for said figure wheels, and means for advancing said mechanism into contact with said operative stops.

24. In a calculating machine, the combination with a series of figure wheels, of a 15 carrier having a plurality of series of normally inoperative key stops, a plurality of downwardly-pressed key stems, means for maintaining the latter in an elevated position, a key stem spring-pressed upwardly as- 20 sociated with each downwardly-pressed key stem, connections between said upwardly and said downwardly-pressed key stem to release the latter, connections between said downwardly-pressed key stems and said key 25 stops to render the latter operative, rotating mechanism for said figure wheels, and means for advancing said mechanism into contact with said operative stops.

25. In a calculating machine, the combi- 30 nation with a series of figure wheels, of a carrier having a plurality of series of normally inoperative key stops, a plurality of downwardly-pressed key stems, a lever pivoted to each of said stems and retaining it 35 in an elevated position, an upwardly-pressed key stem associated with each downwardly-pressed key stem, a ram acting on each lever and operable by said upwardly-pressed key stems to release said downwardly-pressed 40 key stems, connections between the latter and said key stops to render said key stops operative, rotating mechanism for said figure wheels, and means for advancing said mechanism into contact with said operative 45 stops.

26. In a calculating machine, the combi- 50 nation of a plurality of downwardly-pressed key stems, a guide or abutment, a hook carried by each stem engaging said guide, a lever carried by each stem engaging said hook, an upwardly-pressed key stem associated with each downwardly-pressed stem, a ram engaging said lever and operable by said last-mentioned key stem to release said 55 downwardly-pressed key stem, a carrier, a plurality of normally inoperative stops carried thereby, connections between said stops and said downwardly-pressed stems whereby the former are rendered operative, a plu- 60 rality of figure wheels, independent rotating mechanism therefor, and means for advancing said rotating mechanism into contact with said operative stops.

27. In a calculating machine, the combi-

nation with a series of figure wheels, of a 65 carrier having a plurality of series of nor- 70 mally inoperative key stops, a plurality of downwardly-pressed key stems, means for maintaining the latter in an elevated position, means for releasing said stems, connections therebetween and said key stops whereby the latter are rendered operative, 75 rotating mechanism for said figure wheels, means for advancing said mechanism into contact with said operative stops, and means 80 engaging said downwardly-pressed key stems for positively returning the same to their elevated position.

28. In a calculating machine, the combination with a series of figure wheels, of a 80 carrier having a plurality of series of nor- 85 mally inoperative key stops, a plurality of downwardly-pressed key stems, means for maintaining the latter in an elevated position, means for releasing said stems, connections therebetween and said key stops whereby the latter are rendered operative, 90 rotating mechanism for said figure wheels, means for advancing said mechanism into contact with said operative stops, and rotat- 95 ing means engaging said downwardly-pressed key stems for positively returning the same to their elevated position.

29. In a calculating machine, the combi- 100 nation with a series of figure wheels, of a 105 rotating carrier having a plurality of series of normally inoperative key stops, a plu- 110 rality of downwardly-pressed key stems, means for maintaining the latter in an ele- 115 vated position, means for releasing said 120 stems, connections therebetween and said key stops whereby the latter are rendered operative, rotating mechanism for said figure wheels, means for advancing said mechanism into contact with said operative stops, and means 125 rotating with said carrier and engaging said downwardly-pressed key stems for positively returning the same to their elevated position.

30. In a calculating machine, the combi- 110 nation with a series of figure wheels, of a 115 rotating carrier having a plurality of series of normally inoperative key stops, a plu- 120 rality of downwardly-pressed key stems, means for maintaining the latter in an ele- 125 vated position, means for releasing said stems, connections therebetween and said key stops whereby the latter are rendered operative, rotating mechanism for said figure wheels, means for advancing said mechanism into contact with said operative stops, and means connected to and rotating with said carrier and engaging said downwardly-pressed key stems for positively returning the same to their elevated position.

31. In a calculating machine, the combi- 125 nation with a series of figure wheels, of a rotating carrier having a plurality of series

- of normally inoperative key stops, a plurality of key stems spring-pressed downwardly, means for maintaining the latter in an elevated position, means for releasing 5 said stems, connections therebetween and said key stops to render the latter operative, rotating mechanism for said figure wheels, means for advancing said mechanism into contact with said operative stops, a shaft 10 connected to and rotating with said carrier, a plurality of cams carried thereby and engaging said downwardly-pressed key stems to positively return the same to their elevated position.
- 15 32. In a calculating machine, the combination with a series of figure wheels, of a rotating carrier having a plurality of series of normally inoperative key stops, a plurality of key stems spring-pressed downwardly, means for maintaining the latter in an elevated position, means for releasing 20 said stems, connections therebetween and said key stops to render the latter operative, rotating mechanism for said figure wheels, means for advancing said mechanism into contact with said operative stops, a shaft 25 connected to and rotating with said carrier, a foot carried by each downwardly-pressed key stem, a plurality of cams carried by said shaft and engaging said feet when said stems are in their lowermost released position and positively returning the same to their elevated position.
33. In a calculating machine, the combination with a series of figure wheels, of a carrier having a plurality of series of normally inoperative stops, a plurality of downwardly-pressed key stems, means for maintaining the latter in an elevated position, 35 an escapement for said carrier, means for releasing said stems, connections between said stems and escapement whereby the latter is operated on the downward movement of said stems, connections between said key stems and key stops whereby the latter are rendered operative, rotating mechanism for said figure wheels, and means for advancing said mechanism into contact with said operative stops.
- 50 34. In a calculating machine, the combination with a series of figure wheels, of a carrier having a plurality of series of normally inoperative stops, a plurality of downwardly-pressed key stems, means for maintaining the latter in an elevated position, 55 an escapement for said carrier, means for releasing said stems, connections between said stems and escapement whereby the latter is operated on the downward movement of said stems, connections between said key stems and key stops whereby the latter are rendered operative, rotating mechanism for said figure wheels, means for advancing said mechanism into contact with

65 said operative stops, and means automatically engaging said key stems and returning the same to their elevated position.

35. In a calculating machine, the combination with a plurality of figure wheels, of rotating mechanism therefor, a rotating 70 carrier, a plurality of series of normally inoperative stop pins carried thereby, key mechanism for rendering one or more of said pins operative, means for advancing said rotating mechanism into contact with 75 said operative pins to limit the rotation of said figure wheels, an escapement mechanism for said carrier releasing said carrier upon the downward movement of said key mechanism, and means connected to said 80 carrier and elevating said key mechanism simultaneously with the rotation of said carrier.

36. In a calculating mechanism, the combination with a plurality of figure wheels, of 85 rotating mechanism therefor, a rotating carrier, a plurality of series of normally inoperative stop pins carried thereby, key mechanism for rendering one or more of said pins operative, means for advancing said 90 rotating mechanism into contact with said operative pins to limit the rotation of said figure wheels, a rotary escapement mechanism for said carrier releasing said carrier upon the downward movement of said key 95 mechanism, and means connected to said carrier automatically engaging said key mechanism and elevating the same simultaneously with the rotation of said carrier.

37. In a calculating machine, the combination with a plurality of figure wheels, of 100 rotating mechanism therefor, a rotating carrier, a plurality of series of normally inoperative stop pins carried thereby, key mechanism for rendering one or more of 105 said pins operative, means for advancing said rotating mechanism into contact with said operative pins to limit the rotation of said figure wheels, an escapement mechanism for said carrier comprising a wheel, a plurality of normally-restrained pins carried thereby, an abutment for said pins, and means for releasing a desired pin to determine the degree of rotation of said carrier.

115 38. In a calculating machine, the combination with a plurality of figure wheels, of rotating mechanism therefor, a carrier rotating on a horizontal axis, a plurality of series of normally inoperative stop pins carried thereby, key mechanism for rendering one or more of said pins operative, means for advancing said rotating mechanism into contact with said operative pins to limit the rotation of said figure wheels, an escapement wheel mounted on the carrier axis, a plurality of normally-restrained pins carried thereby, an abutment for said pins, and

means for releasing a desired pin for engagement with said abutment to determine the degree of rotation of said carrier.

39. In a calculating machine, the combination with a plurality of figure wheels, of a rotating mechanism therefor, a rotating carrier, a plurality of series of normally-inoperative stop pins carried thereby, key mechanism for rendering one or more of said pins operative, means for advancing said rotating mechanism into contact with said operative pins to limit the rotation of said figure wheels, an escapement wheel connected to the carrier, a plurality of normally-restrained radially-disposed pins carried thereby, an abutment for said pin, and means for releasing a desired pin for engagement with said abutment to determine the degree of rotation of said carrier.

20 40. In a calculating machine, the combination with a plurality of figure wheels, of a rotating mechanism therefor, a rotating carrier, a plurality of series of normally inoperative stop pins carried thereby, key mechanism for rendering one or more of said pins operative, means for advancing said rotating mechanism into contact with said operative pins to limit the rotation of said figure wheels; an escapement wheel connected to the carrier, a plurality of normally restrained pins carried thereby, an abutment normally engaged by one of said pins, and means for disengaging said pin from said abutment and releasing a desired pin for engagement with said abutment to determine the degree of rotation of said carrier.

25 30 35

41. In a calculating machine, the combination with a plurality of figure wheels, of rotating mechanism therefor, a rotating carrier, a plurality of series of normally inoperative stop pins carried thereby, key mechanism for rendering one or more of said pins operative, means for advancing said rotating mechanism into contact with said 45 operative pins to limit the rotation of said figure wheels, an escapement wheel connected to the carrier, a plurality of normally-restrained pins carried thereby, an abutment normally engaged by one of said pins, and means for simultaneously disengaging 50 said pin from said abutment and releasing a desired pin for engagement with said abutment to determine the degree of rotation of said carrier.

55 42. In a calculating machine, the combination with a plurality of figure wheels, of rotating mechanism therefor, a rotating carrier, a plurality of series of normally-inoperative stop pins carried thereby, key
60 mechanism for rendering one or more stop pins operative, means for advancing said rotating mechanism into contact with said operative stop pins to limit the rotation of said figure wheels, an escapement wheel, a

plurality of normally-restrained pins carried thereby, an abutment normally engaged by one of said pins, and means operated by said key mechanism for disengaging said pin from said abutment and releasing a desired pin for engagement with said abutment to determine the degree of rotation of said carrier. 65 70

43. In a calculating machine, the combination with a plurality of figure wheels, of rotating mechanism therefor, a rotating carrier, a plurality of series of normally-inoperative stop pins carried thereby, key mechanism for rendering one or more stop pins operative, means for advancing said rotating mechanism into contact with said operative stop pins to limit the rotation of said figure wheels, an escapement wheel, a plurality of normally-restrained pins carried thereby, an abutment normally engaged by one of said pins, and means simultaneously operated by said key mechanism for disengaging said pin from said abutment and releasing a desired pin for engagement with said abutment to determine the degree of rotation of said carrier. 75 80 85 90

44. In a calculating machine, the combination with a plurality of figure wheels, of rotating mechanism therefor, a rotating carrier, a plurality of series of normally-in-operative stop pins carried thereby, key 95 mechanism for rendering one or more stop pins operative, means for advancing said rotating mechanism into contact with said operative stop pins to limit the rotation of said figure wheels, an escapement wheel, a 100 plurality of normally-restrained pins carried thereby, an abutment normally engaged by one of said pins, a pivoted bail operated by said key mechanism, a ram operated by said bail to release said pin from said abutment, and means operated by said bail to release a desired pin for engagement with said abutment to determine the degree of rotation of said carrier. 105

45. In a calculating machine, the combination with a plurality of figure wheels, of rotating mechanism therefor, a rotating carrier, a plurality of series of normally-inoperative stop pins carried thereby, key mechanism for rendering one or more stop pins operative, means for advancing said rotating mechanism into contact with said operative stop pins to limit the rotation of said figure wheels, an escapement wheel, a plurality of normally restrained pins carried thereby, an abutment normally engaged by one of said pins, a pivoted bail operated by said key mechanism, a ram operated by said bail to release said pin from said abutment, and means simultaneously operated by said bail to release a desired pin for engagement with said abutment to determine the degree of rotation of said carrier. 110 115 120 125

46. In a calculating machine, the combination with a plurality of figure wheels, of rotating mechanism therefor, a rotating carrier, a plurality of series of normally-inoperative stop pins carried thereby, key mechanism for rendering one or more stop pins operative, means for advancing said rotating mechanism into contact with said operative stop pins to limit the rotation of said figure wheels, an escapement wheel, a plurality of normally-restrained pins carried thereby, an abutment normally engaged by one of said pins, a plurality of cipher key stems and lever mechanism associated with each stem and one of said normally-restrained pins whereby said pin is released upon the downward movement of said stem.

47. In a calculating machine, the combination with a plurality of figure wheels, of rotating mechanism therefor, a rotating carrier, a plurality of series of normally-inoperative stop pins carried thereby, key mechanism for rendering one or more stop pins operative, means for advancing said rotating mechanism into contact with said operative stop pins to limit the rotation of said figure wheels, an escapement wheel, a plurality of normally-restrained pins carried thereby, an abutment normally engaged by one of said pins, a plurality of cipher key stems, a shaft, a plurality of lever mechanisms mounted thereon one being associated with each stem and one of said pins and means carried by each of said stems operating a lever mechanism to release one of said pins.

48. In a calculating machine, the combination of a plurality of figure wheels, rotating mechanism for said figure wheels, a rotating carrier, a plurality of series of rows of normally inoperative stop pins, key mechanism for rendering one or more of said stop pins operative, means for advancing said rotating mechanism into contact with said operative stop pins, means for locking a depressed key mechanism in its lowermost position and the other key mechanisms in their elevated positions during the rotation of the carrier, and means engaging said depressed key mechanisms and returning them to their elevated position.

49. In an escapement mechanism, a movable element, a plurality of normally-restrained pins carried thereby, an abutment for a released pin, means for restoring said released pin to its normally-restrained position and simultaneously releasing a predetermined pin to permit of the desired degree of movement of said movable element.

50. In an escapement mechanism, a rotating element, a plurality of normally-restrained pins carried thereby, an abutment for a released pin, means for removing said released pin from said abutment and simultaneously releasing a predetermined pin to

permit of the desired degree of movement of said rotating element.

51. In an escapement mechanism, an escapement wheel, a plurality of radially-disposed spring-pressed pins carried thereby, dogs engaging said pins and preventing radial movement thereof, an abutment for a released pin, means for removing said released pin from said abutment and simultaneously releasing a predetermined pin to permit of the desired degree of rotation of said escapement wheel.

52. In an escapement mechanism, an escapement wheel, a plurality of normally-restrained pins carried thereby, a dash-pot, an abutment for a released pin provided on the dash-pot plunger, means for removing said released pin from said abutment and simultaneously releasing a predetermined pin to permit of the desired degree of movement of said escapement wheel.

53. In combination, a plurality of downwardly-pressed key stems normally held in an elevated position, an escapement wheel, a plurality of normally-restrained pins carried thereby, an abutment for a released pin, and means operated upon the release of a predetermined key stem for removing said released pin from said abutment and simultaneously releasing another pin to permit of the desired degree of rotation of said escapement wheel.

54. In combination, a rotating carrier, a plurality of downwardly-pressed key stems normally held in an elevated position, an escapement wheel for said carrier, a plurality of normally-restrained pins carried thereby, an abutment for a released pin, means operated upon the release of a predetermined key stem for removing said released pin from said abutment and simultaneously releasing another pin to permit of the desired degree of rotation of said carrier, and means automatically returning said released key stem to its elevated position.

55. In combination, a rotating carrier, a plurality of key stems, an escapement wheel for said carrier, a plurality of pins carried thereby, retaining means for preventing movement of said pins, an abutment for a released pin, means operated upon the depression of a key stem for removing a released pin from said abutment, and lever mechanism acting upon one of said retaining means and operated upon the depression of a predetermined key stem to release a predetermined pin to permit of the desired degree of movement of said carrier.

56. In combination, a rotating carrier, a plurality of key stems, an escapement wheel for said carrier, a plurality of pins carried thereby, pivoted dogs preventing movement of said pins, an abutment for a released pin, means operated upon the depression of a key stem for removing a released pin from

said abutment, and lever mechanism acting upon one of said retaining means and operated upon the depression of a predetermined key stem to release a predetermined pin to 5 permit of the desired degree of movement of said carrier.

57. In combination, a rotating carrier, a plurality of key stems, an escapement wheel for said carrier, a plurality of pins carried thereby, retaining means for preventing movement of said pins, an abutment for a released pin, a pivoted lever operated upon the depression of a key stem for removing a released pin from said abutment, and lever 10 mechanism operated upon the depression of a predetermined key stem to release a predetermined pin to permit of the desired degree of movement of said carrier.

58. In combination, a rotating carrier, a plurality of key stems, a rotating escapement wheel for said carrier, a plurality of radially-disposed pins carried thereby, retaining means for each pin preventing movement thereof, an abutment for a released pin, means operated upon the depression of a key stem for removing a released pin from said abutment, a pivoted lever associated with each of a plurality of said retaining means and operated upon the depression of a predetermined key stem to release a predetermined pin to permit of the desired degree of movement of said carrier.

59. In combination, a carrier, a plurality of downwardly-pressed key stems, means 35 for normally retaining said stems in an elevated position, means for releasing one or more key stems, means for rotating said carrier upon the release of a stem, and means engaging said released stem operated during 40 the rotation of said carrier to return said released stem to its elevated position.

60. In combination, a horizontal shaft, a carrier mounted thereon, a cam shaft, a plurality of downwardly-pressed key stems, 45 means for retaining said stems in an elevated position, means for releasing one or more of said stems, means for rotating said carrier upon the release of a stem, a plurality of cams mounted on said cam shaft, and 50 connections between said cam shaft and said carrier shaft to engage a cam with a released key stem to return the same to its elevated position.

61. In a calculating machine, the combination of a plurality of figure wheels, a sector associated with each figure wheel and normally disconnected therefrom, a rack meshing with each sector, means for locking said sectors and figure wheels, and means 55 for advancing said racks to rotate said figure wheels.

62. In a calculating machine, the combination of a plurality of figure wheels, a sector associated with each figure wheel and normally disconnected therefrom, a rack 60

meshing with each sector, a fork mounted on said sector, means for engaging said fork with said figure wheel, and means for advancing said racks to rotate said figure wheels.

70

63. In a calculating machine, the combination of a plurality of figure wheels, a sector associated with each figure wheel and normally disconnected therefrom, a rack meshing with each sector, means for locking said sectors and figure wheels and a spring-pressed gear meshing with each rack to advance the same to rotate said figure wheels.

75

64. In a calculating machine, the combination of a plurality of figure wheels, a sector associated with each figure wheel and normally disconnected therefrom, a rack meshing with each sector, means for locking said sectors and said figure wheels, means 80 for advancing said racks to rotate said figure wheels, and means for returning said racks to their original position.

85

65. In a calculating machine, the combination of a plurality of figure wheels, a sector associated with each figure wheel and normally disconnected therefrom, a rack meshing with each sector, a fork mounted on said sector, means for elevating said fork into engagement with said figure wheel, and means 95 for advancing said racks to rotate said figure wheels.

90

66. In a calculating machine, the combination of a plurality of figure wheels, a sector associated with each figure wheel and normally disconnected therefrom, a rack meshing with each sector, a fork mounted on said sector, a frame associated with said forks, means for elevating said frame to engage each fork with its figure wheel, and means 100 for advancing said racks to rotate said figure wheels.

100

67. In a calculating machine, the combination of a plurality of figure wheels, a sector associated with each figure wheel and normally disconnected therefrom, a rack meshing with each sector, means for locking said sectors and figure wheels, means for elevating said locking means into engagement with said figure wheels, and means for advancing said racks to rotate said figure wheels.

110

68. In a calculating machine, the combination of a plurality of figure wheels, a sector associated with each figure wheel and normally disconnected therefrom, a rack meshing with each sector, means associated with each sector for locking said sectors and figure wheels, a frame associated with said locking means, means moving said frame to connect said sectors and figure wheels, and means advancing said racks to rotate said figure wheels.

115

69. In a calculating machine, the combination of a plurality of figure wheels, a 120

125

130

rack associated with each figure wheel, connections between each rack and its figure wheel normally disconnected from the latter, means for locking said connections to said figure wheels, and means for advancing said racks to rotate said figure wheels.

70. In a calculating machine, the combination of a plurality of figure wheels, a rack associated with each figure wheel, connections between each rack and its figure wheel normally disconnected from the latter, locking means mounted on each of said connections, means moving said locking means into engagement with said figure wheels, and means for advancing said racks to rotate said figure wheels.

71. In a calculating machine, the combination of a plurality of figure wheels, a rack associated with each figure wheel, connections between each rack and its figure wheel normally disconnected from the latter, locking means mounted on each of said connections, means elevating said locking means into engagement with said figure wheels, and means for advancing said racks to rotate said figure wheels.

72. In a calculating machine, the combination of a plurality of figure wheels, a rack associated with each figure wheel, connections between each rack and its figure wheel normally disconnected from the latter, locking means mounted on each of said connections, a frame engaging said locking means, means moving said frame to engage said locking means with said figure wheels, and means for advancing said racks to rotate said figure wheels.

73. In a calculating machine, the combination of a plurality of figure wheels, a rack associated with each figure wheel, connections between each rack and its figure wheel normally disconnected from the latter, locking means associated with said connections and figure wheels, a cam shaft, means operated upon the rotation of said shaft for moving said locking means into engagement with said figure wheels, and means advancing said racks to rotate said figure wheels.

74. In a calculating machine, the combination of a plurality of figure wheels, a rack associated with each figure wheel, connections between each rack and its figure wheel normally disconnected from the latter, locking means associated with said connections and figure wheels, a movable frame associated with said locking means, a cam shaft, means operated upon the rotation thereof to elevate said frame to lock said connections and figure wheels together, and means for advancing said racks to rotate said figure wheels.

75. In a calculating machine, the combination of a plurality of figure wheels, a rack

associated with each figure wheel, connections between each rack and its figure wheel normally disconnected from the latter, a frame, means for moving the same, means operated by said frame for locking said connections and figure wheels together, and means for advancing said racks to rotate said figure wheels.

76. In a calculating machine, the combination of a plurality of figure wheels, a rack associated with each figure wheel, connections between each rack and its figure wheel normally disconnected from the latter, a lock for said figure wheels, means locking said connections and figure wheels together and simultaneously removing said figure wheel lock, and means advancing said rack to rotate said figure wheels.

77. In a calculating machine, the combination of a plurality of figure wheels, a rack associated with each figure wheel, connections between each rack and its figure wheel normally disconnected from the latter, a lock bar normally engaging said figure wheels, means locking said connections and figure wheels together and simultaneously removing said lock bar, and means advancing said racks to rotate said figure wheels.

78. In a calculating machine, the combination of a plurality of figure wheels, a rack associated with each figure wheel, connections between each rack and its figure wheel normally disconnected from the latter, means for locking said connections and figure wheels together, a movable frame engaging said locking means, a lock for said figure wheels carried by said frame, means moving said frame to lock said connections and figure wheels together and simultaneously removing said lock, and means advancing said racks to rotate said figure wheels.

79. In a calculating machine, the combination of a plurality of figure wheels, a rack associated with each figure wheel, connections between each rack and its figure wheel normally disconnected from the latter, means for locking said connections to said figure wheels, means for advancing said racks to rotate said figure wheels, and means returning said racks to their normal position.

80. In a calculating machine, the combination of a plurality of figure wheels, a rack associated with each figure wheel, a slide carried by each rack and normally moving therewith, and means carried by said figure wheels disengaging said slides and racks to permit of a movement of the latter independent of said slides to rotate one or more of said figure wheels a single space.

81. In a calculating machine, the combination of a plurality of figure wheels, a rack associated with each figure wheel, a slide

associated with each rack, a pawl mounted on said rack engaging said slide, a lever associated with each slide, and means carried by said figure wheels engaging said levers and disengaging said racks and slides to permit of movement of said racks independent of said slides to rotate one or more of said figure wheels a single space.

82. In a calculating machine, the combination of a plurality of figure wheels, a rack associated with each figure wheel, a driving gear for advancing each rack to rotate said figure wheels, a shaft, a plurality of gears mounted thereon one meshing with each driving gear, and means rotating said shaft to revolve said driving gear to return said racks to their normal position.

83. In a calculating machine, the combination of a plurality of figure wheels, a rack associated with each figure wheel, a driving gear for advancing each rack to rotate said figure wheels, a shaft, a plurality of gears mounted thereon one meshing with each driving gear, means mounted on said shaft and preventing movement of said racks by said driving gears, means rotating said shaft in one direction to permit of forward movement of said racks and in the opposite direction to return said racks to their normal position.

84. In a calculating machine, the combination of a plurality of figure wheels, a rack associated with each figure wheel, a driving gear for advancing each rack to rotate said figure wheels, a shaft, a plurality of loose gears mounted thereon one meshing with each driving gear, holding means on said shaft engaging said loose gears and preventing movement of said racks, means rotating said shaft in one direction to permit of forward movement of said racks and engaging said loose gears and holding means upon rotation of said shaft in the opposite direction to return said racks to their normal position.

85. In a calculating machine, the combination of a plurality of figure wheels, a rack associated with each figure wheel, a driving gear for advancing each rack to rotate said figure wheels, a shaft, a plurality of loose gears mounted thereon one meshing with each driving gear, holding means on said shaft engaging said loose gears and preventing movement of said racks, a cam shaft, a sector driven therefrom and rotating said first-mentioned shaft in one direction to permit of forward movement of said racks and in the opposite direction to engage said loose gears, and holding means to return said racks to their normal position.

86. In a calculating machine, the combination of a plurality of figure wheels, a rotating carrier, rotating mechanism for each of said wheels movable in line with the axis

of the carrier, a series of rows of normally 65 inoperative stop pins mounted on said carrier, means for rendering one or more of said stop pins operative, means for advancing said rotating mechanism into contact with said operative stop pins, and means 70 for automatically returning said stop pins to their normally inoperative position after the advance movement of said rotating mechanism.

87. In a calculating machine, the combination of a plurality of figure wheels, a rotating carrier, rotating mechanism for each of said wheels movable in line with the axis of the carrier, a series of rows of normally 80 inoperative stop pins mounted on said carrier, means for rendering one or more of said stop pins operative, means for advancing said rotating mechanism into contact with said operative stop pins, means for automatically returning said stop pins to 85 their normally inoperative position after the advance movement of said rotating mechanism, and means automatically returning said stop pins to their normally inoperative position prior to the advance 90 movement of said rotating mechanism.

88. In a calculating machine, the combination of a plurality of figure wheels, a rotating carrier, rotating mechanism for each of said wheels movable in line with the axis of 95 the carrier, a series of rows of normally inoperative stop pins mounted on said carrier, means for rendering one or more of said stop pins operative, means for advancing said rotating mechanism into contact with 100 said operative stop pins, means for automatically returning said stop pins to their normally inoperative position after the advance movement of said rotating mechanism, and manually operated means for returning 105 said stop pins to their normally inoperative position prior to the advance movement of said rotating mechanism.

89. In a calculating machine, the combination of a plurality of figure wheels, a rotating carrier, independent rotating mechanism for each of said wheels movable in line with the axis of said carrier, a series of rows of normally 110 inoperative stop pins mounted on said carrier, means for rendering one or more of said stop pins operative, means for retaining said pins in their operative position, means for advancing said rotating mechanism into contact with said operative stop pins, and a plunger automatically movable in line with the axis of rotation of said carrier and engaging said retaining means to release said operative stop pins. 115

90. In a calculating machine, the combination of a plurality of figure wheels, a rotating carrier, independent rotating mechanism for each of said wheels movable in line with the axis of said carrier, a series of rows 120

of normally inoperative stop pins mounted on said carrier, means for rendering one or more of said stop pins operative, means for retaining said pins in their operative position, means for advancing said rotating mechanism into contact with said operative stop pins, a plunger automatically movable in line with the axis of rotation of said carrier and engaging said retaining means to release said operative stop pins, and means moving said plunger prior to the advance movement of said rotating mechanism to release said operative stop pins.

91. In a calculating machine, the combination of a plurality of figure wheels, a rotating carrier, independent rotating mechanism for each of said wheels movable in line with the axis of said carrier, a series of rows of normally inoperative stop pins mounted on said carrier, means for rendering one or more of said stop pins operative, means for retaining said pins in their operative position, means for advancing said rotating mechanism into contact with said operative stop pins, a plunger movable in line with the axis of rotation of said carrier into engagement with said retaining means to release said operative stop pins, and means for manually moving said plunger to release said operative stop pin or pins.

92. In a calculating machine, the combination of a plurality of figure wheels, a rotating carrier, independent rotating mechanism for each of said wheels movable in line with the axis of said carrier, a series of rows of normally inoperative stop pins mounted on said carrier, means for rendering one or more of said stop pins operative, means for retaining said pins in their operative position, means for advancing said rotating mechanism into contact with said operative stop pins, a plunger automatically movable in line with the axis of rotation of said carrier and engaging said retaining means to release said operative stop pins, means moving said plunger prior to the advance movement of said rotating mechanism to release said operative stop pins, and means for manually operating said plunger to release said operative key stops.

93. In a calculating machine, the combination of a plurality of figure wheels, a rotating carrier, independent rotating mechanism for each of said wheels movable in line with the axis of said carrier, a series of rows of normally inoperative stop pins mounted on said carrier, means for rendering one or more of said stop pins operative, means for retaining said pins in their operative position, means for advancing said rotating mechanism into contact with said operative stop pins, a plunger, means for manually operating said plunger to release said operative stop pins, means for render-

ing said plunger inoperative, and connections between said last-mentioned means and said manually-operated means for rendering said plunger operative upon the operation of said manual means.

94. In a calculating machine, the combination of a plurality of figure wheels, a rack associated with each figure wheel, connections between each rack and its figure wheel normally disconnected from the latter, means for locking said connections to said figure wheels, and means subsequently advancing said rack to rotate said figure wheels.

95. In a calculating machine, the combination of a plurality of figure wheels, a rack associated with each figure wheel, connections between each rack and its figure wheel normally disconnected from the latter, means engaging and locking said figure wheel against rotation, means locking said connections to said figure wheels and simultaneously disengaging said locking means subsequently advancing said racks to rotate said figure wheels, means for returning said racks to their original position, means unlocking said connections and figure wheels, and means engaging said lock with said figure wheels.

96. In a calculating machine, the combination of a plurality of figure wheels, a unison pin provided on each wheel, a rack associated with each figure wheel, connections between said racks and wheels normally disconnected from the latter, means advancing said racks, means carried by said connections engaging said unison pins to limit the forward movement of said racks, means locking said connections and racks together at the end of said forward movement of the racks, and means returning said racks to their normal position.

97. In a calculating machine, the combination of a plurality of figure wheels, a unison pin provided on each wheel, a rack associated with each figure wheel, a sector meshing with each rack associated with each figure wheel but normally disconnected therefrom, means advancing said racks, means carried by said sectors engaging said unison pins to limit the forward movement of said racks, means locking said sectors and racks together at the end of said forward movement of the racks, and means returning said racks to their normal position.

98. In a calculating machine, the combination of a plurality of figure wheels, a unison pin mounted on each wheel, independent rotating mechanism for each figure wheel normally disconnected therefrom, a rotating carrier, a plurality of normally inoperative stop pins carried thereby, means for rendering one or more stop pins operative, means for advancing said racks, means

carried by said rotating mechanism engaging said unison pins to limit the movement of said racks, means automatically releasing said stop pins prior to the forward movement of said racks, means locking said wheels and racks together at the end of the forward movement of the latter, and means returning said racks to their normal position.

10 99. In a calculating machine, the combination of a plurality of figure wheels, independent rotating mechanism for each wheel normally disconnected therefrom, a unison pin carried by each wheel, means carried by said rotating mechanism for engagement with said pins to limit the movement of said mechanisms, means advancing said rotating mechanisms in their disconnected condition, means returning said rotating mechanisms in their disconnected condition, and printing mechanism operated at the end of the advance movement of said rotating mechanisms.

100. In a calculating machine, the combination of a plurality of figure wheels, independent rotating mechanism for each wheel normally disconnected therefrom, an unison pin carried by each wheel, means carried by said rotating mechanism for engagement with said pins to limit the movement of said mechanisms, means advancing said rotating mechanisms in their disconnected condition, means returning said rotating mechanisms in their disconnected condition, a lock engaging said figure wheels and preventing rotation thereof during the forward and backward movement of said rotating mechanisms, and printing mechanism automatically operated at the end of the advance movement of said rotating mechanisms.

101. In a calculating machine, the combination of a plurality of figure wheels, independent rotating mechanism for each wheel normally disconnected therefrom, a carrier, a plurality of normally inoperative stop pins carried thereby, means for rendering one or more stop pins operative, means for releasing said operative stop pins, means for rendering said releasing means inoperative, a unison key, connections between said key and said releasing means for rendering the latter operative upon movement of said key, unison pins carried by said figure wheels, and means carried by said rotating mechanisms and engaging said pins to limit the movement of said racks.

102. In a calculating machine, the combination of a plurality of figure wheels, independent rotating mechanism for each wheel normally disconnected therefrom, a carrier, a plurality of normally inoperative stop pins carried thereby, means for rendering one or more stop pins operative, means for releasing said operative stop pins, means for ren-

dering said releasing means inoperative, a sub-total key, connections between said key and said releasing means for rendering the latter operative upon movement of said key, unison pins carried by said figure wheels, and means carried by said rotating mechanisms and engaging said pins to limit the movement of said racks.

103. In a calculating machine, the combination of a plurality of figure wheels, independent rotating mechanism for each wheel normally disconnected therefrom, a carrier, a plurality of normally inoperative stop pins carried thereby, means for rendering one or more stop pins operative, means for releasing said operative stop pins, means for rendering said releasing means inoperative, a unison key, connections between said key and said releasing means for rendering the latter operative upon movement of said key, unison pins carried by said figure wheels, means carried by said rotating mechanisms and engaging said pins to limit the movement of said racks and means operated upon depression of said unison key for moving said racks.

104. In a calculating machine, the combination of a plurality of figure wheels, independent rotating mechanism for each wheel normally disconnected therefrom, a carrier, a plurality of normally inoperative stop pins carried thereby, means for rendering one or more stop pins operative, means for releasing said operative stop pins, means for rendering said releasing means inoperative, a sub-total key, connections between said key and said releasing means for rendering the latter operative upon movement of said key, unison pins carried by said figure wheels, means carried by said rotating mechanisms and engaging said pins to limit the movement of said racks, and means operated upon depression of said sub-total key for moving said racks.

105. In a calculating machine, the combination of a plurality of figure wheels, independent rotating mechanism for each wheel normally disconnected therefrom, a unison pin carried by each wheel, means carried by said rotating mechanisms for engagement with said pins to limit the movement of said mechanisms, a unison key and means operated thereby to advance said rotating means in their disconnected position into engagement with said pins.

106. In a calculating machine, the combination of a plurality of figure wheels, independent rotating mechanism for each wheel normally disconnected therefrom, a unison pin carried by each wheel, means carried by said rotating mechanisms for engagement with said pins to limit the movement of said mechanisms, a sub-total key and means operated thereby to advance said rotating means

in their disconnected position into engagement with said pins.

107. In a calculating machine, the combination of a plurality of figure wheels, independent rotating mechanism for each wheel normally disconnected therefrom, means for locking said wheels and mechanism, a rotating carrier, a plurality of rows of normally inoperative stop pins carried thereby, means for rendering one or more of said stop pins operative, means for automatically releasing said operative stops, a cam shaft, a cam mounted thereon and effecting the operation of said locking means, a second cam effecting the operation of said releasing means, and means operated to rotate said cam shaft.

108. In a calculating machine, the combination of a plurality of figure wheels, independent rotating mechanism for each wheel
20 normally disconnected therefrom, means for locking said wheels and mechanism, a rotating carrier, a plurality of rows of normally inoperative stop pins carried thereby, means for rendering one or more of said stop pins
25 operative, means for automatically releasing said operative stops, a cam shaft, a sleeve mounted thereon, a cam mounted on said sleeve controlling the operation of said locking means, a second cam controlling the operation of said releasing means, a key, means
30 operated thereby for shifting said sleeve to bring said cams in operative position, and other means operated thereby to rotate said cam shaft.

35 109. In a calculating machine, the combination of a plurality of figure wheels, independent rotating mechanism for each wheel normally disconnected therefrom, means for locking said wheels and mechanism, a rotating carrier, a plurality of rows of normally inoperative stop pins carried thereby, means for rendering one or more of said stop pins operative, means for automatically releasing said operative stops, a cam shaft, a sleeve 40 mounted thereon, a cam mounted on said sleeve controlling the operation of said locking means, a second cam controlling the operation of said releasing means, a key, means operated thereby for shifting said sleeve to 45 bring said cams in operative position, other means operated thereby to rotate said cam shaft, and means associated with said sleeve for preventing rotation thereof during the 50 shifting movement.

55 110. In a calculating machine, the combination of a plurality of figure wheels, rotating mechanism for each wheel normally disconnected therefrom, means for locking said wheels and mechanism, a rotating carrier, a
60 plurality of rows of normally inoperative stop pins carried thereby, means for rendering one or more of said stop pins operative, means for automatically releasing said operative stop pins, a cam shaft, a sleeve
65 mounted thereon, a cam mounted on said

sleeve controlling the operation of said locking means, a second cam controlling the operation of said releasing means, a key, means operated thereby for shifting said sleeve to bring said cam in operative position, other means operated thereby to rotate said cam shaft, and means associated with said sleeve for preventing rotation thereof during the shifting movement. 70

111. In a calculating machine, the combination of a plurality of figure wheels, independent rotating mechanism for each of said wheels, a cam shaft, connections therebetween and said rotating mechanisms for controlling the movement of the latter, a motor, a counter shaft, an electro-magnet mounted thereon normally disconnected from connections between said shafts, and means for energizing said electro-magnet to rotate said cam shaft. 75
80
85

112. In a calculating machine, the combination of a plurality of figure wheels, independent rotating mechanism for each of said wheels, a cam shaft, connections therebetween and said rotating mechanisms for controlling the movement of the latter, a motor, a magnetic clutch between said motor and cam shaft, and means mounted on said cam shaft for operating said clutch. 90

113. In a calculating machine, the combination of a plurality of figure wheels, independent rotating mechanism for each of said wheels, a cam shaft, connections therebetween and said rotating mechanisms for controlling the movement of the latter, a motor, a magnetic clutch between said motor and cam shaft, a multiple lever member mounted loosely on said cam shaft, a claw engaging said member to prevent rotation of said cam shaft, connections between said member and clutch, and means disengaging said claw from said member and operating said clutch to rotate said cam shaft. 95 100 105

114. In a calculating machine, the combination of a plurality of figure wheels, independent rotating mechanism for each figure wheel, a key and means operated by said key engaging the rotating mechanism of the last wheel to prevent movement thereof. 110

115. In a calculating machine, the combination of a plurality of figure wheels, a rack for each wheel, means for moving said rack to rotate said wheels, a key and means operated upon the depression of said key and engaging the rack of the last wheel to prevent movement thereof. 115
120

116. In a calculating machine, the combination of a plurality of figure wheels, a rack for each wheel, the last rack being provided with a notch, means for moving said racks to 125 rotate said wheels, a key and a projection carried thereby engaging said notch upon depression of said key to prevent movement of said rack.

117. In a calculating machine, a plurality 130

of figure wheels, a carrier, a plurality of rows or normally inoperative stop pins carried thereby, means for rendering one or more of said pins operative, means for limiting the rotation of said figure wheels by said operative stop pins, a plunger automatically operated to release said operative stop pins, a lever connected to said plunger, and means for moving said lever to render said plunger 10 inoperative.

118. In a calculating machine, a plurality of figure wheels, a carrier, a plurality of rows of normally inoperative stop pins carried thereby, means for rendering one or 15 more of said pins operative, means for limiting the rotation of said figure wheels by said operative stop pins, a plunger automatically operated to release said operative stop pins, a pivoted lever connected to said plunger, and means for disconnecting said lever 20 from said plunger to render the latter inoperative.

119. In a calculating machine, a plurality of figure wheels, a carrier, a plurality of 25 rows of normally inoperative stop pins carried thereby, means for rendering one or more of said pins operative, means for limiting the rotation of said figure wheels by said operative stop pins, means for automatically releasing said stop pins, two independent key-operated means for disconnecting 30 releasing means, and connections between said keys whereby one key, if depressed, is released when the other is depressed.

120. In a calculating machine, a plurality of figure wheels, a carrier, a plurality of rows of normally inoperative stop pins carried thereby, means for rendering one or 40 more of said pins operative, means for limiting the rotation of said figure wheels by said operative stop pins, means for automatically releasing said stop pins, key-operated means for disconnecting said releasing means, key-45 operated means for restoring said releasing means, and connections between said keys whereby one is released if in a depressed position, when the other is depressed.

121. In a calculating machine, a plurality of 50 figure wheels, a carrier, a plurality of rows of normally inoperative stop pins carried thereby, means for rendering one or more of said pins operative, means for limiting the rotation of said figure wheels by said 55 operative stop pins, means for automatically releasing said stop pins, key-operated means for disconnecting said releasing means, two independent key-operated means for restoring said releasing means, and connections 60 between said keys whereby any one is released if in a depressed position when any other is depressed.

122. In a calculating machine, the combination of a plurality of figure wheels, inde-

pendent rotating mechanism for each figure 65 wheel, a carrier, a plurality of rows of normally-inoperative stop pins mounted thereon, key mechanisms for rendering one or more of said stops operative, an escapement for said carrier, escapement-operating means 70 normally actuated upon the depression of a key mechanism, a power shaft, means for disconnecting said escapement-operating means from said escapement and connecting same with said power shaft whereby upon 75 the depression of a digit key mechanism the machine is tripped and said rotating mechanisms are automatically brought into engagement with said operative stops a plurality of times.

123. In a calculating machine, the combination of a plurality of figure wheels, independent rotating mechanism for each figure wheel, a carrier, a plurality of rows of normally-inoperative stop pins mounted thereon, key mechanisms for rendering one or more of said stops operative, an escapement for said carrier, escapement-operating means normally actuated upon the depression of a key mechanism, a power shaft and 90 means for connecting said escapement-operating mechanism with said power shaft, whereby said power shaft rotates a predetermined number of times upon the depression of a predetermined key stem. 95

124. In a calculating machine, the combination of a plurality of figure wheels, independent rotating mechanism for each figure wheel, a carrier, a plurality of rows of normally-inoperative stop pins mounted thereon, key mechanisms for rendering one or more of said stops operative, an escapement for said carrier, escapement-operating means normally actuated upon the depression of a key mechanism, a power shaft and 100 means for connecting said escapement-operating mechanism with said power shaft whereby said power shaft rotates a predetermined number of times upon the depression of a predetermined key stem, and means for 105 automatically operating the carrier escapement after said predetermined rotation of said power shaft. 110

125. In a calculating machine, a plurality of figure wheels, means for rotating the same, a plurality of slides normally disconnected from said rotating means, and means for engaging said slides and rotating means.

126. In a calculating machine, a plurality of figure wheels, means for rotating the same, a plurality of spring-pressed slides normally out of engagement with said rotating means, means shifting said slides into engagement with said rotating means, and means automatically shifting said slides 125 out of engagement with said rotating means.

127. In a calculating machine, a plurality of figure wheels, a plurality of racks for

rotating said wheels, a plurality of slides normally disconnected from said racks, and means automatically shifting said slides into and out of engagement with said racks.

5 128. In a calculating machine, a plurality of figure wheels, a plurality of racks for rotating said wheels, a plurality of slides normally disconnected from said racks, a multiplication key, and connections therebetween and said slides whereby they are shifted into the path of movement of said racks.

10 129. In a calculating machine, a plurality of figure wheels, a cam shaft associated therewith, a plurality of slides, and means operated from said cam shaft for moving one of said slides one step upon each revolution of said cam shaft.

15 130. In a calculating machine, a plurality of figure wheels, a cam shaft associated with, a plurality of slides, means operated from said cam shaft for moving one of said slides one step upon each revolution of said cam shaft, and means automatically shifting 20 said operating means to move the next slide.

25 131. In a calculating machine, a plurality of figure wheels, a cam shaft associated therewith, a plurality of slides, means operated from said cam shaft for moving one of said slides one step upon each revolution of said cam shaft, an escapement, and connections 30 between said operating means whereby the latter are shifted to move the next slide.

35 132. In a calculating machine, the combination of a plurality of figure wheels, independent rotating mechanism for each wheel, means for limiting the movement of said rotating mechanism, a plurality of movable type-bars normally disconnected from 40 said rotating mechanism, a hammer for each type-bar, retaining means for each of said hammers, means connecting said rotating mechanism and type-bars whereby the latter move with the former and disengage 45 said retaining means, and means releasing the hammers associated with the type-bars that have been moved.

50 133. In a calculating machine, the combination of a plurality of figure wheels, independent rotating mechanism for each wheel, means for limiting the movement of said rotating mechanism, a plurality of vertically movable type-bars normally disconnected from said rotating mechanism, a hammer for each type-bar, retaining means for each of said hammers, means connecting said rotating mechanism and type-bars whereby the latter move with the former and disengage 55 said retaining means, means releasing the hammers associated with the type-bars that have been moved.

60 134. In a calculating machine, the combination of a plurality of figure wheels, independent rotating mechanism for each

wheel, means for limiting the movement of 65 said rotating mechanism, a plurality of vertically movable type-bars normally disconnected from said rotating mechanism, a pivoted hammer for each type-bar, a pivoted dog retaining each hammer in its normal 70 position, means connecting said rotating mechanism and type-bars whereby the latter move with the former and disengage said pivoted dogs, and means releasing the hammers associated with the type-bars that have 75 been moved.

135. In a calculating machine, the combination of a plurality of figure wheels, independent rotating mechanism for each wheel, means for limiting the movement of 80 said rotating mechanism, a plurality of movable type-bars normally disconnected from said rotating mechanism, a hammer for each type-bar, retaining means for each of said hammers, means connecting said rotating 85 mechanism and type-bars whereby the latter move with the former and disengage said retaining means, a cam engaging said hammers, a cam shaft, and means operated therefrom for rotating said cam to release 90 the hammers associated with the type-bars that have been moved.

136. In a calculating machine, the combination of a plurality of figure wheels, independent rotating mechanism for each 95 wheel, means for limiting the movement of said rotating mechanism, a plurality of movable type-bars normally disconnected from said rotating mechanism, a hammer for each type-bar, retaining means for each of said 100 hammers, means connecting said rotating mechanism and type-bars whereby the latter move with the former and disengage said retaining means, a shaft, a cam mounted thereon engaging said hammers, a fixed 105 member and a loose gear mounted on said shaft, a sector meshing with said gear and means operating said sector to rotate said shaft and cam through said fixed member and releasing the hammers associated with 110 the type-bars that have been moved.

137. In a calculating mechanism, the combination of a plurality of figure wheels, independent rotating mechanism for each wheel, means for limiting the movement of 115 said rotating mechanism, a plurality of movable type-bars normally disconnected from said rotating mechanism, a hammer for each type bar, retaining means for each of said hammers, means connecting said rotating 120 mechanism and type-bars whereby the latter move with the former and disengage said retaining means, a shaft, a cam mounted thereon engaging said hammers, a fixed member, a loose gear and a retaining 125 member mounted on said shaft, a sector meshing with said gear and means operating said sector to release said retain-

- ing means and rotating said shaft and cam through said fixed member and releasing the hammers associated with the type-bars that have been moved.
- 5 138. In a calculating machine, the combination of a plurality of figure wheels, independent rotating mechanism for each wheel, means for limiting the movement of said rotating mechanism, a plurality of vertically movable type-bars, means separating and guiding said type-bars in their movement, a vertically-movable rack engaging each type-bar normally disconnected from said rotating mechanisms, means connecting 10 said racks and rotating mechanisms whereby the former move with the latter.
139. In a machine of the character described, the combination of a set of accumulator wheels, a sector associated with each 20 wheel, reciprocating members engaging said sectors to rotate said wheels, a second set of accumulator wheels, normally disconnected from said first set, and means engaging said two sets to simultaneously rotate the 25 same.
140. In a machine of the character described, the combination of a set of accumulator wheels, a sector associated with each wheel and normally disconnected therefrom, 30 reciprocating members engaging said sectors, a second set of accumulator wheels normally disconnected from said sectors, means engaging said sectors and second set of wheels, and means advancing said reciprocating members to rotate said second set of 35 wheels.
141. In a machine of the character described, the combination of a set of accumulator wheels, a sector associated with each 40 wheel and normally disconnected therefrom, means engaging said sectors and wheels, reciprocating members engaging said sectors and wheels, reciprocating members engaging said sectors, a second set of accumulator 45 wheels normally disconnected from said sectors, means engaging said sectors and second set of wheels, and means advancing said reciprocating members to rotate both sets of wheels.
- 50 142. In a machine of the character described, the combination of a set of accumulator wheels, a sector associated with each wheel and normally disconnected therefrom, reciprocating members engaging said sectors, a second set of accumulator wheels normally disconnected from said sectors, means engaging said sectors and second set of 55 wheels, means advancing said reciprocating members to rotate said second set of wheels, and means carried by one set of wheels for limiting the degree of rotation of the other set.
143. In a machine of the character described, the combination of a set of accumulator 60 wheels, a pin carried by each wheel, a rotating mechanism for said wheels, dogs carried by said mechanism, a second set of accumulator wheels, and means advancing said rotating mechanism until said dogs and pins contact to limit the movement of said second set of wheels.
144. In a machine of the character described, the combination of a set of accumulator wheels, a second set of accumulator wheels normally disconnected from said primary wheels, means engaging said sets of wheels to rotate one set from the other, means for carrying tens for one set of wheels initiated when the two sets of wheels are connected, and means for disengaging said sets of wheels and completing the operation of carrying tens.
145. In a machine of the character described, the combination of a set of accumulator wheels, a second set of accumulator 85 wheels, a rack normally engaging each wheel in said second set, means disengaging said racks and wheels and engaging the two sets of wheels, means rotating one set of wheels from the other, and means for carrying tens 90 for one set of wheels operating to initiate the carrying of tens when said sets of wheels engage each other and completing the carrying of tens when said second set of wheels engages said racks.
146. In a calculating machine, a plurality of figure wheels, means for rotating the same, a plurality of slides normally disconnected from said rotating means, means 95 for engaging said slides and rotating means, an eraser key, and means operated thereby for returning said slides to their original positions.
147. In a calculating machine, a plurality of figure wheels, a cam shaft associated 100 therewith, a plurality of slides, means operated from said cam shaft for moving one of said slides one step upon each revolution of said cam shaft, an eraser key, and means operated thereby for returning said slides 105 to their original positions.
148. The combination of a rotatable carrier; a succession of rows of stops thereon substantially parallel to the axis of rotation; keys for setting the stops to represent numbers; and figure wheel mechanism including reciprocating elements movable approximately parallel to the axis of rotation of the carrier into contact with set stops to actuate the figure wheels under control of the latter.
149. The combination of a rotatable carrier; a succession of rows of stops thereon substantially parallel to the axis of rotation; keys for setting the stops to represent numbers; and figure wheel mechanism including reciprocating rods movable approximately 115 parallel to the axis of rotation of the car-

rier into contact with set stops to actuate the figure wheels under control of the latter.

150. The combination of a rotatable carrier; a succession of rows of stops thereon substantially parallel to the axis of rotation; keys for setting the stops to represent numbers; and figure wheel mechanism including reciprocating elements movable approximately parallel to the axis of rotation of the carrier to coact with set stops to actuate the figure wheels under control of the latter.

151. In a calculating machine, the combination of a plurality of figure wheels, rotating means therefor, a cam shaft, a sleeve thereon and a plurality of cams mounted on said sleeve, connections between said rotating means and cams, a lever, means operated thereby to shift said sleeve to bring appropriate cams into engagement with said connections, and connections between said lever and cam shaft.

152. In a calculating machine, the combination of a plurality of figure wheels, rotating means therefor, a cam shaft, a plurality of cams mounted thereon, connections between said rotating means and cams, an indicator lever, means operated thereby to set the parts to shift said cams, a lever, means operated thereby for shifting said cams, and connections between said lever and said cam shaft.

153. In a calculating machine, the combination of a plurality of figure wheels, rotating means therefor, a cam shaft, a plurality of cams mounted thereon, connections between said rotating means and cams, an indicator lever, a cam movable therewith to set the parts to shift said cams, a lever, and connections therebetween and said cam shaft.

154. In a calculating machine, the combination of a plurality of figure wheels, rotating means therefor, a cam shaft, a plurality of cams mounted thereon, connections between said rotating means and cams, an indicator lever, an unison stem and a subtotal stem, a lever, means connected therewith and operated by said indicator lever for engaging said unison or sub-total stem, and connections between said lever and said cam shaft.

155. In a calculating machine, the combination of a plurality of figure wheels, rotating means therefor, a cam shaft, a plurality of cams mounted thereon, connections between said rotating means and cams, a lever, connections between said lever and said cam shaft, printing mechanism, and means operating the same from said lever.

156. In a calculating machine, the combination of a plurality of figure wheels, rotating means therefor, a cam shaft, a plurality of cams mounted thereon, connections between said rotating means and cams, a

lever, printing mechanism, an indicator lever, means operated thereby to set the parts to shift said cams and to connect said printing mechanism and lever, and means operated by said lever for shifting said cams, and operating said printing mechanism.

70

157. In a calculating machine, a plurality of figure wheels, a cam shaft, a plurality of cams, connections between said cams and said figure wheels, means for shifting said cams varying distances, a manually operated means governing said shifting action, a lever, and connections between said lever and said cam shaft for tripping the latter.

75

158. In a calculating machine, a plurality of figure wheels, a cam shaft, a plurality of cams, connections between said cams and said figure wheels, means for shifting said cams varying distances, a manually operated cam governing said shifting action, a lever, and connections between said lever and said cam shaft.

80

159. In a calculating machine, the combination of a plurality of figure wheels, a cam shaft, a plurality of cams mounted thereon, connections between said cams and said figure wheels, means for shifting said cams varying distances, printing mechanism, manually operated means governing the shifting of said cams and the operation of said printing mechanism, a lever, and connections between said lever, said cam shaft and said printing mechanism for controlling the operation of the same.

90

160. In a calculating machine, the combination of a plurality of figure wheels, a second set of wheels, means for engaging said sets and rotating one set from the other, a cam shaft, connections between said cam shaft and one set of wheels, a lever, printing mechanism, means automatically operating the same when said lever is actuated during the engagement of said sets of wheels, and connections between said lever and cam shaft whereby the latter is tripped.

100

161. In a calculating machine, the combination of a plurality of figure wheels, a second set of wheels, means for engaging said sets and rotating one set from the other, a cam shaft, connections between said cam shaft and one set of wheels, a lever, printing mechanism, a printer key, means connecting the same to said lever whereby printing is effected when the latter is operated, and connections between said lever and cam shaft whereby the latter is tripped when the former is actuated.

105

162. In a calculating machine, the combination of a plurality of figure wheels, a second set of wheels, means for engaging said sets and rotating one set from the other, a cam shaft, connections between said cam shaft and one set of wheels, a lever, printing mechanism, a printer key, cam

110

115

120

125

mechanism operated to connect said printer key and lever when said sets of wheels are in engagement, and connections between said lever and cam shaft whereby the latter is tripped.

163. In a calculating machine, the combination of a plurality of figure wheels, a second set of wheels, means for engaging said sets and rotating one set from the other, a cam shaft, connections between said cam shaft and one set of wheels, a lever, printing mechanism, a printer key, cam mechanism manually operated to connect said printer key and lever when said sets of wheels are in engagement, and connections between said lever and cam shaft whereby the latter is tripped.

164. In a calculating machine, the combination of a plurality of figure wheels, a second set of wheels, means for engaging said two sets, and separating means normally preventing such engagement, a lever, an indicating mechanism, and means operated thereby for connecting said separating means and lever whereby the former are moved when the latter is actuated.

165. In a calculating machine, the combination of a set of accumulator wheels, a second set of accumulator wheels, separating means preventing one set engaging the other set, a cam, connections between said cam and said separating means, means for moving said cam to withdraw said separating means, and means for rotating one set of wheels from the other.

166. In a calculating machine, the combination of a set of accumulator wheels, a second set of accumulator wheels, a pivoted lever engaging one set and preventing its engagement with the other set, a cam, connections between said cam and lever, means moving said cam to withdraw said lever, and means for rotating one set of wheels from the other.

167. In a machine of the character described, the combination of a set of accumulator wheels, a pin carried by each wheel, rotating mechanism for said wheels, dogs carried by said mechanism, a second set of accumulator wheels, means advancing said rotating mechanism until said dogs and pins contact, and means moving said dogs out of the path of said pins.

168. In a machine of the character described, the combination of a set of accumulator wheels, a pin carried by each wheel, rotating mechanism for said wheels, dogs carried by said mechanism, a second set of accumulator wheels, means advancing said rotating mechanism until said dogs and pins contact to limit the movement of said second set of wheels, and means automatically moving said dogs out of the path of said pins.

169. In a machine of the character described, the combination of a set of accumulator wheels, a pin carried by each wheel, rotating mechanism for said wheels, dogs carried by said mechanism, a second set of accumulator wheels, means advancing said rotating mechanism until said dogs and pins contact, and pivoted levers automatically operated to move said dogs out of the path of said pins.

170. In a machine of the character described, the combination of a set of accumulator wheels, a pin carried by each wheel, rotating mechanism for said wheels, dogs carried by said mechanism, a second set of accumulator wheels normally disconnected from the first set, and means engaging said two sets of accumulator wheels and simultaneously moving said dogs out of the path of movement of said pins.

171. In a machine of the character described, the combination of a set of accumulator wheels, a second set of accumulator wheels, separating means holding said sets normally disconnected, a normally disconnected printing mechanism, and means simultaneously removing said separating means and throwing said printing mechanism into operative relation with the machine.

172. In a machine of the character described, the combination of a set of accumulator wheels, a second set of accumulator wheels, separating means holding said sets normally disconnected, a normally disconnected printing mechanism, and cam-controlled mechanism simultaneously removing said separating means and throwing said printing mechanism into position to be operated.

173. In a calculating machine, the combination of a normally disconnected printing mechanism, a printer key for shifting said mechanism into operative relation with the machine, a lever, a rotatable shaft, means connecting said printer key and said lever, and connections between said lever, shaft and printing mechanism whereby the latter is operated when said lever is actuated.

174. In a calculating machine, the combination of a normally disconnected printing mechanism, a printer key adapted to be depressed to shift the said mechanism into position to be operated, a rotatable shaft, connections between said shaft and said mechanism, and means maintaining said key in its depressed position whereby all the operations of the machine are printed.

175. In a calculating machine, the combination of a normally disconnected printing mechanism, a printer key adapted to be depressed to shift said mechanism into position to be operated, a rotatable shaft, con-

nections between said shaft and said mechanism, a second key, and connections between said keys whereby depression of said second key maintains said printer key in its depressed position and all of the operations of the machine are printed.

5 In testimony whereof I have signed this

specification in the presence of two subscribing witnesses.

ALFRED S. McCASKEY.
